UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 23, 1922. Serial No. 596,179.

* *To all whom it may concern:*

Be it known that I, SAMUEL B. WILLIAMS, Jr., a citizen of the United States, residing at Brooklyn, in the county of Kings, State of New York, have invented certain new and useful Improvements in Telephone-Exchange Systems, of which the following is a full, clear, concise, and exact description.

This invention relates broadly to telephone exchange systems and more particularly it has to do with telephone exchange systems of the class wherein automatic switching apparatus is employed, either entirely or in part for the establishment of conversational connections.

One of the principal objects of the invention is to improve telephone systems of this character by the use of a more economical form of switching medium, by providing a more efficient and flexible disposition of lines and trunks, by the allotment of important parts of the system to the common use of trunks and switches, reducing the holding time of common equipment, and eliminating complicated and unreliable devices heretofore employed, and to increase generally the efficiency and serviceability of such systems.

Another object of this invention is a telephone exchange system having a new and improved organization of recording and controlling equipment for exercising a quick and reliable control over the selective switching devices.

A feature of the invention relates to a system in which connections are built up over a series of selective switching stages, with a selection controlling device for each stage common to the switches thereat, and wherein a recording mechanism, which receives the wanted designation from the calling party, is arranged to cooperate with the selection controlling devices at the different stages to selectively operate said switches.

Another feature relates to a system of this character wherein the particular recording mechanism which responds to the calling party and stores the wanted designation is connected to the selection controlling device, which is common to a number of such recording mechanisms and also common to all switches at a given stage, for setting one of said switches and then is connected similarly to another selection controlling device at a

succeeding stage to set one of the switches thereat.

A further feature of the invention relates to the provision of means for transferring a part of the designation on the recording mechanism to the common selection controlling device at one stage and then transferring another part of the designation to the common controlling device at a succeeding stage for setting the selective switches.

A further feature of the invention relates to a translating mechanism which acts upon the designation record received from the recording mechanism to bring about selection at the switching stage and also to determine the requirements of the particular class of call involved.

A still further feature relates to an arrangement whereby the common selection controlling device, by means of a circuit extending through contacts of the selector switch, determines the talking and supervisory characteristics of the trunk leading in to such switch.

As a still further feature of invention there is provided at the final switch a testing link which is common to a number of talking links, interposed between the incoming trunks and outgoing lines, and which serves to test the condition of a called line.

Another feature relates to the provision, in a system where a group of trunks are accessible to a number of switches, of means for varying the point at which a test is begun in such group in accordance with which one of said switches is being used for the connection.

Still other and further features and advantages of the invention will be more fully understood from the descriptions given hereinafter and also from the appended claims.

The drawing, which constitutes a part of the disclosure, illustrates, partly in diagrammatic manner and partly in detail, the circuits and apparatus forming a telephone exchange system embodying the principles and features of the invention. In order to further illustrate the invention, switches of the coordinate type are employed, such as shown in the British patent to Western Electric Company, Limited, No. 183,438, accepted September 6, 1923. While a telephone exchange system of the character herein dis-

closed is capable of handling the various classes of calls, giving the different types of service, and is designed to meet the usual requirements found in commercial telephone practice, the drawing in the present case has been limited to exclude many of these well-known features and shows only so much of the entire system as is necessary to a comprehensive understanding of the invention involved. Considering the system as capable of establishing local or intraoffice connections and distant or interoffice connections, the drawing may be divided into two main sections, as illustrated in Figs. 39 and 40. Fig. 39 is a diagram of the manner in which the several sheets of the drawing should be arranged to show the equipment at the central office employed in the establishment of local connections. Fig. 40 is a diagram showing the manner in which the several sheets of drawings should be arranged to illustrate the circuits and apparatus for the establishment of interoffice connections. Comparing these two figures it will be seen that to account for a distant or interoffice call, all that is necessary is to substitute Figs. 26, 29, 30, 28, 27, 31, 32 and 33 for Figs. 19, 23, 24, 20, 22 and 21.

Fig. 1 is a partial showing of one of the coordinate line switches illustrating the manner in which calling subscribers' lines are connected, through link circuits, to idle outgoing trunks. This figure also discloses a step-by-step allotter switch for allotting the outgoing trunks for use in succession.

Fig. 2 shows in detail one of the trunks leading from the line switch which terminates in a first group selector, or district selector as it will be called hereinafter, also of the coordinate type. This figure also shows in a diagrammatic manner a second one of these trunks.

Fig. 3 shows a sender selector switch of the coordinate type for attaching an idle recording mechanism or sender with the trunks, such as the one leading from the line switch to the district selector. This figure also illustrates a step-by-step allotter switch similar to the one shown in Fig. 1 for allotting the recording mechanisms in succession for use.

Figs. 4, 5, 6, 7, 8, 9 and 10 represent one of the several recording mechanisms or senders.

Fig. 4 shows the receiving circuit where the incoming impulses from the subscriber's dial are received on counting relays to be recorded on the registers.

Fig. 5 illustrates the circuits for controlling the operations of the sender in their proper sequence and also for determining the character of these operations in accordance with the class of the call undergoing extension.

Fig. 6 shows the equipment used for trans-

mitting code impulses to distant offices in the case of interoffice connections and other controlling mechanism.

Fig. 7 illustrates the code registers for recording the office designations which are represented by the first three letters or characters. 70

Fig. 8 shows the registers of the recording mechanism which receive the thousands and hundreds numerical designations. 75

Fig. 9 illustrates the tens and units registers which receive the corresponding digits of the wanted number.

Fig. 10 illustrates three registers similar to those above mentioned which may receive so three additional sets of impulses for determining the setting of switches in a distant station, such as a private branch exchange, and which also serve for party line designations. 85

Fig. 11 shows a portion of the district selector switch in which the trunks incoming from the line switch terminate on vertical rows of contacts. Two outgoing trunks leading to succeeding switches are also illustrated, these trunks appearing in different groups on the vertical rows of the switch. 90

Figs. 12, 13 and 14 illustrate a selection controlling device, or district marker, as it will be called hereinafter, common to a plurality of district switches, such as the one shown in Fig. 11. 95

Fig. 12 shows the circuits for controlling the sequential operations of the marker.

Fig. 13 shows the numerical registers which are operated in accordance with the settings of sender registers to determine selection at the district switches, and also to determine the class of the call undergoing extension in order that this latter information may be transferred back to the sender. 100

Fig. 14 shows a testing equipment which is common to several district selector switches and also connecting devices for connecting the testing equipment with the desired selector switch. 110

Fig. 15 shows a connector for connecting the district marker device with any one of the several recording senders, such as the one shown in Figs. 4 to 10, inclusive. 115

Figs. 16 and 17 illustrate circuit connections leading from the recording sender to the district marker connector in Fig. 15.

Fig. 18 shows two of the trunk circuits outgoing from the district selector switch in Fig. 11. 120

Fig. 19 shows a portion of a group selector switch of the coordinate type in which terminate certain of the trunks outgoing from the district selector switch. This figure also shows a number of trunks outgoing from the group selector. 125

Fig. 20 shows one of a plurality of coordinate connector switches similar in construction to the other switches above men- 130

tioned, and in which terminate on vertical rows of contacts the trunk circuits outgoing from the group selector switches. There are also shown a number of subscribers' lines which terminate in contacts on the outgoing vertical rows.

Figs. 21, 22 and 23 illustrate a selection controlling device, which will be referred to hereinafter as a line marker, and which 10 serves in common a number of group selector and connector switches, such as those shown in Figs. 19 and 20.

Fig. 21 shows the controlling circuits and apparatus for governing the sequential operations of the line marker.

Fig. 22 illustrates the marker registers and translating devices for determining selection at the connector switch together with certain testing elements.

20 Fig. 23 shows a testing equipment common to a number of group selector switches together with connector devices for associating said equipment with any one of these switches.

25 Fig. 24 shows a line marker sender connector by means of which the marker device shown in Figs. 21, 22 and 23 may be connected with any one of the recording sender mechanisms.

30 Fig. 25, together with Figs. 16 and 17, show circuit connections extending from the recording sender to the line marker connector.

Fig. 26 illustrates a portion of a second 35 coordinate selector switch, hereinafter to be referred to as the office selector, in which terminate on vertical rows of contacts certain of the trunks leading from the district selector switch in Fig. 11.

40 Fig. 26 also shows an outgoing trunk which leads to a distant office.

Figs. 27, 28 and 29 illustrate a selection 45 controlling device or office marker which is common to a number of office selector switches and is similar in many respects to the district marker.

Fig. 30 shows an office marker sender connector whereby the office marker device may be connected to any one of the recording 50 sender mechanisms, such as the one illustrated in Figs. 4 to 10, inclusive.

Fig. 31 illustrates a manual operator's position in a distant office and shows one of the trunks incoming from the office selector 55 switch at the mechanical office terminating in an operator's cord. This figure also shows a called subscriber's line terminating in the manual office.

Fig. 32 shows the control circuits of a 60 relay call indicator located at the manual operator's position.

Fig. 33 shows the relay registers and display lamps of the call indicator.

Fig. 34 is a schematic drawing of the 65 exchange system.

Fig. 35 is a diagram illustrating the disposition of the trunks between the group selector switches and the connector switches.

Fig. 36 is a perspective view showing the construction and operation of the type of 70 switching mechanism employed in this system.

Figs. 37 and 38 are details of the switch structure.

Figs. 39 and 40 show the manner in which 75 the several sheets of drawing should be arranged.

General description of the system and its Organization.

80

In telephone exchange systems heretofore where machine switching apparatus is used for building up conversational connections, it has been the general practice to employ selective switching devices of the progressively movable type. Within this broad classification there are many and various forms of mechanical switches including step-by-step switches, continuously moving switches, switches propelled by gravity, 85 springs, pneumatic power and other types. There are also various ways of connecting these switches in the system for controlling their movement, such as the direct impulse control in which the impulses are transmitted directly to the switch to cause its operation. Another form of control is the reverting impulse method in which the switch in its motion creates impulses and reverts them to a controlling device of one kind or another. 90

In all of these different types of switches, which may be properly classified as progressive switches, an outstanding characteristic is this, that the selector operation requires that certain parts participate in movements of a considerable distance. Each time the switch is taken for use in setting up the connection, its movable elements, which comprise an appreciable portion of the entire 100 structure, must be advanced to a distance commensurate with the capacity of the switch and then again returned to normal. While switches may be constructed to operate with accuracy and dependability, they 105 are, however, subject to wear and frequently require adjustment owing to the large amount of motion incident to their setting and releasing operations.

Another important feature, which is more 110 or less inherent in a telephone exchange system employing switches of the so-called progressively operable type, is the time consumed by the switches in building up a connection and consequently the time necessary 115 to hold engaged common equipment for controlling the switches during their setting operations. It is highly desirable to reduce, as far as possible, the time required in the selective operations of the switches in set- 120

130

ting up a connection, and it is also very desirable, especially where common controlling equipment of an expensive character is used, to reduce to a minimum the time necessary to hold this equipment engaged in connection with any one call.

The telephone system herein disclosed, incorporating the features of the present invention, employs an improved form of selective switching medium and consists of a novel organization of controlling circuits and apparatus, whereby certain desirable features are realized which, in systems of the prior art, have been unobtainable or else obtained with difficulty and at the sacrifice of economy or other important factors. One of the chief characteristics of the present case is the use of a selective switch of the coordinate type, together with an improved circuit controlling organization, whereby the switch is controlled in its selecting operations. Primarily, the switch comprises a plurality of link circuits which are interposed between a number of incoming lines or trunks and a number of outgoing lines or trunks, in such a manner that a comparatively large number of connections may be established between incoming circuits and outgoing circuits in a speedy manner, and with the use of comparatively little apparatus. As will be explained more fully hereinafter when a description of the structure of the switch is taken up, the connections are effected by means of coordinate bars jointly operated under the control of operating magnets.

Due to the arrangement of the controlling circuits for the switch, whether employed as a non-numerical selecting switch or as a numerical selecting switch, it is possible to obtain a plurality of coexisting connections through any switch unit by the repeated use of the same switch bars, while the amount of apparatus necessary to maintain the established connections is only a fractional part of that used in building up the connection. This latter feature is obtainable, among other reasons, due to the fact that the switch is of the non-progressive type. In addition to a saving in operating time over progressive switches, such as those above mentioned, the coordinate structure has other advantages. For example, the amount of motion necessary for the active parts to take in establishing connections is very slight, and consequently lighter and less expensive parts may be used. The terminal or contact banks in fact may comprise plain ordinary bare wires, the connection being effected by a slight movement of the active terminal wires bringing them into contact with the passive terminal wires.

Another important characteristic of the present system, and one which is in part made possible by the operating time of the

switch, is the allotment of the selection controlling mechanisms or markers to the common use of a large number of switches. Owing to the fact that the selective operation at the switch is practically instantaneous, the controlling equipment, which is associated with the switch only during the interval that connection is being established, is held for a very short interval in connection with any one call and then immediately reverts to the common use of other switches.

A system of this type possesses many other points of advantage. The coordinate switch employed herein permits of great flexibility in the distribution and use of trunk groups. Trunk groups may be varied in size or they may be shifted from one location to another in the switch with slight changes and without disturbing the remainder of the system. Other desirable features will become apparent as the description of the system progresses.

With particular attention to Fig. 34, a description will now be given of the general organization of the system. The total number of subscribers' lines in the office, of which two lines 3400 and 3401 are illustrated, appear as calling lines in a number of line switches 3402 and 3403. The trunks outgoing from the several line switches have an appearance each in sender selector switches. Two trunks 3404 and 3405 are shown, one leading from each of the line switches 3402 and 3403 and these trunks appear in the sender selector switch 3406 which is also a switch of the coordinate type. It is obvious, of course, that as many line switches may be provided as necessary and the same is true of the sender selectors. The circuits 3407 and 3408, outgoing from the sender selector switch, lead each to a different sender or recording mechanism. Two of these senders 3409 and 3410 are diagrammatically illustrated.

Also the trunks outgoing from the line switches appear as incoming trunks in the coordinate district selector switches. There will be a number of these district selectors and each will accommodate a plurality of trunks. Trunks may be distributed among the district selectors in any suitable manner. In the diagram two district selectors 3411 and 3412 are shown and the trunks 3404 and 3405 appear respectively in these switches. The outgoing trunks at the district selectors are divided into numerical groups and lead to succeeding switches. Since each trunk incoming to any one of the district selectors must have access to any of the outgoing numerical groups, the outgoing trunks are multiplied to appear in all of the district switches. For example, trunk 3415 has an appearance in district selector 3411 and a similar numerical appearance in the district selector 3412 and would also have an appear-

ance in the remaining district switches. Likewise, the outgoing trunk 3416, which belongs to another numerical group, appears correspondingly in all of the district selector switches.

There is a selection controlling device or marker 3413 assigned in common to a plurality of the district selectors. This device is known as the district marker and may be 10 temporarily associated with any one of the district switches over which a connection is being extended. The marker 3413 is connectible by means of a sender connector 3414 with any one of the senders 3409, 3410, 15 etc. The record of the wanted designation is received from the calling subscriber's dial and recorded on one of the recording senders. Thereafter, the sender containing the record is associated with the district marker 20 3413 and the district marker is at the same time associated through a connecting device 3430 with the particular district selector switch into which leads the trunk involved. The marker cooperates with the recording 25 sender to determine the selection at the district switch.

The trunk groups outgoing from the district selectors may lead in various directions and serve for the several different classes of 30 calls required in actual practice. In the diagram of Fig. 34 two different types of calls are illustrated. For handling local calls, that is, a call made to a subscriber's line in the same office, there are provided groups of 35 trunks at district selectors 3411, 3412 leading to group selector switches, one of which, 3417, is illustrated. One trunk for such a group, namely, trunk 3415, is shown extending to and incoming at the group selector 40 3417. Trunks which comprise numerical groups outgoing from the group selectors 3417 extend and appear as incoming trunks in connector switches, one of which switches, 3419, is illustrated. A single trunk 3418 interconnecting the group selector and connector switches is shown.

In addition to the district marker, there is also provided for local calls a selection 50 controlling mechanism or line marker 3420. The marker 3420 is common to a plurality of group selector switches and connector switches. Line marker 3420 is arranged to be connected through the line marker connector 3427 to any one of the common recording senders 3409 and 3410. The function 55 of the line marker is to cooperate with the recording sender for determining the selections at the group selector switch and connector switch.

60 Calls to distant exchanges may be routed over trunks connected to the district selector switch or over trunks connected to the office selector, which in turn are connected to the district selector switch. In this illustration it is assumed the trunks are connected

to the office selector switch. When a call is received at the local office intended for a distant exchange, the district selector switch chooses a group of trunks leading to the proper one of a number of office selector 70 switches. One of these trunks 3416 is shown which extends and appears as an incoming trunk in one of a number of office selector switches 3421. The office selector switches are located in the local office and their function is to select groups of trunks outgoing to distant offices. The trunks incoming to the office selector switches are multiplied to have a corresponding appearance in each of the several district selectors. The outgoing 75 trunks at the office switches are divided into convenient groups, each group leading to a different distant office, or, if necessary, several groups may extend to the same distant office. While these distant offices may be of several different types, only one is illustrated in the diagram. This is a manual office equipped with call indicator positions. The group of trunks leading from the office selector switches to the distant manual office 80 is represented by the single interoffice trunk 3425. The trunk 3425 leads to the manual office and terminates at the call indicator operator's position in a cord circuit 3426 by 85 means of which she may complete the connections to called subscribers' lines. Also located at the operator's position is a call indicator 3424 which is positioned by impulses transmitted from the originating mechanical office. 90

Like the district selectors, the office selector switches are provided with a common office marker 3422 which is connectible to any one of the office selectors and is also connectible through an office marker connector 3423 to any one of the several recording senders 3409, 3410, etc. 105

Having given a general outline of the system, a more specific description will now be made of the circuit arrangements together with an explanation of the structure and operation of the various parts of the apparatus. 110

The line switches, sender selector switches, 115 district and office selector switches, group selector and connector switches, such as those shown respectively in Figs. 1, 3, 11, 26, 19 and 20, the structure of which will be described in detail hereinafter, are, in their general mechanical operation, the same as the switch disclosed in the British patent to Western Electric Company, Limited, No. 183,438, accepted September 6, 1923. The subscribers' lines appear in the line switches 120 as seen in Fig. 1 of the drawing, there being a plurality of lines assigned to each vertical row. For example, the two lines shown, 101 and 102, occupy the vertical row 110 in the line switch 100. The line 101 has contacts 125 for connection with each of a plurality of 130

link circuits, or horizontal links as they will be referred to hereinafter. Two of these horizontal links 106 and 107 are shown and there may be any suitable number of similar links to which the line 101 has access. The line 102 in the same vertical row or group has access to the horizontal links 108, 109, etc. of a different horizontal group. In like manner other lines of the same vertical group 110 have access to other horizontal groups not shown in the drawing. There may also be any desired number of vertical rows of groups of lines, one other of which, group 111, is illustrated. The outgoing trunks, two of which, trunks 114 and 115, are illustrated, occupy each a complete vertical row intersecting all horizontal links in the line switch. The trunk 114 occupies the vertical row 112, while the trunk 115 occupies the vertical row 113.

The contact controlling bars assigned to the vertical rows 110, 111, 112 and 113 are operated by the respective magnets 116, 117, 118 and 119, while the contact controlling bars for the horizontal links 106, 107, 108 and 109 are operated by their respective operating magnets 124, 125, 153 and 154.

For determining the selection of an idle outgoing trunk an allotter switch 143 is employed. The allotter 143 is an ordinary step-by-step switch which is automatically advanced from position to position to find and allot an idle trunk for use.

The trunks outgoing from the line switches lead to district selector switches and appear therein as incoming trunks, each occupying a full vertical row of terminals. There may be any suitable number of these trunks depending upon the number and capacity of the line switches and they may be distributed in any convenient manner among a plurality of district selectors. The two particular trunks 114 and 115 shown extend from the line switch 100 and appear as incoming trunks in the district selector switch 1100. The trunk 114 is shown in detail with its controlling equipment in Fig. 2 and occupies the vertical row 1108 in the district selector switch 1100. The trunk 115 has its controlling equipment in Fig. 2 illustrated schematically and this trunk occupies the vertical row 1109 of the district selector 1100. It will be understood that other trunks leading from the line switch 100 may appear in the district selector 1100 or in any suitable number of other similar district selector switches and also that similar trunks coming from other line switches may be distributed likewise.

The trunks extending between the line switches and district selectors also have appearances in a sender selector switch 300. These trunks appear in the sender selector switch in substantially the same fashion as

the subscribers' lines appear in the line switches. A plurality of trunks occupy each vertical row, each trunk being accessible to a group of horizontal link circuits. For example, the trunks 114 and 115 appear in the vertical row 301 of the sender selector 70 switch, the trunk 114 having access to the group of links containing links 307 and 308 and the trunk 115 having access to a group containing the links 305 and 306. In like manner other trunks would occupy other incoming vertical rows. One of these, the row 302, is illustrated. The outgoing circuits from the sender selector switch lead to separate recording sender mechanisms and each such circuit employs a full vertical 75 row of contacts. The circuit 332 occupies the vertical row 304, being accessible to all horizontal links in all groups and leads to the particular recording sender shown in the drawing. Another outgoing circuit 333 80 occupies the vertical row 303 and would lead to another sender similar to the one illustrated. There will be as many of these circuits as there are senders required for the system. A step-by-step allotter switch 326 85 is associated with the sender selector switch and serves to keep an idle recording sender continually allotted for use.

The sender selector switch 300 is a non-numerical switch and operates on substantially the same principle as the line switches. The purpose of the sender selector is to connect any one of the trunks appearing therein, to which a subscriber's line has been extended over the line switch, to the allotted 90 idle recording sender. The operation of the sender selector is initiated due to the presence of a call on any one of its trunks.

The purpose of the recording sender mechanisms, such as the one shown in Figs. 4 to 10 inclusive, is to receive and record the designation of a wanted line. To this end the sender is associated with the calling line through the sender selector switch and responds to a series of impulses transmitted 95 by the calling subscriber and sets up the record thus received on a series of registers. The receiving portion of the sender is shown in Fig. 4 and consists of a series of counting relays 413, 414, 415, etc. which respond 100 to impulses transmitted over the calling subscriber's line.

The first three registers 700, 701 and 702 consist each of a plurality of relays and are set by the counting relays in Fig. 4 in response to the first three series of impulses to establish a record of the office designation. The next four registers 800, 801, 900 and 901 are set similarly by the counting relays to establish the thousands, hundreds, 105 tens and units designations. These registers likewise consist of a plurality of relays. The last three registers 1000, 1001 and 1002 110

are also positioned by the counting relays in the event it is necessary to transmit extra series of impulses for controlling the automatic switches in a distant station such as 5 a private branch exchange. These registers may also serve in connection with the selection of ringing current on party lines, which require a suffix designation to distinguish the stations on the line.

10 The circuit shown in Fig. 5 consists for the most part of relays and its function is to cooperate with other parts of the system for determining the various kinds of information necessary for the sender to have, such, 15 for example, as class indications, and to govern the sequential operations of the sender accordingly.

The circuit arrangement illustrated in Fig. 6 is for controlling the operation of the 20 sender under given conditions and serves particularly for transmitting codes of impulses for transferring designations to distant offices in case of interoffice calls.

25 The district selector switches as above observed receive trunks incoming from the line switches and it is their function to connect these trunks in a group selecting action to outgoing trunks. The arrangement of the outgoing trunks on the district selector switches, the grouping of these trunks and the number of the trunks per group depend upon the character of the system and the kind of service to be rendered. This selector switch must have access to various types 30 of outgoing trunks such as those leading to succeeding switches for making local connections, trunks leading to office switches which in turn have access to interoffice trunks and also to trunks leading to the different 35 supervisory and special operators' positions. In order to enable a better understanding of the appearance of the groups of trunks in the district switches, a brief explanation will be given of the numerical 40 grouping of the subscribers' lines as regards 45 the establishment of local connections.

Assuming for the purpose of illustration only that the local exchange has a capacity of 10000 subscribers' lines, these lines may 50 be divided into five terminal groups of 2000 lines. Each terminal group of 2000 lines is served by a number of group selector switches and connector switches such as those shown in Figs. 19 and 20. The district selector switches have access to trunk groups which lead directly to the switches of the terminal line groups. Hence, the several district selector switches, such as switch 55 1100, are provided each with five groups of trunks leading to the five different terminal line groups.

60 Furthermore, for the sake of illustration, it may be considered that the district selector switches are equipped with 70 horizontal

link circuits for interconnecting the incoming trunks to the outgoing trunks which are divided into two groups of 35 each. In the district selector switch 1100, three horizontal links 1103, 1104 and 1105 in the lower group 1101, and two horizontal links 1106 65 and 1107 in the upper group 1102 are illustrated. All incoming trunks such as the trunks 114 and 115 have access to all the horizontal links in both groups.

With this arrangement each of the several vertical rows 1111, 1112, 1113, 1114, etc. 70 may serve a maximum of 70 outgoing trunks, 35 in the lower group and 35 in the upper group. Depending upon the character of a particular trunk group outgoing 75 from the district selector, it may occupy all or a portion of either one of the lower or upper groups in a vertical row, or it may occupy both groups. If a small trunk group is sufficient, either the lower or the upper 80 portion of a given vertical row is sufficient, whereas for larger trunk groups a full vertical row may be utilized. While the assumption was made that the district selector switch is provided with 70 horizontal links 85 divided into two groups of 35 each, it is obvious that any required total may be employed and the division may be such as to give two or three or any required number 90 of groups.

95 Consider as an example that each of the five terminal line groups requires a group of 35 trunks outgoing from the district selector switch banks. The group of trunks leading to the first line terminal group of 100 2000 lines, which is assumed to be the one illustrated in the drawing, may occupy the lower half of the vertical row 1114 of the district selector switch 1100. The groups of trunks leading to the second and third terminal groups may occupy respectively the upper and lower halves of the vertical row 1113. The groups of trunks leading to the fourth terminal group of subscribers' lines may occupy the lower half of the vertical row of 110 1112. The group of trunks leading to the fifth terminal line group may 115 occupy the upper half of the vertical row 1112. One trunk 1129 is shown of the group leading from the district selector switch to the group selector switch 1900 associated 110 with the first group of 2000 subscribers' lines.

The vertical row 1111 of the district selector may accommodate a group which leads 120 to the office selector switches which in turn have access to trunks outgoing to distant offices. One of these trunks 1128 is shown in detail and leads to the office selector switch 125 illustrated in Fig. 26.

Since there are a number of district selector switches similar to the switch 1100 all having access to the same groups of trunks,

it is necessary that each of the several trunks have a corresponding appearance in each of the several switches. The manner in which these trunks are multiplied is 5 shown in the schematic drawing of Fig. 34.

The district marker shown in Figs. 12, 13, and 14, which is provided for the common use of a plurality of district selector switches, is a device made up almost entirely of relays. The function of the district marker is to take a portion of the record initially recorded on the sender mechanism and to use the record thus received to determine selection at the district switch 10 and to determine the class of the call being extended. Inasmuch as a plurality of the recording senders are available to calling subscribers for recording the designation, it is necessary to make provision for connecting 15 any one of these senders to the district marker allotted to the district switches that serve those calling subscribers' lines. To this end the district marker sender connector 1500 is provided. The sender connector 20 1500 comprises a plurality of multi-contact relays 1501, 1502, 1503 and 1504. Each of these relays represents a recording sender and serves when actuated to connect such 25 sender to the common district marker.

The district marker consists of, among other elements, the three relay registers 1301, 1302 and 1303. These three registers receive the three portions of the office code designation from the corresponding registers 30 700, 701 and 702 of the recording sender. The district marker also consists of a translator mechanism 1300 which is made up of a number of multi-contact relays 1305 to 1319, inclusive. The translator is operated 35 in accordance with the records on the registers 1301, 1302 and 1303 to determine the class of the call involved and to place the necessary conditions upon the class conductors 1336 for governing the operation of the 40 recording sender and for properly preparing the talking circuit for conversation.

The portion 1320 of the translator consists of multi-contact relays 1305 to 1312, inclusive, having contacts for cooperating 45 with a bank of horizontal conductors. This bank of horizontal conductors is divided into two sections 1323 and 1322. The contacts of the relays 1305, 1306, 1307, etc. which cooperate with the horizontal conductors 50 are arbitrarily wired to the class conductors 1336 in such a fashion as to give the desired number of class combinations.

The portion 1321 of the translator 1300 is made up of multi-contact relays 1313 to 55 1319 which operates under the control of registers 1302 and 1303 to select the relays 1305, 1306, 1307, etc. The register 1301 selects the relays 1308 to 1312, inclusive, whereby a potential is placed upon the corresponding 60 horizontal conductor in the section 1323.

Thus, through the cooperation of registers 1301, 1302 and 1303 and the sections 1321 and 1323 of the translator, electrical potential may be placed upon a large number of combinations of class conductors 1336. 70 While only the five multi-contact relays 1308 to 1312, inclusive, controlled by the register 1301, are shown, there would in practice be ten such relays. Furthermore, only three relays 1305, 1306 and 1307 have 75 been shown cooperating with the horizontal conductors of the section 1321, but as many other similar relays may be provided as are necessary.

Another function of the translator is to 80 cooperate with the relay register 1304, which receives the thousands record from the thousands register 800 in the recording sender, to determine group selection at 85 the district selector switch. For this purpose the contacts cooperating with the upper section 1322 of the translator bank are wired in a suitable fashion to the contacts of the thousands register relays 1304.

In addition to the elements above described the district marker includes two sets of testing relays 1400 and 1403. The set of testing relays 1403 is common to all district selector switches and also common to 90 all vertical groups of outgoing trunks on any switch. This set of testing relays comprises three relays 1427, 1428 and 1429 for testing the first horizontal link and the corresponding outgoing trunk in any vertical group 1111, 1112, etc. of the lowermost group 95 1101. It also includes relays 1430, 1431 and 1432 for testing the second horizontal link in the group 1101 and also the corresponding outgoing trunk such as the trunk 1129 100 in any vertical row of any district selector switch to which it is multiplied. The third group of three relays 1433, 1434 and 1435 similarly serve to test the third horizontal link such as the link 1105 and the corresponding outgoing trunk in any vertical 105 row. In a like fashion the set of test relays 1403 has a number of other testing relays for the remaining horizontal links in the lower group 1101 and for the corresponding 110 outgoing trunks in all vertical rows. 115

The upper set of testing relays 1436 to 1444, inclusive, are for testing the horizontal link circuits 1106, 1107, etc. of the upper group 1102 and the corresponding outgoing 120 trunks in all vertical rows on any district selector switch.

Since the testing relays 1400 and 1403 are common to all district selector switches and common to all outgoing trunk groups, it is necessary to provide some means for associating either one or the other, or both of these sets with the proper district selector switch and with the proper outgoing trunk group. For this purpose the multicontact 125 relays 1426, 1420, 1428, 1425, 1419, 1422, 130

1424, 1418 and 1421 are provided. For example, the relays 1423, 1420 and 1426 are individual to the particular district selector switch 1100 shown and when operated they 5 associate the testing relay sets 1400 and 1403 with the horizontal link circuits of that particular district selector.

In order that the testing relay sets 1400 and 1403 may also be associated with the 10 proper group of outgoing trunks at the district selector switch, the relays 1412 to 1417, inclusive, are provided. Each of these multicontact relays is individual to a particular group of trunks outgoing from the 15 district selector switch. When any one of these multicontact relays is operated, it associates the testing relays with the sleeve conductors of the trunks of the group to which it is individual for the purpose of 20 testing and selecting, any one thereof.

As hereinbefore explained, a terminal line group of 2000 lines is served by a number of group selector switches and a number of connector switches. For the particular terminal group illustrated, one group selector 25 1900 and one connector 2000 are shown in the drawing. For the purpose of explanation it will be assumed that each of the connector switches 2000 has a capacity for 30 250 called subscribers' lines. These 250 lines may be divided into twenty-five groups of ten lines, each group occupying a vertical row on the connector switch. The group to which the line 2031 belongs occupies the 35 vertical row 2006. Two other rows 2007 and 2008, each of which likewise accommodates a ten line group, are shown.

Assume also that the connector switch 40 2000 has a vertical capacity for seventy horizontal links the same as the district selector switch in Fig. 11. With seventy links in the structure and ten lines per vertical group, each line may, therefore, be accessible to seven different links. Of these seven 45 links six are used for the establishment of talking connections, while the remaining link is employed for testing purposes. Referring to the figure, two of the ten groups of horizontal links 2001 and 2002 are illustrated, only a portion of these being shown. The line 2031, appearing in the vertical row 50 2006, is served by the group of horizontal links 2001. Connections may be established to the line 2031 over any one of the six horizontal links 2009, 2010, etc. while the line 55 is tested over the common test link 2011.

The group of horizontal links 2001 also 60 serves corresponding lines in each of the remaining twenty-four vertical rows 2007, 2008, etc.

The second group of horizontal links 2002 65 shown serves similarly a line in each of the twenty-five ten-line groups, the connecting links 2012, 2013, etc. being used for establishing the talking connections and the

testing link 2014 being used for testing purposes.

Since each connector switch 2000 accommodates 250 subscribers' lines there will be a total of eight of these connector switches for 70 each 2000 lines. Connections are extended from the group selector switch 1900 to any one of the eight different connector switches 2000 over interconnecting trunk circuits. A group of trunks is provided between the 75 group selector 1900 and each of the eight connector switches 2000, whereby a connection incoming to a group selector may be extended to any one of the eight connector switches each serving 250 called lines. Before describing the arrangement of these trunk groups between the connector and selector switches, it will be necessary to first explain the construction of the selector switches.

There will be a suitable number of group 80 selectors 1900 for serving the terminal line group, and the trunks incoming from the district selector switches are distributed among the several group selectors. The trunk 1129, illustrated in the drawing, appears in the 85 group selector switch 1900 and occupies the vertical row 1903 having access to all horizontal links in the switch. Other trunks of the incoming group would occupy other vertical rows, two of which, 1904 and 1905, are 90 shown. Still other trunks of the incoming group will be allotted to the incoming vertical rows of the remaining group selector switches, not shown in the drawing.

Assuming that the group selector switches 100 1900 have a vertical capacity for seventy horizontal links, a convenient arrangement is to divide the total number into two groups of thirty-five links each. The lower group of 105 thirty-five links 1901 is represented by the three links 1912, 1913 and 1914, while the upper group 1902 is illustrated by two links 1910 and 1911. There being eight different connector switches in the terminal line group which must be reached from the group selector switch, the terminal bank of said group selector must be provided for eight groups of outgoing trunk circuits. One convenient method of allotting the trunk groups to the 110 terminal bank of the group selector switch is to assign the lower and upper portions of each vertical row of terminals to two different trunk groups. For instance, the group of trunks extending between the group selector 1900 and the connector 2000 comprises 115 thirty-five trunks and these trunks occupy the upper portion of the vertical row 1906 in the group selector 1900. With thirty-five trunks and thirty-five horizontal links, each trunk, therefore, has an appearance before a 120 separate horizontal link and only one. The trunk 1927 is accessible to the horizontal link 1910; the trunk 1928 is accessible to the link 1911; and so on for the remaining trunks 125 of the group.

The lower portion of the vertical row 1906 accommodates a second group of thirty-five trunks extending to other connector switches. The upper and lower portions of the vertical row 1907 accommodate two groups of thirty-five trunks leading to other connector switches. The fifth group of trunks extending to other connector switches may be assigned in like manner to the upper portion, 5 for example, of the third vertical row 1908.

Where several group selector switches similar to the switch 1900 are provided, all having access to all of the eight connector switches, it is necessary to multiple the interconnecting trunk groups to appear in all 15 of the group selectors. Considering the trunk group assigned to the upper portion of the vertical row 1906, this group would have a similar appearance in each of the total 20 number of group selectors. In other words, the trunk 1927 would be multiplied to appear in the row corresponding to the row 1906 and to be accessible to the link corresponding to the link 1910 in all of the remaining group 25 selector switches. The same would be true of all other trunks in all other groups.

Each of the five terminal line groups of 2000 lines is further provided with a line marker. The marker shown in Figs. 20, 21, 30 22 and 23 belongs to the terminal line group represented in the drawing and may be associated with any of the group selector and connector switches of that group for governing their selective operations. The line marker 35 is provided with a sender connector 2400 consisting of a plurality of multicontact relays 2401, 2402, 2405, 2406, etc. Each of the multicontact relays is allotted to a different recording sender and serves, when actuated, to 40 connect the sender to the line marker.

The line marker includes the four relay registers 2241, 2203, 2204 and 2205, which receive the thousands, hundreds, tens and units designations from the recording sender 45 after the line marker has been attached. The translator device 2200, consisting of two banks of horizontal conductors 2242 and 2243, together with a series of multicontact relays, is also provided. The thousands register relays 2211 and 2212 determine the operation of either multicontact 50 relay 2209 or multicontact relay 2210, according as the called line belongs in the first or second thousand of the terminal 55 group. The relay 2209 renders the upper bank 2242 of the translator 2200 effective, while the relay 2210 renders the lower bank 2243 effective. The hundreds register 2203 determines the selection of one of ten multicontact relays, such as 2207 and 2208, to 60 pick a group of one-hundred in either one of the two thousands. The tens register 2204 places a condition on the horizontal conductors in both banks 2242 and 2243 of 65 the translator 2200. Thus, a cooperation of

the registers 2241, 2203 and 2204 with the translator determines the selection of the vertical operating magnet of the vertical row on the connector accommodating the group of ten subscribers' lines that contains 70 the wanted line. In the drawing the three vertical magnets 2018, 2019 and 2020, corresponding to the three vertical rows 2006, 2007 and 2008 on the connector switch 2000, are shown. The selection of any one of the 75 total 250 of these vertical magnets on the eight different connector switches is accomplished, as explained, by the registers and translator 2200 of the line marker.

Inasmuch as each group of ten subscribers' lines in the vertical row has a different units designation, it is necessary to ascertain which of the ten groups of horizontal links will be used for making connection to the called subscriber's line. 80 Hence, a multicontact relay device 2430 is provided individual to the connector switch and constitutes ten multicontact relays 2027, 2028 and 2029, each of which operates to 85 associate the line marker with the group of horizontal link circuits to which it is individual. For example, multicontact relay 2027 is individual to the group of horizontal links 2002, the multicontact relay 2028 is individual to the group 2001, and so on. 90 The multicontact relays 2027, 2028 and 2029 are selected by the units register 2205 co-operating with the multicontact relay device 2201.

The marker also contains a set of testing 100 relays 2202 which are associative through the multicontact relay device 2430 with any group of horizontal links on the connector switch for testing and selecting an idle one 105 of these links to be used for establishing connection to the subscriber's line.

There are, as noted, eight different connector switches 2000 to the terminal line group, and the particular one that contains the called subscriber's line is the one that 110 will be taken in use by the line marker. In order that the line marker may be able to test the group of trunks leading from the group selector to the connector switch taken for use, it is necessary to provide some 115 means of identifying that group of trunks. This is done by the multicontact relay devices 2303, 2304 and 2305. The multicontact relays 2318, 2316 and 2314 are individual to the group of trunks leading to 120 the connector switch 2000 and they are operated whenever this connector switch is taken into use. The multicontact relays 2317 and 2313 are individual to a second group of trunks leading to another connector switch 125 and are likewise operated whenever this other connector switch is taken into use. In a similar manner there will be sets of relays for the remaining groups of trunks leading to the other connector switches. 130

The purpose of the multicontact relays, above mentioned, is to associate the set of common testing relays 2306 with the proper one of the groups of trunks interconnecting the group selector and connector switches. Since there are thirty-five trunks in each of the groups leading to the eight different connector switches, there are provided in the testing relay set 2306 thirty-five testing relays each associative with a different trunk in any one group and also with corresponding trunks in all of the remaining groups.

If it is assumed for example that there are a total of four group selector switches 1900 in a terminal group, it is then necessary to make provision for associating the line marker with a particular one of these four group selectors in which appears the trunk over which the connection has been extended from the district selector switch. To this end a multicontact relay device 2302 is employed. The multicontact relay 2307 is operated whenever the switch 1900 is taken into use. Likewise, the multicontact relays 2308, 2309 and 2310 are operated whenever the corresponding group selector switches are appropriated. Furthermore, there are provided the multicontact relay devices 2300 and 2301 which serve to associate the common testing relay set 2306 with the horizontal link circuits on the particular group selector switch determined by the multicontact relay device 2302 as the one to be used for the connection. The upper multicontact relay device 2300 associates the common testing relay set 2306 with the horizontal links in the upper section 1902 of the group selector switches. The lower multicontact relay device 2301 associates the common testing relay set with the horizontal links in the lower group 1901 of the group selector switches.

It will be understood, of course, that the dimensions and capacities of the various switches employed in this system and the size and subdivisions of the terminal line groups mentioned herein are given only as an illustration of convenience. Other capacities, groupings, arrangements and methods of assigning trunks may be used without departing from the scope of this invention.

For handling interoffice connections a group of trunks at the district selector switches 1100 is provided leading to a suitable number of office selectors 2600. It will be assumed that the group of trunks, of which one trunk 1128 is illustrated extending to the office selectors, occupies a full vertical row 1111 on the district switch 1100. The trunk 1128 appears in the office selector 2600 in the vertical row 2608 and is accessible to all horizontal links in both the lower and upper groups 2601 and 2602. Other trunks, similar to the trunk 1128, will

appear in other vertical rows of this particular office switch and also in vertical rows of other office selectors, not shown in the drawings.

The office marker shown in Figs. 27, 28 and 29 is similar, in many respects, to the district marker and is arranged in common to all of the office selector switches. A sender connector device 3000, comprising a number of multicontact relays, operates to connect the office marker to any one of the several recording sender mechanisms.

The office marker comprises three relay registers 2802, 2803 and 2804 which receive the three portions of the office code designation from the registers 700, 701 and 702 of the recording sender. These relay registers, cooperating with translator devices 2800 and 2801 determine the selection of the proper group of trunks outgoing from the office switch to the distant office. Moreover, the office marker comprises the common testing relay sets 2905 and 2906 which are associative through multicontact relay devices 2902 and 2903 with the horizontal link circuits of the particular office switch taken into use. Furthermore, the multicontact relay devices 2900 and 2901 serve to associate the common testing relay sets 2905 and 2906 with the several groups of outgoing trunks on the office switches.

The grouping and distribution of the trunks outgoing from the office switches 2600 may be taken to suit the particular traffic conditions concerned. These groups of trunks may extend to all of the various types of offices with which cooperation is required. The particular distant office illustrated in the present disclosure is a manual office equipped with a relay call indicator. Trunks leading to this office are assigned to the vertical row 2611 in the office selector switch 2600, and one such trunk 2623 is shown leading to the manual office and there terminates in the operator's cord circuit 3100. Other trunks outgoing from the office switch, such as trunk 2624 appearing in the vertical row 2612, may lead to a distant office of the full mechanical type where the connection is completed over machine switches either to called subscribers' lines or to trunks outgoing to still further offices, such as private branch exchanges.

Detailed description of the switch structure. 120

Before proceeding with a detailed description of the circuit operation, an explanation will be made of the mechanical construction of the switching device employed in this system. For this purpose reference is made to Figs. 36, 37 and 38 which are perspective and detailed views of a portion of the switching mechanism clearly illustrating the manner in which it operates. 130

Considering the terminal portion of the switch, there are provided a plurality of intermediate or horizontal link circuits 3600, 3601, consisting each of a number of plain bare wire conductors. The horizontal link 3600 includes, as shown, four conductors 3602, 3603, 3604 and 3605, and the horizontal link 3601 likewise has four conductors 3606, 3607, 3608 and 3609. As many of these horizontal links may be provided as is necessary and each may have more or less than the number of conductors actually shown. These horizontal bare wire link circuits constitute the passive or stationary part of the terminal arrangement.

Regarding the switch in the capacity of a selector, as shown in Figs. 11, 19, 20 and 26, the incoming trunks or circuits each constitute a full vertical row of movable terminals and have access to all the horizontal link circuits. Fig. 36 shows one of these incoming trunks which is made up of four conductors 3610, 3611, 3612 and 3613. This trunk has a set of movable bare wire terminal conductors 3614, 3615, 3616 and 3617 connected to the respective conductors and which extend through a window 3679 occurring in the vertical channel guide member 3663. After passing through the window 3679 the movable terminal conductors pass through respective diagonal slots 3668, 3669, 3670 and 3671 in a slideable insulating card 3666. The card 3666 is retained in the guide member 3663 and adapted to slide freely up and down therein. For supporting the card 3666 in its normal position, a spring wire 3667, firmly attached to the insulating block 3698 in the rear, extends through the window 3679 and through the lower end of the card 3666. The movable terminals 3614, 3615, 3616 and 3617 are also secured to the insulating block 3698, and with the spring support wire 3667 in its normal position these terminal wires are out of engagement with the respective wires 3602, 3603, 3604 and 3605 of the horizontal link 3600 with which they coact.

The conductors 3610, 3611, 3612 and 3613 of the incoming trunk are provided with a second set of movable wire terminals 3618, 3619, 3620 and 3621, attached to the block 3698, and which extend through a window in the guide 3663 and thence through diagonal slots in the insulating card 3672 to a point where they cooperate with the respective wires 3606, 3607, 3608 and 3609 of the next horizontal link 3601. The insulating card 3672 is supported by the flexible spring wire 3673. In like fashion, the incoming trunk conductors have a set of these movable terminals in the vertical row for every horizontal link circuit. Obviously, there will be one of these vertical rows of contacts for each trunk incoming to the switch.

In addition to the several vertical rows

of incoming circuits, each representing a single incoming trunk, there are provided a plurality of vertical rows of outgoing trunks to be fully described hereinafter. In Fig. 36, two such vertical rows of outgoing trunks are illustrated, two separate trunks in each row being shown. One of these trunks appears in the switch in the single set of movable wire terminals 3622, 3623, 3624 and 3625, secured to the insulating block 3699, and which extend through the window 3680 in the terminal guide 3664 and through diagonal slots in the sliding card 3674 to cooperate with the respective conductors of the link 3600. The other outgoing trunk in the same vertical row is represented by the movable conductors 3626, 3627, 3628 and 3629, which are also secured to the block 3699, and extend through the window 3682 and through diagonal slots in the card 3676 and cooperate with the conductors of the horizontal link 3601. One of the trunks in the second vertical row of outgoing trunks appears in the switch in the movable wire terminals 3630, 3631, 3632 and 3633, secured to the block 3901, and which extend through the window 3914 of the channel guide 3665, and thence through the slots and sliding card 3677 in cooperative relation with the conductors of the link 3600. The second outgoing trunk illustrated in this vertical row appears in conductors 3634, 3635, 3636 and 3637, extending through diagonal apertures of the card 3678 to cooperate with the conductors of the link 3601. Similarly, each vertical row of outgoing trunks has as many trunks therein as required and each trunk is provided with terminals coacting with one of the horizontal link circuits.

For operating and maintaining the terminals to establish connection through incoming trunks, links and outgoing trunks, there are provided a plurality of operating members or bars, a bar being arranged to serve each of the several vertical and horizontal rows of trunks. The vertical bar 3640 is individual to the row represented by the incoming trunk 3610, 3611, 3612 and 3613, and controls all of the movable contacts pertaining to this trunk. The next vertical bar 3641 is individual to the row of contacts belonging to the group of outgoing trunks appearing in the terminals 3622, 3623, 3624 and 3625 and 3626, 3627, 3628 and 3629. Likewise, the vertical bar 3642 is individual to the vertical row in which appear the outgoing trunks represented by the movable terminals 3630, 3631, 3632 and 3633 and 3634, 3635, 3636 and 3637. The function of these vertical bars is to prepare the contacts for operation, and after the contacts have been operated said bars may be restored ready to be taken again for preparing another set of contacts.

The horizontal operating members or

bars, two of which bars 3638 and 3639, are shown, are each individual to a corresponding one of the horizontal links 3600 and 3601. The function of these bars is to operate the sets of prepared contacts and maintain these contacts in operated condition after the vertical bars have restored to normal.

The switching device has been outlined 10 in its capacity as a selector. When desired to employ this switch as a line switch or trunk connector, as illustrated in Fig. 1, it is obvious that the incoming lines appear in the vertical rows containing the terminals 15 3622, 3623, 3624 and 3625 and 3626, 3627, 3628 and 3629 and 3630, 3631, 3632 and 3633, etc. The outgoing trunks would then appear as trunks, such as 3610, 3611, 3612 and 3613, each comprising a full vertical 20 row of trunks. Dependent upon the number of horizontal links required for serving each incoming subscriber's line, said line may be provided with a variable number of movable wire terminals for cooperating 25 with the respective corresponding links.

In the perspective view of Fig. 36, the horizontal link conductors are shown as straight bare wires in order to give clearness to the illustration. In practice, however, 30 these horizontal conductors are woven in and out among a series of vertical insulating strips to form a grid construction for the stationary portion of the terminal bank. This construction is illustrated in the details 35 of Figs. 37 and 38. A series of vertical insulating strips 3902, 3903, 3904 and 3905 are spaced at a proper distance. The horizontal link conductors are woven in and out among these vertical strips and secured 40 in any suitable manner to form a rigid structure which may be assembled and held in place in any convenient manner. Due to the sinuating disposition of the wire conductors in this grid construction, the distance 45 of each conductor from the insulating blocks 3698, 3699 and 3901 varies at different points along said conductor. This construction serves to very good advantage, as will be explained hereinafter for the purpose 50 of maintaining clean electrical contacts for the engaging wires.

Assume that it is desired to connect incoming trunk or circuit 3610, 3611, 3612 and 3613 to the outgoing trunk which appears 55 in the conductors 3634, 3635, 3636 and 3637. First, a circuit is closed for the vertical operating magnet 3645. The magnet 3645 attracts its armature 3652 which rotates the lever 3654, which in turn, bearing against the lever 3656, rotates the vertical rod 3640 60 against the action of the retractile spring 3660. In the drawing the vertical bar 3640 is shown in its normal or released position but its operating position may be understood 65 by observing the vertical rod 3641, which is

shown fully rotated by its vertical operating magnet 3646. The bar 3640, in rotating to its said position, brings the cam elements 3688 and 3685 around to a position where their camming surfaces are immediately 70 above the ends of the respective levers 3686 and 3683. These levers are secured to the horizontal bars 3639 and 3638. The relative position of a cam to its cooperating lever is illustrated in connection with the positioned vertical bar 3641. Here the cam 3691 is shown as rotated to a point where it presents its camming surface to the lever 3689, which is attached to the horizontal bar 3638. In a similar manner all other cams 80 on the vertical bar 3640, each individual to a horizontal link, are similarly positioned with respect to levers on corresponding horizontal link bars.

At the same time, subsequently, or in any desired sequence, a circuit may be closed for the vertical operating magnet 3647. The magnet 3647, through its armature 3653 and levers 3655 and 3659, rotates the vertical bar 3642 against the helical spring 3662. The bar 3642 is also shown in its normal position but when fully rotated it brings the cams 3907 and 3908 into cooperative relation with the corresponding levers 3697 and 3695 on the respective horizontal bars 3639 and 3638. 95

Thus, when the contacts of the incoming trunk and the contacts of the outgoing trunks are prepared, it is only necessary to operate the horizontal bar 3639, pertaining to the outgoing trunk, to bring about the connection. This is done by energizing the magnet 3644, which rotates the horizontal bar 3639 by attracting its armature 3649. The bar 3639 is shown in the drawing as being in its operated condition. As the bar 100 3639 rotates the levers 3686, 3692 and 3697, attached thereto, are swung upwardly. The lever 3686, on its first upward movement, encounters the inclined surface of the cam 3688 and being guided thereby is flexed to the right. Normally, the lever 3686, on rotating upwardly, would not encounter the flexible supporting spring 3673, but when flexed to the right by the cam 3688 the V shaped portion 3687 of the lever 3686 engages the flexible spring 3673. Due to this engagement the continued upward movement of the lever forces the spring 3673 upwardly, which, in turn, slides the card 3672 up in the channel member 3663. Upon 110 the initial upward movement of the card 3672, conductors 3618, 3619, 3620 and 3621, which have a slight tension, normally overcome by the stronger spring 3673, engage the corresponding horizontal conductors 115 3606, 3607, 3608 and 3609. Thus the movable conductors engage the stationary horizontal conductors at the beginning of the upward movement of the card 3672. As the card 3672 continues to move upwardly, the 120

125

130

135

diagonal slots have a camming effect on the flexible conductors whereby these conductors are moved laterally with a wiping action over the surface of the respective horizontal conductors with which they are in engagement.

Considering Fig. 38 for example, the advantage of the sinuating horizontal conductors will be readily seen. When the insulating card 3666, for example, is started in its upward movement the flexible conductor 3614 encounters the cooperating horizontal conductor 3602. As the card 3666 continues upwardly, the diagonal slot 3668 moves the conductor 3614 laterally to the right, causing it to slide or drag over the surface of the curved wire 3602. The result is that the surface of the wire 3602 is cleaned or polished for a distance equal to the stroke of the moving conductor 3614. Moreover, the moving conductor 3614 has its surface polished and cleaned over a considerable length due to the curved formation of the conductor 3602.

In a similar manner the lever 3697 encounters the cam 3907 and flexes to the right so that the V portion 3909 engages the spring 3910. The spring 3910, acting on the card 3678, causes the flexible conductors 3634, 3635, 3636 and 3637 to engage the corresponding conductors 3606, 3607, 3608 and 3609 with a wiping action. At the time the horizontal rod 3639 is rotated all other vertical bars including the bar 3641 are supposed to be in their normal condition, hence the lever 3692 on moving upwardly, fails to encounter the cam 3694 and the V shaped portion 3693 passes by without interfering with the supporting spring 3911. Likewise, all other levers on the rotating horizontal row 3639 fail to engage the corresponding card supporting springs.

Following this, the vertical magnets 3645 and 3647 may be released permitting the bars 3640 and 3642 to return to normal position. The continued energization of the horizontal magnet 3639 holds the slidable cards 3672 and 3678 in their upward positions, and thereby maintains an electrical connection between the incoming trunk 3610, 3611, 3612 and 3613 and the horizontal link 3601, and also maintains a connection between the horizontal link 3601 and the outgoing trunk appearing in conductors 3634, 3635, 3636 and 3637.

Should another connection be desired over a trunk in the same vertical row, as, for example, the trunk appearing in the wire terminals 3630, 3631, 3632 and 3633, this can be obtained by operating the second horizontal bar 3638 after having reoperated the vertical bar 3642 and after having operated another vertical bar representing another incoming trunk. The reoperation of the vertical bar 3642, controlling the same

vertical row of outgoing trunks, brings the cams 3907 and 3908 back into their operating positions. Cam 3907, in returning to its operating position, however, passes freely under the operated lever 3697, and, therefore, does not touch any of the parts involved in the establishment of the first connection, whereby no disturbance is created in the talking circuit. The cam 3908 also moves to its operated position and when the horizontal bar 3638 is subsequently rotated the lever 3695 is flexed so that the V shaped element 3696 engages the spring support 3912 and a second connection is effected between the incoming trunk, the horizontal link 3600 and between the horizontal link 3600 and the second outgoing trunk appearing in terminals 3630, 3631, 3632 and 3633 in the same vertical row or group of trunks. In a similar manner the vertical operating magnets may be released and the connection is held by the continued energization of the horizontal magnet 3643.

When it is desired to release the connection first established, for example, the horizontal magnet 3644 is simply deenergized. The spring 3651 rotates the bar 3639 to its normal position whereby the levers 3686 and 3697 permit the springs 3673 and 3910 to restore the slidable cards to their normal positions, thus disengaging the active and passive contacts. As the levers 3686 and 3697 rotate downwardly, the V shaped portions 3687 and 3909 disengage from the spring wires 3673 and 3910, whereby said levers are permitted to flex back to their normal positions.

When the connection is being released the slidable insulating card during the major part of its downward stroke causes the movable conductors to wipe over the surface of the horizontal stationary conductors which they are engaging. At the latter part of the downward movement of the card the diagonal notches engage the flexible conductors and carry them out of engagement with the horizontal stationary conductors. In this way the wiping action between the active and passive contacts of the switch is secured both during the operation and release of said active contacts.

General operation of the system.

Having hereinbefore explained the organization of the system, giving an account of the manner in which the lines and trunks are grouped, the construction and operation of the switching devices and controlling apparatus, it is believed that a brief description of the general operation involved in the extension of a connection will be helpful before proceeding with a detailed discussion. Upon the initiation of a call on a subscriber's line, such as line 101, the coordinate line switch 100 is automatically

- operated to prepare for the connection of the calling line to an idle link circuit 106, 107, etc. and to prepare for the connection of the idle link circuit to the particular 5 trunk 114, for example, that happens to be allotted at this time. At substantially the same time the line switch 100 is making preparation for the connection of the calling line to an idle outgoing trunk, the sender selector switch 300, in response to the initiation of the same call, is also making preparation for extending the allotted trunk 10
- 114 through to the particular recording sender that happens to be at this time allotted for use. While both the line switch and the sender selector are making their 15 preparations for the connections above outlined, a time interval is measured at the end of which the line switch and sender selector are operated and the prepared connections are completed. The allotter switch 143 at the line switch is advanced to find and allot a new trunk for the next call, and the allotter switch 326 likewise advances to 20 allot the next idle recording sender for use.
- The calling subscriber's line is now extended over an idle trunk to the district selector switch 1100 and also is extended through the sender selector switch 300 to the 25 idle recording sender shown in Figs. 4 to 10, inclusive. The calling subscriber manipulates his dial to transmit the first three series of impulses representing the three portions of the office code designation. The names of 30 the different offices in the exchange may be designated by abbreviations consisting of three letters and these letters are represented by series of impulses. The office code series of impulses are received on the 35 counting relays in Fig. 4 which cause the office record to be established on the three corresponding registers 700, 701 and 702.
- Following the office code the subscriber transmits, for local connection, four series of 40 impulses representing the thousands, hundreds, tens and units digits of the called line and these designations are registered on the corresponding registers 800, 801, 900 and 901.
- As soon as the three office designations 45 have been received, together with the thousands digit, the recording sender brings about a condition whereby the sender connector 1500 is operated to associate the recording sender with the district marker. As 50 soon as the district marker is associated, the office registration and the thousands registration are transferred from the registers 700, 701, 702 and 800 to the corresponding relay registers 1301, 1302, 1303 and 1304 in the 55 common district marker. During the interval that the district marker is associated with the recording sender involved in this connection, which is only a slight period of time, it is impossible for a second recording sender 60 to be attached to the district marker by
- reason of non-interfering provisions made in the connecting device 1500.
- With the office record and thousands record set up in the district marker, the translator 1300 is brought into play and the necessary indications, according to the nature of the call, are transmitted back to the recording sender to later determine its behavior during the extension of the connection. Moreover, the translator 1300, in conjunction 70 with the thousands register 1304, determines the operation of the multicontact relays shown in Fig. 14 for the purpose of connecting the common testing relays 1400 with the selected outgoing group of trunks at the district switch 1100.
- With the testing relays 1400 associated with the district selector switch 1100 to which the incoming trunk 114 extends, and with these testing relays associated with the selected group of outgoing trunks leading 75 from the district selector switch 1100, a simultaneous test is made to ascertain an idle link circuit having access to an idle trunk circuit in the said selected group. With this condition attained the district selector switch is operated and the calling subscriber's line is thus extended over the trunk 114 through the district selector switch 1100 to the trunk, such as 1129, leading to a group selector 80 switch 1900. Immediately that the connection is established the common district marker is disassociated from the district switch 1100 and also disconnected from the recording sender and may be again taken for use 85 for another call.
- At the time the district marker is disconnected from the recording sender an indication of this fact is set up in the controlling 90 circuits of said sender. At this time, or as soon thereafter as the last series of impulses has been received and recorded on the sender, a circuit is established for initiating the operation of the line marker connector 2400. The connector 2400 thereupon associates the 95 line marker individual to the terminal line group to which the connection has been extended with the recording sender upon which the record is established. Thereupon the 100 thousands, hundreds, tens and units designations are taken from the recording sender and transferred to corresponding registers in the associated line marker. The line marker now determines the selection of the group of 105 subscribers' lines containing the called line, is associated with the group selector switch 1900 into which the selected trunk from the district switch leads, tests and selects an idle trunk in the group leading from the group selector to the proper connector switch 2000, 110 tests and selects an idle horizontal link on the group selector 1900, available for the connection, and also locates an idle horizontal link in the particular horizontal group at the connector switch which has access to the 115 120 125 130

called subscriber's line. With the above functions all completed the line marker makes a test of the called subscriber's line to determine its condition. If the line is busy the 5 connector and group selector switches are released without actually establishing the connection prepared, and a busy signal condition is set up in the recording sender which thereupon causes the application of a busy 10 tone to the calling subscriber's line. The calling subscriber may release the connection by hanging up his receiver.

On the other hand if the line marker finds the called line idle it causes the group 15 selector and connector switches to establish the connection already prepared, whereupon ringing current is applied to the wanted line and the conversational circuit made ready for taking purposes. Immediately that the 20 line marker completes its test of the called line and the connection is completed, it releases, disassociating itself both from the switches of the terminal group and also from the recording sender mechanism.

25 For an interoffice call the operation of the system is generally the same up to the point where the district selector switch 1100 is operated under the control of the district marker. At this point, however, the district 30 selector switch chooses an idle trunk leading to an office selector switch, such as the office selector 2600. As soon as the idle trunk is chosen leading to the office selector, the office marker shown in Figs. 27, 28 and 29 is connected 35 through the connector device 3000 to the recording sender, which bears the wanted designation. The office code record on the register 700, 701, and 702, which was previously transferred to the district marker, 40 is now transferred to the office marker and there determines the selection of a group of trunks at the office selector switch. These trunks extend out of the office and lead to the distant called office and an idle one 45 thereof is selected by the testing equipment in the common office marker. Upon the completion of this function the office marker is disconnected from the office selector switch and also from the recording sender, thereby 50 reverting to common use.

Owing to the character of the office code 55 designation representing this particular distant called office, the translator of the district marker has ascertained the class of the call and has transmitted this information back to the recording sender. The recording sender having received indications that the call undergoing extension is one for a distant relay call indicator office, prepares itself for the transmission of series of code 60 impulses over the interoffice trunk to position the relay call mechanism in the distant office. The transmission of these impulses proceed and the call indicator shown 65 in Figs. 32 and 33 is operated to cause the

illumination of the number of the called subscriber's line 3122. The operator in the manual office completes the connection by inserting the plug into the jack of this line.

When the conversation has been completed 70 the calling subscriber, replacing his receiver on the switchhook, causes the release of the selector switches in the mechanical office and, in turn, a signal is given to the call indicator operator informing her that the 75 plug of her cord circuit may be withdrawn from the jack of the called line.

In all types of connections the recording 80 sender mechanism is released as soon as it has completed its cooperation either with the marker devices in the local office or with corresponding mechanisms in distant offices.

*Detailed operation of the system—Establish-
ment of a local full mechanical connec- 85
tion.*

A description will now be made of the details of operation in the extension of a full 90 mechanical connection from a calling subscriber's line to the line of any called subscriber in the same office. Assuming that the name of the local office is one having the abbreviation of G E R, which, with respect to the dial operation, corresponds to series 95 of 4, 3 and 7 impulses. Moreover, it may be assumed that the number of the desired subscriber's line in the local office is 1326.

*Initiation of a call and operation of the line 100
switch.*

When the calling subscriber of line 101 removes his receiver from the switch hook, a circuit is closed from battery through the winding of line relay 121, inner contact of cut-off relay 120, conductor 104, over the 105 loop of the substation, conductor 103, outer contact of relay 120 to ground. The line relay 121 energizes and closes a circuit from battery through the winding of relay 129, 110 right back contact of relay 128, conductor 110 155, left contact of relay 121, conductor 156, winding of relay 133 to ground.

The relay 129, together with the relays 115 128 and 130 included within the broken rectangle, are individual to the vertical group 120 of lines appearing in the vertical row 110 of the line switch. The two subscribers' lines 101 and 102 shown belong to this vertical group. There will be for each of the remaining vertical groups of subscribers' lines a similar set of group relays. Relay 129 is energized in the manner explained through the left contact of the line relay of any subscriber's line in the first vertical group, 125 which is the one illustrated.

Relay 129 closes a circuit from battery through the winding of relay 131, inner front contact of relay 129, conductor 156, winding of relay 133 to ground. Relay 131, 130 the function of which will be explained here-

- inafter, becomes energized. Relay 129 also closes a circuit for the group relay 130 traceable from battery through the left-hand winding of said relay 130, outer front contact of relay 129, conductor 157, left back contact of relay 135, outer right contact of relay 137, conductor 158, winding of relay 133 to ground. Relay 130 operates and closes a circuit from battery through the winding of relay 128, inner left contact of relay 130 to ground. Relay 128 energizes and opens the circuit above traced for relay 129 permitting this latter relay to become deenergized.
- When relay 130 operates it closes a holding circuit for itself as follows prior to the deenergization of relay 129: battery, through the right-hand winding and inner right front contact of relay 130, winding of relay 135, outer right back contact of relay 137 to ground over conductor 158. Relay 130 locks and relay 135 becomes energized in this circuit. Should a second call appear in the first vertical group, as, for example, on line 102, relay 129 cannot again become operated so long as the relay 128 remains energized. Relay 128 for the time being is held energized, as explained, through the inner left contact of relay 130.
- Relay 135, in operating, closes a circuit from battery through the winding of slow-to-release relay 136, inner right contact of relay 135, inner right back contact of relay 137 to ground over conductor 158. Relay 136 operates and the holding circuit for relays 130 and 135 is modified so that it now extends from battery through the right-hand winding and inner right front contact of relay 130, winding of relay 135, contact of relay 136 to the grounded conductor 158.
- Relay 130, on first energizing, closes a circuit from ground over conductor 158, outer right back contact of relay 137, left front contact of relay 135, outer right front contact of relay 130, conductor 159, winding of the vertical operating magnet 116 to battery. Magnet 116 rotates the vertical rod associated with the row 110 to prepare the switch contacts of all lines in that row for connection with the contacts of the horizontal links. The relay 135, which operates in series with relay 130 as described, closes a circuit from the grounded conductor 158, outer right contact of relay 135, left contact of relay 137, contact of slow-to-release relay 139, brush 144 of the allotter 143, which is standing in a position to allot the trunk 114, winding of the vertical operating magnet 118 to battery. Magnet 118 rotates the vertical bar belonging to the row 112 and prepares the contacts of the trunk 114 for connection with any of the horizontal link circuits. Magnet 118 also closes a circuit from battery through its winding and inner front contact, winding of relay 137, outer right front contact of relay 135 to the grounded conductor 158. This circuit, including the winding of relay 137 however, is in parallel to the circuit above traced which leads directly to ground in shunt of the winding of relay 137. Hence, the relay 137 will not operate in series with magnet 118 so long as the shunt circuit, which extends through the brush 144 of the allotter switch, remains closed.
- When the vertical magnet 116 operates it completes a circuit from ground through its contact, conductor 160, left contact of relay 134, outer left contact of relay 130, right contact of relay 121, left-hand winding of relay 122 to battery.
- Relay 122 is individual to the horizontal group of link circuits which serve the subscriber's line 101 in the vertical group 110 and the corresponding line in each of the remaining vertical groups. Similarly, the relay 123 is a horizontal group relay individual to the group of link circuits which serve the subscriber's line 102 in the vertical group 110 and the corresponding lines in all other vertical groups.
- The relay 122 is operated, as above noted, and completes a circuit from battery through its right-hand winding and right front contact, conductor 161, right back contact of horizontal group relay 123, assuming this relay is deenergized due to the fact that no line in that particular horizontal group is calling at the time, conductor 162, winding of relay 134, conductor 160 to ground at the contact of magnet 116. Thus far the vertical magnets 116 and 118 have been operated to prepare the line switch for operation but a horizontal link bar has not been actuated to connect the line to the link and the link to the allotted trunk.
- The vertical magnet 118 also closes a circuit from ground through its outer contact, conductor 151, winding of the individual trunk relay 146 to battery. Relay 146 operates and ground is extended over conductor 151 through the right contact of relay 146, brush 145, right contact of relay 140, contact and winding of the stepping magnet 138, winding of slow relay 139 to battery. The stepping magnet 138 energizes and interrupts its own circuit and thereby advances the brushes 144 and 145 of the allotter switch to their next position terminals. If the next trunk is busy the brush 145 will encounter a ground potential on the corresponding terminal and the stepping magnet 138 will continue to operate to advance the brushes through another position. This action continues until the allotter switch finally locates the first idle trunk.
- The relay 139, which also energizes in series with the stepping magnet 138, opens the shunt circuit previously traced around the winding of relay 137. Relay 137 im-

mediately operates and in so doing opens the original operating circuit of relay 135. Relay 135, however, is held, as above explained, to the front contact of the slow relay 136. 5 Relay 137 also opens the holding circuit of relay 136. Relay 136 having its circuit opened commences to release. The releasing period of the slow relay 136 is calculated to be sufficient for permitting the operation 10 of the horizontal link bar magnet of the line switch 100. During the holding period of relay 136 and following the release of relay 137, a circuit is completed from the grounded conductor 158, inner right front 15 contact of relay 137, right contact of relay 134, left back contact of relay 123, left front contact of relay 122, front contact of relay 127 (assuming the horizontal link 107 and its associated magnet 125 to be busy), back 20 contact of relay 126, winding of the horizontal magnet 124 to battery. The horizontal magnet 124 operates the rod individual to the link 106, whereby the subscriber's line 101 is connected to the link 106 and also 25 the trunk 114 is connected to said link.

The subscriber's line 101 is now connected through the line switch 100 to the trunk 114 leading to the district selector switch 1100. When this connection is effected a 30 circuit is closed from ground through the outer contact of magnet 118, test conductor 163, contacts of the trunk 114, test conductor 164 of the link 106, contacts of the line 101, conductor 105, winding of the cut-off relay 35 120 to battery. Cut-off relay 120 operates and opens the circuit of line relay 121 and this latter relay becomes deenergized. Another circuit is closed from battery through the winding of the horizontal magnet 124, 40 winding of relay 126, horizontal link conductor 164, thence to ground, as above traced, at the outer right contact of magnet 118. Magnet 124 is held but relay 126 does not operate since it is shunted by the 45 direct path to ground through relay 133.

After an interval of time the slow relay 136 becomes deenergized and in so doing opens the holding circuit of relays 130 and 135. Relay 130 opens the original energizing circuit of relay 128. If no other line in the same or in any vertical group is calling at this time the relay 131 is deenergized and relay 128 releases since it cannot lock over the circuit through the left contact of relay 50 131 and the contact of relay 132. If another call exists in the first vertical group while all other vertical groups are free from calls, relay 131 will be operated, as hereinbefore explained, and relay 132 will also be 55 operated. Under these conditions relay 128 also releases upon the deenergization of relay 130 since it cannot lock due to the fact that the left contact of relay 132 is opened.

60 Relay 136 also opens the circuit of the vertical magnet 116 and this magnet deen-

ergizes to restore the vertical rod to its normal position. Magnet 116 opens the holding circuit of the horizontal group relay 122 and relay 134. Relay 122 releases and restores the starter wire circuit in the horizontal groups so that a call may be made in the next succeeding group. Relay 122 removes the shunt from relay 126 which operates in series with magnet 124. Relay 126 70 extends the start circuit to the next horizontal trunk in the group. Relay 135, upon deenergizing, opens the above traced circuit for magnet 118 and relay 137. Magnet 118 restores the associated operating rod to its normal position and relay 137 also releases. 75 Thus the vertical group relays 129, 128 and 130, the horizontal group relay 122 and the common relays 133, 134, 135, 136, 137, 131 and 132 are again in their normal condition. The allotter switch 143 has advanced to 80 allot the next idle trunk in order. The subscriber's line 101 is extended through the line switch 100 to the district selector and this connection is maintained solely by the energization of the horizontal link magnet 124 which is held, as will be explained hereinafter, over a circuit leading to the grounded sleeve conductor 150.

Before proceeding with the operation of the sender selector switch a brief explanation will be given of the provision for taking care of simultaneous calling lines in the line switch. The prevention of interference between calling lines in a given group is accomplished substantially the same as in the British patent to Western Electric Company, Limited, No. 183,438, accepted September 6, 1923. If a plurality of subscribers belonging to the same vertical group initiate calls simultaneously, the relays 129, 130 and 128 are operated in the manner described. Due to the preferred order in which the horizontal group relays 122, 123, etc. are arranged, the subscriber's line having first choice, such for example as the line 102, will cause this horizontal group relay 123 to lock while the remaining horizontal group relays 122, etc. will immediately release, their circuit to the conductor 161 being opened by the relay 123. Therefore, 100 one subscriber's line will succeed in putting through a call and the remaining simultaneously calling lines in that vertical group will be required to wait until the horizontal group relay 123 is deenergized. 105

If two subscribers in different vertical groups of lines initiate calls simultaneously, the one in the first vertical group will succeed while the call in the second vertical group in order will be required to wait. 110 The vertical group relay 130 for example, pertaining to the first calling subscriber's line, on operating, locks, as above described, through the winding of relay 135. The corresponding vertical group relay in the sec- 115 120 125 130

- ond calling group will be energized through its left-hand winding but its locking circuit through the right-hand winding, which normally extends by way of conductor 166, is opened at the contact of relay 130. Consequently, the second vertical group relay becomes deenergized and the call in the corresponding group must wait for the first call to be satisfied. 5
- 10 Should two lines in the first vertical group 110 initiate calls simultaneously with a line in another vertical group, one call in the first vertical group will be satisfied but the second call therein would be required to 70 wait until the call in the other group had been taken care of. Due to the calling line 102, for instance, in the first vertical group having initiated a call, the relays 130, 129 and 128 are operated and the switch is prepared for extending said line to an idle trunk. Relay 128, it will be recalled, upon operating through the contact of relay 130, opens the circuit of relay 129. Moreover, relay 128 closes a holding circuit for relay 23
- 25 131 which extends over conductor 155 through the left contact of the line relay 167, and relay 131 is maintained energized after the deenergization of relay 129. As soon as the horizontal link is operated and 30 the line 102 is extended through the trunk, the cut-off relay 168 is energized in the manner explained to permit the deenergization of the line relay 167. Relay 167 opens one branch of the holding circuit of relay 131. 35
- 35 However, since another line in the same vertical group, namely line 101 is calling simultaneously, relay 131 is maintained energized in a second branch which extends through the left contact of the line relay 121 to ground. A time later when the slow relay 136 deenergizes and opens the circuit of relay 130 this relay releases and opens the original energizing circuit of relay 128. Relay 128 retains its armatures attracted by 40 means of the following circuit: battery, through the winding and left contact of relay 128, left contact of relay 131, contact of relay 132 to ground. Relay 128, by remaining energized, prevents the reenergization 45 of relay 129 in response to the call on line 101 and therefore this second line is required to wait. 50
- 50 As soon as the relay 130 releases and the call on line 102 has been taken care of, the group relay, corresponding to relay 130 of the next group containing the other calling line, is energized in series with relay 135 and this call is satisfied in exactly the same manner as that already explained. 55
- 55 Whenever a plurality of calls occur in one vertical group and no calls are present in any other vertical group, relay 129, on deenergizing, completes a circuit from ground over conductor 158, outer right back contact of relay 137, outer left back contact 60 of relay 135, conductor 157, outer left back contact of relay 129, thence in series through the outer left back contact of other group relays corresponding to relay 129, right contact of relay 131, winding of the slow-to-release relay 132 to battery. Relay 132 operates and opens the circuit previously traced which would otherwise maintain relay 128 operated by reason of the second call in the vertical group. Relay 128 thereupon becomes deenergized and another call in the same group may be satisfied by the reoperation of relay 129 in the manner above explained. 75
- 65 *Operation of the sender selector.* 80
- During the foregoing operations of the line switch, all of which take place in a very brief space of time, the sender selector switch 300 is also being operated to extend the trunk 114 to the allotted idle recording sender. Returning to the point where the vertical magnet 118 of the line switch is operated, a circuit is closed by this magnet for the relay 313 of the sender selector and may be traced as follows: battery, through the winding of relay 313, conductor 334, outer right contact of relay 230, right back contact of slow release relay 204, conductor 150, right front contact of trunk relay 146, conductor 151, right contact of magnet 118 to ground. Relay 313 operates and locks in a circuit from battery through its winding and inner left contact, conductor 335, outer left back contact of relay 201 to ground. Relay 313 completes a circuit from ground through its outer right contact, conductor 336, winding of relay 204 to battery. Relay 204, which has a slow-to-release characteristic, operates and applies ground potential to the holding or sleeve conductor 150. The application of this ground potential to the conductor 150 occurs during the period that relay 136 is still holding its armature attracted. New holding circuits are therefore prepared for the horizontal magnet 124, relays 126, 120 and 146. These circuits, instead of extending to ground at the outer right contact of magnet 118 as previously traced, may be followed in an obvious manner through the right front contact of relay 146 to the holding conductor 150. 100
- 105 Relay 313, in operating, completes a circuit for the vertical group relay 315 traceable from battery through the winding of said relay, right back contact of vertical group relay 314, conductor 337, outer left contact of relay 313, conductor 338, winding of relay 318 to ground. Relays 315, 314 and 316, included in the broken rectangle, are individual to the first vertical group 101 and the remaining relays of the sender selector control circuit correspond closely to the controlling relays of the line 110 115 120 125 130

switch 100, above described. Relay 315 closes a circuit from battery through the winding of relay 319, inner front contact of relay 315, winding of relay 318 to ground. Relay 319 operates in this circuit. Relay 315 also closes a circuit from battery through the left-hand winding of vertical group relay 316, outer left front contact of relay 315, conductor 339, left back contact of relay 317, outer right contact of relay 323, conductor 340 to ground through the winding of relay 318. Relay 316 operates and closes a locking circuit for itself from battery through its right-hand winding and inner right front contact and winding of relay 317, outer right contact of relay 323 to the grounded conductor 340. Relay 316, at its inner left contact, closes a circuit for relay 314 and this latter relay opens the energizing circuit of relay 315.

Relay 317 also operates in series with relay 316 and closes a circuit for the slow-to-release relay 322 traceable from battery through the winding of relay 322, inner right contact of relay 317, inner right back contact of relay 323 to the grounded conductor 340. Relay 322 operates and closes a holding circuit for relays 316 and 317. This circuit extends through the right-hand winding and inner right front contact of relay 316, winding of relay 317, contact of relay 322 to the grounded conductor 340.

With the relays 316 and 317 operated a circuit is closed from battery through the vertical operating magnet 329, outer right front contact of relay 316, left front contact of relay 317, contact of relay 322 to ground over conductor 340. Magnet 329 prepares the vertical operating bar and also closes a circuit from ground through its contact, left contact of relay 321, outer left contact of relay 316, inner right contact of relay 313, left-hand winding of the horizontal group relay 312 to battery. Relay 312 becomes energized and closes a circuit from battery through its right-hand winding and right front contact, conductor 341, winding of relay 321 to ground at the contact of magnet 329. Relay 312 locks and relay 321 becomes energized in this circuit.

At the time relay 317 operates a circuit is closed from battery through the winding of the vertical operating magnet 331, brush 327 of the allotter switch 326 (which is standing in a position to allot the circuit 332 leading to the recording sender illustrated in the drawing), contact of the slow-to-release relay 325, left contact of relay 323, outer right contact of relay 317 to the grounded conductor 340. The vertical magnet 331 operates and prepares the contacts in the row 304. Magnet 331 closes a circuit from battery through its winding and inner contact, conductor 342, winding of

relay 323, outer right contact of relay 317 to the grounded conductor 340. Relay 323 is shunted, however, by the circuit previously traced for energizing the magnet 331 so long as the allotter switch 326 remains in its present condition. The magnet 331 also closes a circuit from ground through its outer contact, conductor 343, brush 328 of the allotter switch, contact and winding of the stepping magnet 324, winding of the slow-to-release relay 325 to battery. The magnet 324 operates, interrupts its own circuit and advances the brushes 327 and 328 forward to allot the next idle recording sender for use. The relay 325, which also energizes in series with the stepping magnet 324, opens the previously traced shunt circuit around the winding of relay 323. Relay 323 now operates and in so doing opens the circuit of the slow-to-release relay 322.

With relay 323 energized and relay 322 holding its armature attracted for an interval, a circuit is closed from the grounded conductor 340, inner right front contact of relay 323, right contact of relay 321, left front contact of relay 312, front contact of relay 311—assuming the horizontal link 308 to be engaged at this time—left back contact of relay 309, winding of the horizontal link 310 to battery. Magnet 310 operates the bar associated with the horizontal link 307, which is assumed to be idle, and the trunk circuit 114 is thus connected through the link 307 to the circuit 332 extending to the recording sender. When this connection is effected a circuit is first closed from battery through the winding of magnet 310, winding of relay 309, horizontal conductor 344, contacts of the sender selector switch, conductor 343, outer contact of magnet 331 to ground. The horizontal magnet 310 is held temporarily in the circuit traced and the relay 309, being shunted, does not operate at this time.

The sender selector, in operating, closes a circuit from ground through the outer contact of the magnet 331, conductor 343, contacts of the sender selector, horizontal conductor 344, contacts of the sender selector, conductor 346, winding of relay 201 to battery. Relay 201 operates and at its outer left contact opens the circuit of relay 313. Relay 313 releases and opens the circuit previously traced for the relay 204. Relay 204, however, is held energized after the release of relay 313 by means of the following circuit: battery, through the winding of relay 204, outer left front contact of relay 201 to ground.

Relay 201 extends the talking conductors 148 and 149 of the trunk circuit 114 through to the conductors 211 and 213 which lead through the sender selector switch to the recording sender. This results in the comple-

tion of the impulse circuit which includes the calling subscriber's line and the impulse relay 400 of the recording sender. The impulse circuit may be traced as follows: battery, through the right-hand winding of relay 400, normal inner right-hand contact of relay 409, conductor 420, right back contact of relay 411, inner left contact of relay 412, conductor 350, contacts of the sender selector switch, conductor 213, inner left front contact of relay 201, conductor 149, contacts of the line switch 100, horizontal conductor 169, contacts of the line switch, conductor 104, over the loop of the calling line, conductor 103, contacts of the line switch, horizontal conductor 170, contacts of the line switch, trunk conductor 148, inner right front contact of relay 201, conductor 211, contacts of sender selector, horizontal conductor 348, contacts of the sender selector, conductor 351, outer left contact of relay 412, left back contact of relay 411, conductor 421, outer right contact of relay 409, upper winding of coil 422 to ground. The impulse relay 400 operates in this circuit and closes a circuit from battery through the winding of the slow-to-release relay 401, left contact of relay 400 to ground. Relay 401 operates and closes a circuit from ground through its left contact, conductor 423, winding of relay 402 to battery. Relay 402 operates and at its innermost right contact places a ground on the holding conductor 343.

The above events have all taken place while the slow-to-release relay 322 is maintaining its armature attracted following the energization of relay 323. Hence, the subscriber's line is connected through to the recording sender and the slow relay 402 is operated to place a holding ground on the conductor 343 prior to the release of relay 322, which, as will presently be seen, brings about the release of the vertical magnet 331. After the interval has expired relay 322 releases its armature and opens the circuit of relays 316 and 317. Relay 316 opens the circuit of relay 314. Relay 314 opens the circuit of relay 319 which, in turn, deenergizes. Relay 316 furthermore opens the holding circuit of the vertical magnet 329 and this magnet restores the associated rod to its normal position. Magnet 329 also opens the circuit of relays 321 and 312.

Relay 317, in releasing, opens the holding circuit of magnet 331 and relay 323. Magnet 331 restores the vertical rod to normal and at the same time disconnects its outer armature from the holding conductor 343. Conductor 343, as above noted, however, is already grounded by the operation of relay 402 and therefore the connection through the sender selector is now held by means of the following circuit: battery, through the winding of the horizontal magnet 310, winding of relay 309, conductor 344,

contacts of the sender selector, conductor 343 to ground at the contact of relay 402. The operating relays and circuits of the sender selector switch 300 are now restored to their normal condition ready to extend another trunk to the next allotted sender while the present connection is held by the maintained energization of the horizontal magnet 310 alone.

The relay 201, which at first was operated and held over the above traced circuit leading to ground at the outer right contact of magnet 331, is now maintained by the ground applied to conductor 343 by the relay 402.

Setting the recording sender in accordance with the wanted designation.

As soon as the recording sender is attached to the trunk by the sender selector and is ready for receiving impulses from the calling line, a dial tone is transmitted back to the calling subscriber's station, notifying him that he may proceed to manipulate his calling transmitter. For this purpose a circuit is closed from the source of dial tone current 732, Fig. 7, outer left back contact of relay 710, conductor 733, condenser 424, lower winding coil 422, conductor 425 to ground at the outermost left contact of relay 402. Current in this circuit induces a flow of current in the upper winding of coil 422 which is transmitted over the subscriber's line to produce a characteristic tone in his receiver.

When relay 401 was first operated a circuit was closed from battery through the coil 426, conductor 427, left-hand winding of relay 407, right front contact of relay 401 to ground. Relay 407, however, did not operate in this circuit due to the following shunt around its winding: battery, through the winding of coil 426, right contact of relay 400, right front contact of relay 401 to ground.

The subscriber on hearing the dial tone in his receiver manipulates his dial to transmit a series of four impulses representing the first letter G of the office code. On the first opening of the line the relay 400 releases its armatures but relay 401 being slow to release maintains its armatures attracted. Relay 400, at its right contact, opens the shunt around the left-hand winding of relay 407 and this latter relay immediately operates. Relay 407 closes a holding circuit for itself from battery through its right-hand winding and inner right contact, outer left back contact of relay 408 to the grounded conductor 425. Relay 407 also closes a circuit from battery through the winding of relay 404, conductor 428, outer left contact of relay 407 to the grounded conductor 425. Relay 404 operates and closes a locking circuit for itself from battery through its winding and

left front contact, right contact of relay 403 to ground on conductor 425. Relay 407 furthermore closes a circuit from battery through the winding of the slow-to-release relay 405, conductor 429, outer right contact of relay 407 to ground at conductor 425.

Relay 407 also establishes a circuit from battery through the right-hand winding of relay 408 to ground at the inner left contact of relay 407. Relay 408 operates and closes a circuit from battery through its left-hand winding and inner left contact to the grounded conductor 425. Relay 408 completes a circuit from battery through its right-hand winding and right contact, conductor 430, outer right back contacts of counting relays 416, 415, 414 and 413 in series, winding of relay 413, outer left back contact of relay 414, conductors 431 and 432, outer left contact of relay 403, left front contact of relay 404, right back contact of relay 403 to the grounded conductor 425. The counting relay 413 is not operated in this circuit so long as relay 407 is held energized to maintain the shunt around the winding of said counting relay. This shunt, as above traced, leads from battery through the right-hand winding of the relay 408, and thence direct to ground at the inner left contact of relay 407. At the end of the first impulse the subscriber's line is closed and the relay 400 operates. Relay 400 replaces the shunt around the winding of relay 407 and this latter relay deenergizes. Relay 407 opens the shunt around the counting relay 413 and this relay is operated in series with the right-hand winding of relay 408.

It will be noted that the operating circuit of the counting relay 413 leads through the back contact and its outer right-hand armature. This relay and relays 414, 415 and 416 as well are arranged such that the back contact of the outer right-hand armature is maintained closed in the operation of the relay until a slight interval after the front contact of the inner right-hand armature has closed to complete the locking circuit. Therefore, the relay 413 is operated in the circuit above traced and on making its inner right front contact closes a locking circuit for itself as follows: battery, through the inner right contact and winding of relay 413, outer left back contact of relay 414, conductor 431, conductor 432, and thence as above traced to the grounded conductor 425.

The instant relay 407 releases it opens the original energizing circuit of relay 408. The resistance of relay 413 is included in series with the right-hand winding of said relay 408, causing a reduction of the flow of current through this winding. Shortly thereafter when relay 413 makes its inner right front contact a shunt effect on the right-hand winding of relay 408 is pro-

duced by closing the above traced circuit from battery through the inner right front contact and winding of relay 413 to ground. Following this the relay 413 opens its outer right back contact and severs completely the circuit through the right-hand winding of relay 408. The left-hand winding of relay 408 is wound differentially with respect to the right-hand winding. Hence, the current flow through the right-hand winding of the relay 408 after being reduced by two successive steps is finally differentiated by the flux produced in the left-hand winding and the relay releases its armatures quickly.

When the next impulse is sent relay 407 operates and closes the above traced circuit for relay 408. Relay 408 energizes and closes a circuit from battery through its right-hand winding and right contact, conductor 430, outer right back contacts of relays 416, 415 and 414 in series, outer right front contact of relay 413, winding of relay 414, outer left front contact of relay 415 to ground over conductor 431. Relay 414 remains shunted while relay 407 is energized, as explained in connection with relay 413. At the end of the impulse the subscriber's line closes and relay 407 is shunted to remove the short circuit from around the winding of counting relay 414. Relay 414 operates in series with relay 408 in the manner above described and locks in a circuit from battery through its inner right front contact and winding, outer left back contact of relay 415 to the grounded conductor 431. Relay 414, at its outer left back contact, opens the circuit of the previously energized relay 413 permitting this latter relay to release. When the second impulse is transmitted, as explained in connection with relay 413, relay 414, on operating, first shunts the right-hand winding of relay 408 and then opens the circuit of such winding permitting said relay to become differentiated and released.

Upon the transmission of the third impulse relay 408 is again energized and closes a circuit from battery through its right-hand winding and right contact, conductor 430, outer right back contacts of relays 416 and 415, outer right front contact of relay 414, winding of relay 415, outer left contact of relay 416 to ground over conductor 432. Relay 415 operates as soon as the impulse terminates and relay 407 is released to remove the shunt. Relay 415 opens the circuit of relay 408 and this latter relay becomes released. Relay 415, on operating, locks in a circuit from battery through its inner right front contact and winding, outer left contact of relay 416 to the grounded conductor 432. Relay 415, operating, opens the locking circuit of relay 414 and relay 414 thereupon restores to normal.

Finally, upon the transmission of the last of the four impulses in the series, relay 407 becomes energized and closes the operating circuit of relay 408. Relay 408 completes a circuit from battery through its right-hand winding and contact, conductor 430, outer right back contact of relay 416, outer right front contact of relay 415, winding of relay 416, outer left back contact of relay 417, conductor 431 to ground. At the end of the impulse relay 407 deenergizes removing the shunt from the winding of relay 416 and said relay 416 energizes in series with relay 408. When relay 416 is fully operated it closes a locking circuit for itself from battery through its inner right front contact and winding, outer left back contact of relay 417 to ground over conductor 431. Relay 416 also opens the circuit of relay 408 and the last mentioned relay retracts its armatures. Relay 416, furthermore, opens, at its outer left contact, the holding circuit of relay 415. Thus, at the end of the impulse series relay 416 is energized and the remaining counting relays are in their inert condition.

During the transmission of the impulse series the above traced circuit for relay 405 was repeatedly opened and closed by the action of relay 407. Relay 405, however, being slow to release retains its armature during the brief interruptions of its circuit. At the end of the impulse series, however, the circuit of relay 405 is held opened for a sufficient interval to permit its release. Relay 405 deenergizes and closes a circuit from ground by way of conductor 425, contact of relay 405, right contact of relay 404, inner left contact of relay 403, conductor 434, right back contact of relay 710, winding of relay 709 to battery. Relay 709 becomes energized and establishes a circuit from battery through its winding and inner upper contact, conductor 734, winding of relay 403, contact of relay 404, contact of relay 405 to the grounded conductor 425. The relay 403 does not operate in this latter circuit due to the fact that its winding is shunted by the first circuit traced for the energization of relay 709. Relay 709 operates and connects the leads from the counting relays in Fig. 4 through to the relays 703, 704, 705 and 706 of the register 700.

Since the counting relay 416 alone is energized a circuit is closed from the grounded conductor 432, outer left back contact of relay 413, conductor 435, inner left contact of relay 416, conductor 436, next to the lowermost contact of relay 709, winding of relay 705, conductor 735, winding of relay 708 to battery. Relays 708 and 705 energize and lock in a circuit traceable through the inner left contact of relay 705, conductor 736, conductor 737, conductor 738 to ground

at the middle right-hand armature of relay 402. Relay 708 established a circuit from ground over conductor 736, contact of relay 708, winding of relay 710 to battery.

Relay 710, at its right back contact, opens the shunt around the winding of relay 403 and the latter relay operates in series with relay 709 in the circuit hereinbefore traced. Relay 403 opens the holding circuit of relay 404 at its right contact. Relay 404, on de-energizing, opens the circuit of relays 403 and 709 permitting these relays to retract their armatures. Relay 403 also causes the release of all energized counting relays; in this particular case only the relay 416 is operated. The impulse receiving circuit is now in condition to receive the next series of impulses. Relay 709 in the recording circuit, upon deenergizing, disconnects the conductors extending from the counting relays from the first register 700.

The subscriber next manipulates his dial in accordance with the second letter E of the office code to transmit a series of three impulses. The impulse receiving mechanism in Fig. 4 functions in the same manner as explained in connection with the first impulse series, and when the third impulse has been received counting relay 415 alone is operated while relays 413 and 414 have been deenergized successively. After an interval relay 405 releases and the circuit above traced from grounded conductor 425, contact of relay 405, right contact of relay 404, inner left contact of relay 403 and conductor 434 now extends through the right front contact of relay 710 to conductor 741, right back contact of relay 716, winding of relay 717 to battery. Relay 717 operates and extends the leads from the counting relays through to the relays of the second register 701. Relay 717 also closes a circuit from battery through its winding and inner upper contact, conductor 734, winding of relay 403, right contact of relay 404, thence to ground over conductor 425. As before explained, relay 403 does not operate due to the fact that it is shunted by the original circuit through the winding of relay 717.

Since the counting relay 415 is operated a circuit is completed from the grounded conductor 431, outer left front contact of relay 415, conductor 437, innermost lower contact of relay 717, winding of relay 711, winding of relay 715 to battery. Another circuit is traceable from grounded conductor 431, inner left front contact of relay 415, conductor 438, next to the inner lower contact of relay 717, winding of relay 712, winding of relay 715 to battery. Relays 711, 712 and 715 operate and lock in a circuit traceable from battery through the winding of relay 715, thence in parallel through the windings and inner left contacts of relays

711 and 712, conductor 742 to the grounded conductors 737 and 738. Relay 715 closes a circuit from battery through the winding of relay 716, contact of relay 715 to the 5 grounded conductor 742. Relay 716 operates and locks through its winding and left contact to the grounded conductor 742. Relay 716, at its right back contact, opens the shunt circuit around the winding of relay 403. Relay 403, in operating, opens the circuit of relay 404 and the circuit of the counting relay 415. Relay 404 releases and opens the circuit of relays 403 and 717. Relay 717 disconnects the counting relay leads from 10 the register 701.

Next the subscriber transmits a series of seven impulses representing the third code letter R of the office designation. As previously explained, the counting relay 416 at 20 the end of the fourth impulse is energized and all other counting relays are in de-energized condition. At the beginning of the fifth impulse the subscriber's line opens and relay 407 becomes energized to close the 25 operating circuit for relay 408. Relay 408 completes a circuit from battery through its right-hand winding and contact, conductor 430, outer right front contact of relay 416, outer right back contact of relay 417, winding 30 of relay 417 to the grounded conductor 431. Relay 417 operates as soon as the subscriber's line is closed and relay 407 becomes deenergized and relay 417 completes a locking circuit for itself as follows: battery, 35 through the inner right contact and winding of relay 417 to the grounded conductor 431. Relay 417 opens the circuit of relay 408 and also opens the circuit of relay 416 whereby these last two mentioned relays become de-energized. At the beginning of the sixth 40 impulse relay 408 operates and completes a circuit from battery through its right winding and left contact, conductor 430, outer right back contacts of relays 416, 415, 414 and 413 in series, winding of relay 413, outer left back contact of relay 414 to ground at conductor 431. At the end of the impulse relay 413 operates and locks in the manner hereinbefore explained. When the line opens at the 45 beginning of the seventh impulse the relay 408 operates in the usual manner and completes a circuit from battery through its right-hand winding and contact, conductor 430, outer right back contacts of relays 416, 415 and 414, outer right front contact of relay 413, winding of relay 414, outer left back contact of relay 415 to the grounded conductor 431. When the impulse has ceased relay 414 operates and locks as above explained. 50 Relay 414 opens the circuit of relay 408 and also opens the circuit of the preceding counting relay 413. Relay 414 in addition closes a circuit from battery through the winding of relay 418, inner left contact of relay 414, conductor 439, outer left front contact of re-

lay 417, to the grounded conductor 431. Relay 418 energizes in this circuit and locks in a circuit from battery through its winding and inner right contact to ground over conductor 431. Thus, at the end of seven impulses counting relays 414, 417, and 418 are operated.

After an interval following the last of the third series of impulses the slow relay 405 retracts its armature and closes a circuit 75 from ground through the outermost left contact of relay 402, conductor 425, contact of relay 405, right contact of relay 404, inner left contact of relay 403, conductor 434, right front contact of relay 710, right front contact of relay 716, right back contact of relay 723, winding of relay 724 to battery. Relay 724 operates and extends the counting relay leads through the register sender 702. Relay 724 also closes a circuit from battery 80 through its winding and inner upper contact, conductor 734, winding of relay 403, back contact of relay 404, contact of relay 405 to ground over conductor 425. Relay 403 remains shunted until relay 723 operates. 90

Where the counting relay 414 is operated a circuit may be traced from ground over conductor 431, outer left front contact of relay 414, conductor 438, next to the lowermost contact of relay 724, winding of register relay 719, conductor 743, winding of relay 722 to battery. Another circuit may be traced from ground over conductor 431, inner left front contact of relay 417, conductor 440, inner left contact of relay 413, conductor 441, innermost lower contact of relay 724, winding of relay 721, winding of relay 722 to battery. Relays 722, 719 and 721 operate and lock in a circuit from battery through the winding of relay 722, thence in parallel 105 through the windings and inner left contacts of relays 719 and 721, conductor 744, conductor 737 to ground. Relay 722 completes a circuit from battery through the winding of relay 723, contact of relay 722 to the 110 grounded conductor 744. Relay 723 operates and locks in a circuit through its winding and left contact to the grounded conductor 744. Relay 723, at its right back contact, opens the shunt circuit around the winding 115 of relay 403. Relay 403 retracts its armatures opening the circuit of the energized counting relay and also the circuit of relay 404. Relay 404 releases and opens the circuit of relay 403 and 724 whereby these two relays 120 become deenergized.

Following this the subscriber sends four series of impulses representing the thousands, hundreds, tens and units digits of the called line number which is assumed to be 125 1326. The first series consisting of one impulse is received in the manner explained and at the end of this impulse relay 413 alone is energized. After an interval following the impulse slow relay 405 releases and a 130

circuit is closed from grounded conductor 425 through the contact of relay 405, right contact of relay 404, inner left contact of relay 403, conductor 434, right front contact of relays 710, 716 and 723 in series, conductor 745, right back contact of relay 808, winding of relay 809 to battery. Relay 809 operates and extends the counting relay leads through to the relays 803, 804, 805 and 806 of the thousands register 800. Relay 809 also completes a circuit from battery through its winding and inner upper contact, conductor 734, winding of relay 403, right contact of relay 404, contact of relay 405 to ground over conductor 425. Relay 403 being shunted remains deenergized until relay 808 is operated.

With the counting relay 413 energized at the end of the thousands impulses and with the counting relay leads extended through to the thousands register, a circuit may be traced from ground over conductor 431, outer left front contact of relay 413, conductor 442, outer right back contact of relay 418, conductor 437, lowermost contact of relay 809, winding of relay 803, winding of relay 807 to battery. A branch of this circuit extends by way of conductor 829, winding of relay 826 to battery. Relays 807 and 803 operate and lock in a circuit from battery through the winding of relay 807, winding and inner front contact of relay 803, conductor 830 to the grounded conductor 737. Relay 826 also operates and locks in a circuit from battery through its winding, conductor 829, inner right front contact of relay 803 to ground over conductor 830. Relay 807 closes a circuit from battery through the winding of relay 808, contact of relay 807 to ground over conductor 830. Relay 808 operates and locks in a circuit from battery through its winding and innermost left contact to ground over conductor 830. Relay 808, at its right back contact, opens the shunt circuit around the winding of relay 403 and this latter relay operates releasing in turn the counting relay 413 and relay 404. Relay 404 opens the circuit of relays 403 and 809 whereby these relays retract their armatures.

The calling subscriber now manipulates the transmitter 171 to send a series of three impulses representing the hundreds digit. At the termination of the hundreds series of impulses, the counting relay 415 is operated and after an interval of time expires the slow-to-release relay 405 retracts its armature. Relay 405 completes a circuit from ground over conductor 425, contact of relay 405, right contact of relay 404, inner left contact of relay 403, conductor 434, thence through the right front contacts of relays 710, 716, 723 and 808, conductor 831, right back contact of relay 818, winding of relay 819 to battery. Relay 819 operates and

extends the counting relay leads to the relays of the hundreds register 801. Relay 819 also closes a circuit from battery through its winding and inner upper contact, conductor 734, winding of relay 403, thence, as above traced, to ground over conductor 435. Relay 403 being shunted at this time does not operate.

With the counting relay 415 in energized condition and the controlling leads extended through the hundreds register, a circuit may be traced from ground over conductor 431, outer left front contact of relay 415, conductor 437, lowermost contact of relay 819, windings of register relays 810 and 814 in parallel to battery. Another circuit is established from the grounded conductor 431 through the inner left front contact of relay 415, conductor 438, next to the lowermost contact of relay 819, thence through the windings of relays 811 and 815 in parallel to battery. Relays 810 and 814 operate and lock in circuits traceable through the windings of these relays, inner left contact of relay 810, conductor 832 to the grounded conductor 737. Relays 811 and 815 operate and lock in circuits from battery through their windings, inner left contact of relay 811 to the grounded conductor 832. The relay 818 is now operated in a circuit from battery through its winding, outer left contact of relay 810 to ground over conductor 832. Relay 818 locks in a circuit from battery through its winding and inner left contact to ground over conductor 832. Relay 818, at its right back contact, opens the shunt around the winding of relay 403 and this latter relay energizes to cause the release of relays 404 and 415. Relay 404, on releasing, opens the circuit of relays 403 and 819 whereupon these relays retract their armatures.

Next the calling subscriber operates his dial 171 to transmit a series of two impulses characterizing the tens digit of the wanted number. As already explained in detail, a series of two impulses results in the energization of the counting relay 414 which locks in the circuit controlled by relay 403. After the required interval following the tens series the slow relay 405 retracts its armature and the above traced circuit from ground by way of conductor 434 is now completed through the right front contacts of relays 710, 716, 723, 808 and 818 to conductor 833, right back contact of relay 910, winding of relay 911 to battery. Relay 911 operates and extends the controlling leads from the counting relays through to the relays of the tens register 900. Relay 911, moreover, completes a circuit from battery through its winding and inner upper contact, conductor 734, winding of relay 403, and thence as previously traced to ground over conductor 425. Relay 403 being shunted does not operate at this time.

Since only the one counting relay 414 remains energized at the end of the tens series of impulses, the following circuit alone may be traced for operating the tens register: 5 ground, over conductor 431, outer left front contact of relay 414, conductor 438, next to the lowermost contact of relay 911, winding of relays 903 and 907 in parallel to battery. Relays 903 and 907 operate and lock in a 10 circuit through their windings in parallel, inner left contact of relay 903, conductor 925, to ground over the holding conductor 737. A circuit may now be traced from battery through the winding of relay 910, 15 outer left contact of relay 903 to ground over conductor 925. Relay 910 actuates and locks in a circuit from battery through its winding and inner left contact to ground over the conductor 925. Relay 910, at its 20 right back contact, opens the short circuit around the winding of relay 403. Relay 403 operates in series with relay 911 and opens the holding circuits of relays 404 and counting relay 414. Relay 404, upon releasing, 25 opens the circuit of relays 403 and 911 and these relays in turn deenergize.

Lastly, the calling subscriber sends a series of six impulses over the line representing the units digit of the called subscriber's 30 line. The receiving mechanism in Fig. 4 responds to the series of impulses and at the end of the last impulse counting relays 413 and 417 are energized and locked in the manner explained while the remaining 35 counting relays are inert. After the necessary interval has elapsed the slow relay 405 retracts its armature and the circuit hereinbefore traced from grounded conductor 425 to the conductor 434 may now be followed through the right front contacts of 40 relays 710, 716, 723, 808, 818 and 910 to conductor 926, outer right back contact of relay 927, winding of relay 928 to battery. Relay 928 operates and extends the control 45 leads from the counting relays through to the units register 901. Relay 928, furthermore, completes a circuit from battery through its winding and inner upper contact, conductor 734, winding of relay 403, 50 thence as traced to the grounded conductor 425. In the same manner as previously explained, relay 403 is shunted and does not operate until relay 927 is energized.

Since the counting relay 413 is actuated a 55 circuit may be traced from the grounded conductor 431, outer left front contact of relay 413, conductor 442, outer right back contact of relay 418, conductor 437, lowermost contact of relay 928, winding of relays 912 and 916 to battery. Another circuit is 60 traceable from the grounded conductor 431 through the inner left front contact of relay 417, inner left back contact of relay 418, conductor 441, innermost lower contact of

relay 928, windings of relays 915 and 919 65 in parallel to battery. Relays 912 and 916 operate and lock in a circuit through their windings in parallel, inner left contact of relay 912, conductor 929, thence to ground at the holding conductor 737. Relays 915 70 and 919 are locked similarly in a circuit through the inner left contact of relay 915 to ground over conductor 929. Relay 927 is also operated in a circuit from battery 75 through its winding, outer left contact of relay 912 to the grounded conductor 929. Relay 927 actuates and closes a locking circuit through its inner right contact to the conductor 929. Relay 927, at its outer right back contact, opens the shunt circuit around the winding of relay 403. Relay 403 operates in series with relay 928 in the circuit 80 above traced and opens the holding circuits of relays 404, 413 and 417. Relays 413 and 417 release and relay 404 also restores and 85 relay 404 opens the circuit of relays 403 and 928 causing these relays to become deenergized.

A complete registration has now been made in the office and numerical registers of 90 the recording sender. The called subscriber's line is assumed to be a direct line. Where a called line terminates in a distant office, such as a private branch exchange, extra 95 series of impulses may be transmitted following the numerical portion of the designation to cause the setting of the registers 1000, 1001 and 1002 in identically the same manner as that described in connection with the other registers of the sender. The manner in which these latter registers may determine the transmission of impulses to the private branch exchange will become apparent 100 from the description to be given herein-after.

After a complete series of impulses have been transmitted over the line and received by the impulse mechanism in Fig. 4, the counting relays are restored to their normal condition and the impulse relay 400 remains 110 energized in series with the subscriber's line. Relay 400, as above explained, maintains the energization of slow relays 401 and 402 to hold the connection in its present condition under the control of the calling subscriber's switchhook.

Association of the recording sender with the district marker.

The record of the wanted line having been 120 made in the recording sender, the next operation to take place is the association of this particular sender with the district marker which is common to a number of such senders and which controls the group of district selector switches containing the particular switch 1100 to which the selected trunk 114 125 extends. The district marker is concerned

only with a portion of the entire designation; namely, the office code and the thousands digit. Hence, the sender may be associated with the marker immediately that 5 the office and thousand records are received by the sender and this association need not await the receipt of the remaining part of the designation. In other words the recording sender is connected to the district marker 10 at the instant the thousands digit has been recorded on the sender.

It will be recalled that following the registration of the thousands digit, the relay 808 is operated. The relay 808 completes a 15 circuit from ground over conductors 737 and 830, middle left contact of relay 808, conductor 835, conductor 740, winding of relay 505 to battery. Relay 505 operates and locks in a circuit from battery through its 20 winding and right contact to ground over conductors 506 and 507. Relay 505 closes a start circuit for the sender connector 1500 in order that the multicontact relay 1501, which is individual to the recording sender 25 concerned, may be operated to connect such sender to the district marker. The start circuit is traceable from ground over conductor 507, conductor 509, inner left back contact of relay 510, outer left back contact 30 of relay 511, conductor 512, inner left front contact of relay 505, outer right back contact of relay 513, conductor 514, winding of relay 1509 to battery. Relay 1509 serves to initiate the operation of the sender 35 connector device 1500. Before proceeding with the operation of the sender connector 1500, an explanation will be given of the plan employed for grouping the multicontact operating relays of the sender connector. 40

Where there are a comparatively large number of recording senders, all of which have access to the marker, it is advisable to provide some means for distributing evenly 45 among the different senders the availability of which they have in gaining access to the district marker. To this end the total number of senders are divided into several small groups as regards their appearance in the 50 sender connector 1500. Two such groups, namely the groups 1522 and 1523 are illustrated. The last group in the series 1523 is represented by the two multicontact relays 1501 and 1502, each of which is individual to a recording sender. Obviously, 55 more than two senders may be assigned to a group if desirable. The relays 1513 and 1514 are common to the last group 1523. The next to the last group 1522 also is illustrated as having two recording senders to which the relays 1503 and 1504 are respectively connected. Relays 1515 and 1516 are the group relays common to the group 1522. As will be taken up later on, the circuit ar-

angement of the connector 1500 is such that 65 each group of senders has preference over all succeeding groups in the series in the event that two senders occurring in a different group are attempting simultaneously to gain access to the district marker. The 70 plan, however, is such that if two senders in one group and another sender in a succeeding group are attempting connection to a district marker simultaneously, one sender in the first group will succeed in appropriating the district marker but the second sender in the first group will be required to wait until the sender in the succeeding group has been connected to the marker. That is to say, a second sender in any group seeking 80 access to the district marker must wait until one sender in each of all such succeeding groups as have any sender simultaneously attempting connection with the marker has been so connected. 85

Since the groups 1522 and 1523 are respectively the next to the last and the last groups of senders in the series, it follows that all preceding groups have preference over these two and that the group 1522 has 90 preference over the group 1523 as regards two senders simultaneously attempting connection to the marker. The recording sender shown in Figs. 4 to 10, inclusive, belongs in the last group 1523 and is individual to the 95 multicontact relay 1501 in such group. Hence, the individual relay 1509 is operated as described when the sender is ready for connection to the marker. Relay 1509 completes a circuit from ground through its 100 right contact, common conductor 1524, right back contact of relay 1513, winding of relay 1514 to battery. Relay 1514 operates and locks in a circuit from battery through its winding and right contact, left back 105 contact of relay 1516, thence through the left back contacts of all corresponding relays 1516 of the preceding groups, conductor 1525, outer right back contact of relay 1201, conductor 1216, contact of relay 1204 110 to ground. The closure of this locking circuit for relay 1514 depends upon the fact that all corresponding relays in preceding groups are deenergized indicating that no other group having a higher preference is 115 requiring connection to the marker at this time. On this assumption the relay 1514 locks in the circuit traced and completes a circuit from battery through the right-hand winding of relay 1505, left contact of relay 1509, left back contact of relay 1510, through the back contacts of all corresponding relays in the group 1523 (assuming that no other sender in this group is attempting 120 connection to the marker), left front contact of group relay 1514, thence over the conductor 1525, as previously traced, to ground at the contact of relay 1204. Relay 125

1505 becomes energized and closes a circuit from battery through the winding of relay 1513, inner right front contact of relay 1505 to ground. Relay 1513 operates, opens the original circuit of relay 1514, and closes a circuit from ground through the right contact of relay 1509, conductor 1524, right front contact of relay 1513, conductor 1526, winding of relay 1202 to battery. Relay 1202 attracts its armatures and closes a locking circuit for relay 1513 as follows: Battery, through the winding and inner left contact of relay 1513, conductor 1527, left contact of relay 1202, contact of relay 1203 to ground. 65

With relay 1513 operated a locking circuit for relay 1505 is completed from battery through the left-hand winding and left contact of relay 1505, left back contacts of relay 1506 and the corresponding relays in the same group, outer left contact of relay 1513, conductor 1528, outer left back contact of relay 1515, outer left back contact of similar relays in preceding groups, conductor 1529, winding of relay 1201, conductor 1216 to ground at the contact of relay 1204. Relay 1505 locks and relay 1201 is operated in this circuit. Relay 1201, at its outer right contact, opens the holding circuit of relay 1514 permitting this latter relay to release its armatures. Relay 1514 opens the original energizing circuit of relay 1505. 80

With relays 1505 and 1201 energized a circuit is established from battery through the winding of the multicontact relay 1501, outer right contact of relay 1505, conductor 1530, inner left contact of relay 1201 to the grounded conductor 1216. Relay 1501 moves its gang of contacts into engagement with the corresponding horizontal wires of the connector 1500 whereby the leads coming from the recording sender are extended through to the district marker. Relay 1501, moreover, completes a circuit from ground through its contact, conductor 1531, outer left contact of relay 1201, inner right back contact of relay 1200, winding of relay 1206 to battery. The energization of the relay 1206 gives an indication to the recording sender that the district marker has been associated and is ready to receive the office and thousands records. Before going on with this an explanation will be given as to the operation of the sender connector 1500 when a number of senders are simultaneously seeking to be connected to the district marker. 100

Considering, for example, that both senders illustrated in the group 1522 and the sender shown in the drawing which belongs to the group 1523 are simultaneously attempting to be connected to the marker. Relays 1511 and 1512 being operated circuits are closed in an obvious manner for the

energization of relay 1516. Relay 1516 operates and locks in the manner explained through its winding and right contact, conductor 1525 to the grounded conductor 1216. Relay 1516 closes a circuit from battery through the right-hand winding of relay 1508, left front contact of relay 1512, left front contact of relay 1516, conductor 1525 to ground. The corresponding circuit for the relay 1507 of the other sender in the group is closed at the left contact of relay 1511 but is held opened by the left contact of relay 1512, which has first preference. Relay 1508 completes a circuit from ground through its inner right contact, winding of relay 1515 to battery. Relay 1515 operates and a circuit is closed from battery through the winding of relay 1202, conductor 1526, right front contact of relay 1515, thence to ground at the right contact of either relay 1512 or relay 1511. Relay 1202 operates and a locking circuit for relay 1515 is established as follows: battery, through the winding and inner left contact of relay 1515, conductor 1527, left contact of relay 1202, contact of relay 1203 to ground. Relay 1515 closes a circuit from battery through the left-hand winding and left contact of relay 1508, outer left front contact of relay 1515, conductor 1529, winding of relay 1201, to ground on conductor 1216. Relay 1201 operates and as above noted opens the holding circuit of relay 1516. Relay 1508 operates and in the manner above explained completes a circuit for the multicontact relay 1504 which operates and connects the corresponding sender to the district marker. Relay 1201 opens the circuit of relay 1516 which retracts its armatures. 115

When the district marker has completed its function it is disconnected from the recording sender in a manner to be explained hereinafter. The disconnection results in the deenergization of relays 1508, 1504 and 1512. Relay 1512, at its right contact, removes ground from the circuit previously traced for relay 1202. However, relay 1202 is now held by a circuit leading to ground at the right contact of relay 1511 since the other sender in the same group is waiting to be connected to the district marker. Relay 1508, upon deenergizing, opens the original energizing circuit of relay 1515. Relay 1515, however, is locked in the circuit traced through the contacts of relays 1202 and 1203. Hence, the relay 1516 cannot again be operated to connect the second sender in the group 1502 to the district marker. 120

With relays 1201 and 1516 deenergized after the first sender in the first group has been disconnected from the marker, a circuit is closed for holding the relay 1514 as follows: battery, through the winding and

right contact of said relay, left back contact of relay 1516, conductor 1525, thence to the grounded conductor 1216. Relay 1514 in the fashion already explained brings about the operation of relays 1505, 1513 and 1501 and the recording sender in the last group 1523 is connected to the district marker.

After the second sender has been disconnected from the marker the other sender in the first group 1522 waiting connection may now be associated with the marker provided there is no other sender in any other group waiting for connection to the marker. Since there is no other group of senders active at this time all relays 1514, 1516, etc. are in deenergized condition. Hence, a circuit is closed when the last one of these relays releases traceable from battery through the winding of relay 1203, right contact of relay 1202, conductor 1218, left back contact of relay 1514, left back contact of relay 1516, etc. to the conductor 1525, outer right back contact of relay 1201 to the grounded conductor 1216. Relay 1203 operates and opens the holding circuit of relay 1515. Relay 1515 immediately releases and in the manner above described the other sender in group 1522 is associated with the district marker.

When relay 1515 releases it opens the circuit of relay 1202. Relay 1202 becomes deenergized and in turn releases the relay 1203.

Returning now to the point where the recording sender shown in the drawing is associated with the district marker by the operation of the multicontact relay 1501 and relay 1206 is energized, a circuit may be traced from ground over conductor 1216 through the outer right front contact of relay 1201, outer left front contact of relay 1206, conductor 1220, contacts of relay 1501, conductor 1532, outer left back contact of relay 513, conductor 515, contacts of the sender selector switch 300, conductor 352, inner-most right back contact of relay 205, conductor 221, winding of the vertical operating magnet 1115 to battery. Thus, the vertical magnet 1115, controlling the vertical row of contacts 1108 in which appears the trunk 114 to which the calling subscriber's line has been extended, has been selected and operated. The magnet 1115 prepares the contacts of the trunk for connection to a horizontal link circuit. Magnet 1115 also closes a circuit from battery through the winding of relay 208, conductor 222, left front contact of magnet 1115, conductor 223, right contact of relay 201 to grounded conductor 150. Relay 208 locks through its inner upper contact and the inner right contact of relay 230 to ground over conductor 223 as traced.

Also at the time relay 1201 operates a circuit is established from battery through the

winding of slow-to-release relay 1212, left back contact of relay 1214, inner right contact of relay 1201 to the grounded conductor 1216. Relay 1212 energizes and closes a circuit from battery through the winding of the slow-to-release relay 1213, contact of relay 1212, thence, as traced, to the grounded conductor 1216. Relay 1213 operates and completes a circuit from battery through the winding of slow-to-release relay 1214, inner front contact of relay 1213 to ground as traced. Relay 1214 operates and opens the circuit of relay 1212, which, after an interval of time, retracts its armature. Relay 1212 opens the circuit of relay 1213 which, after a second interval, becomes deenergized. With relay 1213 released and relay 1214 maintaining its energization a circuit is momentarily completed from ground over conductor 1216 through the inner right contact of relay 1201, inner back contact of relay 1213, inner right contact of relay 1214, conductor 1221, winding of release relay 1200 to battery. The combination of slow operating relays 1212, 1213 and 1214 act in this manner to measure a given interval of time following the operation of relay 1201. If at the end of this interval relay 1201 does not become deenergized, indicating that the marker completed its functions, the relay 1200 is operated as described and brings about the release of the marker and the sender connector 1500 in a manner to be related hereinafter.

At the time relay 1206 operates it closes a circuit from ground over conductor 1216, outer right front contact of relay 1201, outer left front contact of relay 1206, conductor 1222, outer left back contact of relay 1446, winding of slow-to-release relay 1448 to battery. Relay 1448 becomes energized and completes a circuit from ground through its left contact, winding of slow-to-release relay 1447 to battery. Relay 1447 operates in this circuit.

At the time relay 1201 operates and before relay 1206 operates, a circuit is closed momentarily as follows: battery, through the winding of relay 1205, outer left back contact of relay 1206, outer right front contact of relay 1201, to ground at the contact of relay 1204. Relay 1205 being slow to release holds the conductor 1225 open for an interval to insure that all relays of the registers 1301, 1302 and 1303 are operated before selection of the translator relay is made.

Transfer of office and thousands records from the recording sender to the district marker.

The apparatus is now in condition for marking at the district selector switch 1100 the particular group of outgoing trunks

which lead into the desired terminal group of 2000 lines. For this purpose the office code record and the record of the thousands digit, already established in the sender, are transferred into the district marker.

- 5 The transfer of the first portion of the office record from the register 700 to the register 1301 of the district marker will now be described. Since the register relay 10 705 is operated a circuit may be traced from ground through the contact of relay 1204 in the district marker, conductor 1216, inner left contact of relay 1206, conductor 1223, contacts of multicontact relay 1501, conductor 1534, conductor 747, outermost right contact of relay 705, conductor 772, contacts of relay 1501, conductor 1535, winding of relay 1325 to battery. Thus, the register relay 1325 operates and the remaining three 15 20 relays 1324, 1326 and 1327 remain inert.

- 10 The second and third portions of the office designation are transferred from the recording sender to the marker registers 1302 and 1303 in a similar manner. With the 25 register relay 711 operated a circuit is completed from the grounded conductor 1216 over conductor 1534, as above traced, conductor 747, outermost right contact of relay 711, conductor 748, contacts of relay 1501, conductor 1536, winding of register relay 1331 to battery. With register relay 712 energized another circuit is established from ground over conductors 1534 and 747, outermost right contact of relay 712, conductor 30 35 40 45 50 55 60 65 70 75 77 79 80 82 84 86 88 89 90 92 94 96 98 100 102 104 106 108 110 112 114 116 118 120 122 124 126 128 130 132 134 136 138 140 142 144 146 148 150 152 154 156 158 160 162 164 166 168 170 172 174 176 178 180 182 184 186 188 190 192 194 196 198 200 202 204 206 208 210 212 214 216 218 220 222 224 226 228 230 232 234 236 238 240 242 244 246 248 250 252 254 256 258 260 262 264 266 268 270 272 274 276 278 280 282 284 286 288 290 292 294 296 298 300 302 304 306 308 310 312 314 316 318 320 322 324 326 328 330 332 334 336 338 340 342 344 346 348 350 352 354 356 358 360

- Since relay 719 of the office register 702 is operated a circuit is established from the grounded conductor 1534, conductor 747, 40 outermost right contact of relay 719, conductor 750, contacts of relay 1501, conductor 1538, winding of relay 1334 to battery. With relay 721 operated another circuit is closed over the grounded conductors 1534 and 747 through the outermost right contact of relay 721, conductor 751, contacts of relay 1501, conductor 1539, winding of relay 1332 to battery.

- Considering the thousands digit it will be recalled that the relay 803 of the thousands register 800 is operated while the remaining relays 804, 805 and 806 are deenergized. A circuit is, therefore, completed from ground over the conductor 1534, conductor 747, lowermost back contact of relay 824, outer right back contacts of relays 806, 805 and 804 in series, conductor 836, innermost upper back contact of relay 824, conductor 837, contacts of relay 1501, conductor 1540, winding of relay 1338 to battery. Relay 1338 which represents the first terminal line group of 2000 subscribers' lines operates in this circuit and the remaining four relays of the register 1304 remain inactive.

- 65 The office designation having thus been

transferred to the three registers 1301, 1302 and 1303, these registers now become effective to control the translator 1300 to determine the class of the call and to prepare for the group selecting operation of the 70 district selector switch. The three registers 1301, 1302 and 1303, each capable of taking any one of ten different settings according to the number of impulses in the series representing the three abbreviation letters of 75 the office designation, cooperate with each other to provide a large number of different conditions in the translator 1300. The first register 1301, for instance, is capable of selecting any one of ten different multicontact 80 relays of which five such relays 1308 to 1312, inclusive, are shown. Relay 1308, in operating, applies ground, as will be shown hereinafter, to a certain pair of horizontal conductors in the section 1323 and also applies ground to a certain horizontal conductor in the section 1322. Likewise, each of the remaining relays 1309, 1310, etc. applies ground potential to a different pair of conductors in the section 1323 and also applies ground potential to the different conductors in section 1322.

The register 1302, representing the second letter of the office abbreviation, is capable of applying ground potential to any 95 one of the ten horizontal conductors in the portion 1321 of the translator 1300. Moreover, the third register 1303 is arranged to select any one of ten multicontact relays of 100 which seven, 1313 to 1319, inclusive, are 105 shown. The contacts of each of the relays 1313, 1314, 1315, etc. are connected arbitrarily to the windings of a plurality of multicontact relays, three of which, relays 1305, 1306 and 1307 are shown in the drawing. The contacts of the relays 1305, 1306 and 1307 are connected in arbitrary fashion to the class leads and to the other leads which terminate in the distributing rack 1339.

110 From the above description it will be seen that the three code registers 1301, 1302 and 1303 of the district marker cooperate with each other in accordance with the office designation transmitted over the calling subscriber's line to the recording sender and then transferred to the district marker for the purpose of applying the necessary conditions to the proper ones of the conductors terminating in the distributing rack 1339 whereby 115 class information is secured for governing the operation of the sender and whereby group selection at the district switch may take place. This arrangement affords an opportunity for making changes readily in the office codes by a simple wiring operation in the district marker translator, of which there is only one for a large number of recording senders. The economical advantage of making the changes in the marker translator in 120 125 130

stead of making them in each of the several different recording senders is obvious without explanation. The necessity for making such changes is continually arising in commercial practice.

The particular call now being extended, namely, a full mechanical local call, requires only the setting of the district selector, a group selector switch and a connector switch. 10 For this purpose the recording sender does not require any additional class information and accordingly none of the class leads in the group 1336, which cooperate with the lower section 1323 of the translator 1300, 15 need be affected so far as the recording sender is concerned.

Since the local connection requires a talking circuit having minimum of loading and ordinary supervision, the translator 1300, in response to this office code, has no influence 20 upon the three class conductors 1340, 1341 and 1359 which lead to the class horizontal trunk 1131 of the district selector switch 1100. It will be explained hereinafter in 25 connection with another type of call how the translator prepares circuits over these conductors through the class horizontal trunk 1131 to adjust the equipment in the trunk 114, illustrated in Fig. 2, for the proper talking circuit and for the necessary supervisory conditions.

Inasmuch as the relay 1325 of the register 1301 is operated, a circuit is completed from the grounded conductor 1216, inner left contact of relay 1206, contact of relay 1205, conductor 1225, conductor 1343, inner right contact of relay 1324, inner right front contact of relay 1325, winding of multicontact relay 1310 to battery. Relay 1310 operates and 40 connects the horizontal conductor 1344 to the two horizontal conductors 1345 and 1346. Relay 1310 also connects the horizontal conductor 1347 to the horizontal conductor 1348. With the relays 1330 and 1331 of the second 45 register operated a circuit may be traced over the grounded conductors 1225 and 1343 to the inner right back contacts of relays 1328 and 1329, inner right front contact of relay 1330, inner left front contact of relay 1331 50 to the horizontal conductor 1349. Moreover, with the register relays 1334 and 1332 of the third register operated, a circuit is completed over the grounded conductors 1225 and 1343 through the outer left contact of relay 1335, 55 left contact of relay 1332, left back contact of relay 1333, outer left front contact of relay 1334, winding of multicontact relay 1319 to battery. Relay 1319 operates and engages its contacts respectively with each of the 60 horizontal conductors of the portion 1321 of the translator.

Since the register 1302 has applied ground potential to the horizontal conductor 1349, a circuit is completed over this conductor 65 through contacts of the relay 1319, conduc-

tor 1350, winding of multicontact relay 1305 to battery. Relay 1305 thereupon operates and connects its contacts with the horizontal conductors in the portion 1320 of the translator. Since, as hereinbefore noted, the recording sender requires no information regarding the class of the call where a local full mechanical connection is being established, the particular contacts of the relay 1305, which engage the grounded horizontal 70 conductors 1345 and 1346, are not connected to any of the class leads on the distributing rack 1339.

Marking the groups of trunks at the district selector switch.

With the multicontact relay 1305 operated and with the thousands register relay 1338 actuated, a circuit is completed for selecting one of a number of relays 1406, 1407, 1408, 1409, 1410, 1411, etc. Each of these relays represents a group of trunks outgoing from the district selector switches. Five of these relays are individual respectively to the five different groups of trunks leading to the 85 live 2000 line terminal groups. Another relay is individual to the group of trunks extending to the office selector switches 2600. Still other relays represent groups of trunks leading to special positions. The relay 1408 90 is the one which designates the group of trunks containing the trunk 1129 leading to the first terminal line group of 2000 lines containing the called subscriber's line. Hence, the following circuit may be traced: 100 grounded conductors 1225, 1343, 1351, 1352 to the horizontal conductor 1347, thence through contacts of relay 1310 to the horizontal conductor 1348, contacts of relay 1305, contact of thousands register relay 1338, conductor 1353, winding of relay 1408 105 to battery. The relay 1408 is in this manner selected and operated as a result of the combined effects of the office and thousands 110 designations to mark the group of trunks leading from the district selector switch to the first terminal line group as the group of trunks to be used for this connection.

Testing the selected group of trunks.

The next operation to be performed is to test the trunks of the selected outgoing group and to test the horizontal links of the particular district selector switch involved to ascertain an idle trunk in such group which is accessible to an idle one of the horizontal links.

Referring back to the time when the district marker was first connected through the sender connector 1500 to the recording sender, it will be recalled that a circuit was established for the operation of the vertical operating magnet 1115 of the particular district selector switch 1100 in which appears 125 the trunk 114. In a manner about to be 130

described the vertical operating magnet 1115 serves to associate the district selector switch 1100 with the common district marker. There are, as hereinbefore observed, a plurality of district selectors to which the marker is common. Hence, it is necessary whenever a particular one of the district selectors is appropriated for use to associate the common marker with that district selector to the exclusion of all others. To this end the district selector switch 1100 is provided with three multicontact relays 1423, 1420 and 1426, which are individual thereto. Another district selector switch, not shown, is provided with three multicontact relays 1422, 1419 and 1425. Still another district selector switch is provided with individual relays 1421, 1418 and 1424. It is the purpose of these multicontact relays to associate the common marker with the individual district selector switch. Therefore, when any one of the incoming vertical magnets, such as the magnet 1115 is operated, a circuit is closed from ground through the inner right contact of such magnet, conductor 1132, thence in parallel to the windings of relays 1423, 1420 and 1426 to battery. These relays operate, and as will be explained later on, extend the operating circuits of the horizontal link magnets through to the common testing relays in the marker.

In passing it may be noted at this point that when any one of the incoming vertical magnets 1115, 1116, 1117, etc. is operated, a circuit is closed through its outer right contact, conductor 1133, left-hand winding of the horizontal magnet 1127. The magnet 1127 operates the bar individual to the trunk 1131 of the district selector switch. The purpose of this horizontal link circuit will be explained hereinafter.

The relay 1408, in operating, completes a circuit from battery through the winding of relay 1446, conductor 1450, lowermost contact of relay 1408 to ground. The relay 1446 energizes and opens the circuit of relay 1448. The relay 1448 remains energized for an interval before it releases its armatures and after this the relay 1447, being slow to release, retains its armatures attracted for a still further interval. The interval of time measured by the relays 1448 and 1447 is sufficient for associating the common testing relays 1400 and 1403 with the district selector switch 1100, for selecting an idle link and outgoing trunk circuit in the proper group and for effecting a connection over such link and trunk. Relay 1448 measures the interval for testing, while relay 1447 measures the time necessary for making the connection, as will be explained hereinafter. With relay 1446 operated a circuit is completed as before traced over the grounded

conductor 1222, outer left front contact of relay 1446, left contact of relay 1447, conductor 1451, contact of relay 1426, conductor 1452, middle lower contact of relay 1408, winding of relay 1414 to battery. Relay 1414 is individual to the selected group of outgoing trunks appearing in the lower half of the vertical row 1114 of the district selector switches. The relay 1414 associates the testing relays 1403 with the test conductors of the outgoing trunks 1134, 1129, 1135, etc. in the lower half of the vertical row 1114. The testing relay 1429 serves to test the first trunk 1134 in the group. The testing relay 1432 serves to test the second trunk 1129. Relay 1435 is arranged to test the third trunk 1135 and so on. Moreover, the relay 1429 is arranged to make a test of the horizontal link 1103, which has access to the outgoing trunk 1134 in the selected group. Also relay 1432 is arranged to make a test of the next horizontal link 1104 having access to the outgoing trunk 1129. Relay 1425 similarly serves to test the horizontal link 1105 having access to the outgoing trunk 1135. To this end the relays 1429, 1432 and 1435 are provided with two windings, the right-hand windings being employed for testing the outgoing trunks, and the left-hand windings for testing the corresponding horizontal links.

At the time the marker is associated with the district selector switch 1100, it will be assumed that the first trunk 1134 in the desired group is idle, link 1103 is busy, trunk 1129 is idle, link 1104 is idle, trunk 1135 is busy and that the link 1105 is busy. Under these conditions a path may be traced from battery through the right-hand winding of relay 1429, right contact of relay 1428, contact of relay 1414, conductor 1453 to the test conductor of trunk 1134. Since the trunk is idle no ground potential exists on the test conductor and therefore the right-hand winding of relay 1429 is not energized. Also, a path may be traced from battery through the left-hand winding of relay 1429, outer left back contact of relay 1428, contact of relay 1420, conductor 1454 to the test conductor 1137 of the horizontal link 1103. Since the link 1103 is busy the test conductor 1137 is grounded and hence the left-hand winding of relay 1429 is energized and the relay attracts its armatures. Relay 1429 locks in a circuit from battery through its right-hand winding and right contact, conductor 1455, middle right contact of relay 1446 to ground. Relay 1429 remains locked in this circuit even though the busy condition on link 1103 may subsequently be withdrawn in order to maintain undisturbed the starter circuit which will be explained presently. Relay 1429 also completes a circuit from battery through the winding of relay 1427, left contact of relay 1429 to ground

over conductor 1455. Relay 1427 operates and at its outer left contact closes an energizing circuit for relay 1428.

Another circuit is closed from battery 5 through the right-hand winding of relay 1432, right contact of relay 1431, contact of relay 1414, conductor 1456 to the test conductor of trunk 1129. The trunk 1129 being idle the right-hand winding of relay 1432 10 remains deenergized. Another circuit may be traced from battery through the left-hand winding of relay 1432, outer left back contact of relay 1431, contact of relay 1420, conductor 1458, test conductor 1138 of the 15 link 1104. Since under the assumption the link 1104 is idle the left-hand winding of relay 1432 remains inert.

Another circuit may be traced from battery through the right-hand winding of relay 1435, right contact of relay 1434, contact of relay 1414, conductor 1457 to the grounded test conductor of the busy trunk 1135. Still another circuit is completed from battery through the left-hand winding of relay 25 1435, outer left back contact of relay 1434, contact of relay 1420, conductor 1459 to the grounded test conductor 1139 of the busy link circuit 1105. With both windings of the relay 1435 energized, either of which 30 is sufficient to operate the relay, said relay attracts its armatures. A locking circuit is closed from battery through the right-hand winding and right contact of relay 1435 to the grounded conductor 1455. Furthermore, relay 1435 closes a circuit from battery 35 through the winding of relay 1433, left contact of relay 1435 to ground over conductor 1455. Relay 1433 in turn closes a circuit for relay 1434. In a manner similar to this the testing relays allotted to the 40 remaining trunks in the group and to the corresponding link circuits are operated, either due to the energization of one or the other or both of their windings, or else remain unoperated according to the conditions 45 existing on the trunks and links.

During the preparation of the testing relays, as above described, all of which takes place in a brief interval of time, the slow-to-release relay 1448 is maintaining its armatures attracted. Returning to the point 50 where relay 1446 is operated a circuit is closed from ground through the inner left contact of relay 1446, right front contact of relay 1447, conductor 1460, innermost upper contact of relay 1408, conductor 1461, contacts of relay 1426, conductor 1462, winding of vertical magnet 1121 to battery. The magnet 1121 rotates the associated operating 55 rod and prepares the contacts of each of the trunks in the vertical row 1114 for connection with the corresponding horizontal link circuit. Magnet 1121 also closes a circuit from ground through its contact, con-

ductor 1140, winding of relay 1449 to battery. Relay 1449 operates in this circuit.

As soon as the necessary time interval has expired the relay 1448 retracts its armatures and opens the circuit of relay 1447. While relay 1447 is maintaining its energization, a circuit is completed over the grounded conductor 1222 through the right contact of relay 1449, right contact of relay 1448, innermost right contact of relay 1446, conductor 1463, contacts of relay 1414, inner 65 left front contact of relay 1427, inner left back contact of relay 1430, winding of relay 1431 to battery. Relay 1431 attracts its armatures and closes the series start circuit for the windings of the horizontal operating magnet 1123 as follows: ground, through the left contact of relay 1449, conductor 1464, contact of relay 1414, right front contact of relay 1427, right back contact of relay 1430, thence through the left front 70 contacts of relay 1431, contacts of relay 1420, conductors 1458 and 1465 in parallel through the right-hand and left-hand windings, respectively, of the magnet 1123 to battery.

Magnet 1123 rotates the horizontal bar and thereby establishes connection between the link circuit 1104 and the incoming trunk 114 and between the link 1104 and the selected idle outgoing trunk 1129. Immediately that the link 1104 is connected to the trunk 114, a circuit is closed from battery through the right-hand winding of magnet 1123, contacts of the selector switch 1100, to the grounded test conductor 150 of 85 the trunk 114. Therefore, the horizontal magnet 1123 is locked in a holding circuit dependent upon the test conductor 150 and independent of the original operating circuits established in the common marker.

After the elapse of a second interval of time the relay 1447 retracts its armatures and opens the circuit of relay 1414. Relay 1414 releases and disconnects the testing relays 1403 from the sleeve conductors at the 90 outgoing group of trunks. Relay 1431 thereupon releases and opens the original energizing circuits of the horizontal magnet 1123. Relay 1447 also opens the circuit of the vertical magnet 1121. Magnet 1121 de- 95 energizes and restores the associated bar to its normal position ready for another use. Relay 1447, moreover, completes a circuit from ground through the inner left contact of relay 1446, right back contact of relay 1447, conductor 1467, winding of the release relay 1200 to battery.

Release of the district marker.

When relay 1200 operates it closes a temporary locking circuit for itself from battery through the winding and inner right front contact of said relay, outer left con-

tact of relay 1201, conductor 1531 to ground at the contact of relay 1501. Relay 1200 also completes a circuit from ground through its outermost right contact, winding of relay 1204 to battery. Relay 1204, which provides holding ground for the various energized relays in the district marker, is designed to be slow both in attracting and in releasing its armature. Hence, the relay 1204 does not open its contact until a definite interval following the operation of relay 1200. Relay 1200, furthermore, opens the circuit of relay 1206. Relay 1206 removes ground from the conductor 1225, whereupon the relays 1325, 1330, 1331, 1332, 1334, 1319, 1310 and 1305 become deenergized. The release of the translator multi-contact relays opens the circuit of relay 1408, which also retracts its armatures. Relay 1408 releases and also relay 1446 which in turn opens the locking circuits of relays 1429 and relay 1427 and also opens the circuits of relays 1427, 1433 and 1435. Relays 1427 and 1433, respectively, open the circuits of relays 1428 and 1434.

While the slow relay 1204 is still in its retracted condition following the operation of relay 1200, a circuit is completed momentarily from ground over conductor 1216 through the outer left contact of relay 1200, conductor 1226, contact of relay 1501, conductor 1541, winding of relay 513 to battery. Relay 513 energizes and locks in a circuit from battery through its winding and inner right contact to ground over conductors 506 and 507. Relay 513, at its outer left back contact, opens the circuit, previously traced, for the vertical magnet 1115. Magnet 1115 releases the associated bar and the connection through the district selector switch is now held alone by the maintained operation of the horizontal magnet 1123. Magnet 1115, on releasing, closes a circuit from battery through the winding of relay 205, inner lower front contact of relay 208, conductor 224, left back contact of magnet 1115, conductor 223, to ground through the right contact of relay 201 as traced. Relay 205 operates and locks through its left contact.

When relay 1204 finally operates it removes ground potential from conductor 1216, whereupon relays 1505 and 1201 release. Relay 1505 opens the circuit of relays 1501 and 1513, which also become deenergized. Relay 1501 opens the temporary locking circuit for relay 1200 and this relay, after an interval, retracts its armature. Relay 1200 opens the circuit of relay 1204 which becomes deenergized after the lapse of a given time interval. Relay 1501, on releasing, disconnects the recording sender from the common district marker and the relay 1338 of the thousands register thereupon release. At the time the vertical op-

erating magnet 1115 releases following the energization of relay 513, it opens the circuit hereinbefore traced for the multicontact relays 1423, 1420 and 1426. These relays become deenergized and disconnect the common district marker from the selector switch 1100.

Thus the operation of the release relay 1200, following selection of the district switch, brings about a disconnection of the marker from the recording sender and also a disconnection of the marker from the selector switch. The marker being released is restored to use and may again be associated with another sender and with the same or with another district selector switch.

Association of the recording sender with the line marker.

Up to this point the calling subscriber's line 101 has been extended through the district selector switch 1100 over a selected idle trunk 1129 to the group selector switch 1900 which serves the first terminal line group of 2000 lines wherein the called line 2031 is located. The next thing to be done is to associate the recording sender, on which is registered the information pertaining to the selection of the called line, with the line marker disclosed in Figs. 21, 22 and 23 having control over the group selector switch 1900 and the particular connector switch 2000 in which the called line appears.

If by the time the district marker is disassociated from the recording sender the calling subscriber has completed the dialing of all digits, a circuit is established for initiating the operation of the sender connector 2400 which connects the recording sender to the line marker. If, however, all digits have not been dialed, the completion of this starting circuit is postponed. Assuming that the units digit has been transmitted and the relay 927 operated, as hereinbefore related, a circuit is now established as follows: ground, through the inner left contact of relay 927, conductor 930, inner right contact of relay 517, conductors 518 and 519, inner left contact of relay 513, inner left back contacts of relays 502 and 503, lowermost contact of relay 501, outer right back contact of relay 520, outer left contact of relay 500, conductor 521, windings of relays 828 and 824 in parallel to battery. Relay 824 operates and closes the start circuit for the sender connector 2400 which may be traced from ground through the inner left contact of relay 927, thence over the path just described through the outer right back contact of relay 520, and from thence through the inner left back contact of relay 500, conductor 522, uppermost back contact of relay 825, lowermost front contact of relay 824, outer right back contacts of relays 806, 130

805 and 804 in series, conductor 836, lowermost upper front contact of relay 824, lower back contact of relay 825, conductor 838, winding of relay 2404 to battery.

- 5 It may be explained at this point that the sender connector 2400 is substantially the same as the sender connector 1500, already described in connection with the district marker. The connector 2400 comprises a plurality of multicontact relays 2401, 2402, 2405, 2406, etc., each individual to a different recording sender for connecting the sender to the line marker shown in Figs. 21, 22 and 23. The control circuits of the sender connector 2400 are, like those of the sender connector 1500, arranged to distribute the availability of the different groups of senders to the line marker in the event of simultaneous requirements. The multicontact relay 2401 is individual to the particular recording sender illustrated in the drawing, while the remaining multicontact relays represent other recording senders, not shown.

Relay 2404, in operating, completes a circuit from ground through its right contact, right back contact of group relay 2407, winding of group relay 2408 to battery. Relay 2408 operates and locks in a circuit from battery through its winding and right contact, conductor 2411, left back contact of relay 2412, through the left back contacts of other and similar relays, conductor 2413, outer right back contact of relay 2101, conductor 2119, contact of relay 2108 to ground. Relay 2408 also closes a circuit from battery through the right-hand winding of relay 2403, left contact of relay 2404, left contact of relay 2414, left front contact of relay 2408, thence to ground over conductor 2411 as traced. Relay 2403 energizes and closes a circuit from ground through its inner right contacts, winding of relay 2407 to battery. Relay 2407 completes a circuit from battery through the left-hand winding and left contact of relay 2403, left back contact of relay 2415, conductor 2417, winding of relay 2101 to the grounded conductor 2119. Relay 2403 locks and relay 2101 operates in this circuit. With relay 2403 operated a circuit is closed from battery through the winding of relay 2401, outer right contact of relay 2403, conductor 2418, inner left contact of relay 2101 to the grounded conductor 2119. Relay 2401 operates and connects the leads coming from the recording sender to the common line marker. Relay 2401 also closes a circuit from ground through its contact, conductor 2420, outer left contact of relay 2101, inner right back contact of relay 2104, winding of relay 2105 to battery.

When the relay 2105 energizes it closes a circuit which may be traced from ground through the contact of relay 2108, conductor 2119, inner right contact of relay 2101, front contact of relay 2105, conductor 2120, con-

tact of relay 2401, conductor 2421, uppermost contact of relay 828, conductor 839, outer right contact of relay 500, conductor 523, conductor 556, contacts of the sender selector switch 300, conductor 353, middle right contact of relay 205, uppermost front contact of relay 208, trunk conductor 225 through the operated contacts of the district selector, trunk conductor 1142, outer left contact of relay 1800, conductor 1810, right back contact of relay 1801, conductor 1802, winding of vertical magnet 1915 to battery. The magnet 1915 rotates the associated rod and prepares the contacts of the trunk 1129 for connection with any of the horizontal link circuits of the group selector switch 1900.

Transfer of the numerical record to the line marker.

With the sender connected to the line marker the numerical portion of the designation consisting of the thousands, hundreds, tens and units records may now be transferred and recorded in the marker. The terminal line group contains only 2000 lines and therefore the thousands digit is needed only for the purpose of determining which one of the two thousands is involved. If the thousands digit represents the first or even thousand of the group, the relay 2211 of the register 2241 is operated, whereas if the digit represents the odd or second thousand, the register relay 2212 is operated from the sender.

The hundreds, tens and units records are transferred from the recording sender and established on the respective relay registers 2203, 2204 and 2205 in the line marker. The three numerical registers in the line marker after receiving the complete record cooperate with each other through the translator device 2200 to select the particular vertical row of ten lines on the particular one of the eight connector switches 2000, which contain the called subscriber's line. The translator device 2200 consists of a bank of horizontal wires divided into two sections 2242 and 2243. The multicontact relay 2209, which is arranged to make contact with the upper section of the bank of wires, represents the odd thousand of the 2000 line group and is operated from the register relay 2212. The multicontact relay 2210, having access to the lower section 2243 of the translator, represents the even thousand of the 2000 line group and is operated from the register 2211. In addition to the thousands relays 2209 and 2210, there are provided ten multicontact relays of which two, 2207 and 2208, are shown. Each of these ten relays has contacts connectable to both the lower and upper sections of the translator and each such relay represents one of the ten different hundreds digits relating either to the even or to the odd thousand.

In the call at present under consideration the number of the wanted line was assumed to be 1326. It will be seen that this line belongs to the first group of 2000, and, 5 furthermore, belongs to the second or odd thousands of the first 2000 group.

Since the first digit is odd, a circuit may be traced as follows for the thousands register relay 2212: battery, through the winding 10 of said relay, conductor 2221, contact of relay 2401, conductor 2422, uppermost contact of relay 826, conductor 2421, and thence over the path previously traced through the connector 2400 to the grounded conductor 15 2119. With relay 2212 operated, a circuit is established from ground over conductor 2119, inner right contact of relay 2101, front contact of relay 2105, conductor 2120, contact of relay 2106, conductor 2123, front contact of relay 2212, right back contact of relay 2211, conductor 2244, winding of the multicontact relay 2209 to battery.

Regarding the hundreds digit, a circuit is completed from ground on conductor 2119, 25 thence over conductor 2120 through the connector 2400, through conductor 2421, in the manner above explained, uppermost contact of relay 828, lowermost contact of relay 828, conductor 840, outermost contact of hundreds register relay 814, conductor 841, contact of relay 2401, conductor 2423, winding of register relay 2216 to battery. Still another circuit is traceable from ground over the conductor 2421, uppermost and lowermost contact of relay 828, conductor 840, outermost contact of relay 815, conductor 842, contact of relay 2401, conductor 2424, winding of relay 2215 to battery. Relays 2215 and 2216 being operated and relays 2213 40 and 2214 unoperated, a circuit may be traced from ground over conductor 2123, inner right back contacts of relays 2213 and 2214, inner right contact of relay 2215, inner left front contact of relay 2216, winding of relay 45 2207 to battery. Relay 2207, representing the hundreds digit 3, operates and makes contact with the horizontal wires in the translator bank.

Considering the tens digit, a circuit may 50 be followed from ground over the conductor 2421 through the uppermost contact of relay 828, next to the uppermost contact of said relay, conductor 843, conductor 931, next to the outermost contact of relay 907, conductor 932, contact of relay 2401, conductor 2425, winding of relay 2219 to battery.

Lastly, the transfer of the units designation will be described. Since relay 916 of 60 the units register 901 is operated, a circuit is established over the grounded conductor 2421, uppermost contact of relay 828, next to the uppermost contact of relay 828, conductor 843, conductor 933, next to the outermost contact of relay 916, conductor 934,

contact of relay 2401, conductor 2426, winding of relay 2224 to battery. Still another circuit is established from the grounded conductor 2421, uppermost contact of relay 828, next to the uppermost contact of relay 828, 70 conductors 943 and 933, next to the outermost contact of relay 919, conductor 935, contact of relay 2401, conductor 2427, winding of relay 2221 to battery.

Operation of the connector and group selector switches. ⁷⁵

As soon as one of the relays 2209 or 2210 and one of the ten relays 2207, 2208, etc. has been operated, a circuit is closed for the 80 relay 2235. This circuit may be traced from battery through the winding of relay 2235, contact of relay 2209, contact of relay 2207, conductor 2248, to ground over conductor 2123. Relay 2235 operates and a circuit is 85 established from ground over the conductors 2123, 2263 and 2262, contact of relay 2235, conductor 2249, inner right contact of relay 2217, inner right back contact of relay 2218, inner right front contact of relay 2219, inner left back contact of relay 2220, conductor 2245, contact of relay 2209, horizontal conductor 2246, contact of relay 2207, conductor 2247, winding of the vertical magnet 2018 to battery. The magnet 2018 rotates the associated rod and prepares the contacts of the group of ten subscribers' lines for connection with the horizontal link circuits. In this manner the particular connector switch 90 2000 having access to the group of 250 subscribers' lines containing the called line 2031 has been determined, and, moreover, the particular group of ten subscribers' lines appearing in the vertical row 2006 containing said wanted line is selected. Now remains to select the wanted line out of the group and to determine an idle horizontal link circuit available for making connection with this line. ⁹⁵

Upon the operation of the vertical magnet 110 2018 on the connector switch 2000, a circuit is closed from ground through the contact of said magnet, conductor 2033, thence over conductor 2250 to the winding of multicontact relay 2239 to battery. Relay 2239 is 115 individual to the connector switch 2000 and serves to associate the units register 2205 with the units selecting device 2430, also individual to the connector switch. Relay 2239 also establishes a circuit from battery through the winding of relay 2236, the contact of relay 2239, conductor 2248, to ground over conductor 2123. ¹²⁰

It will be recalled that the register relays 2221 and 2224 are operated. Hence, a circuit is traced from ground over conductors 2123, 2263, 2248 and 2251 through the contact of relay 2236, conductor 2252, outer right contact of relay 2224, outer right contact of relay 2221, outer right contacts of re- ¹²⁵ ¹³⁰

lays 2222 and 2223, conductor 2253, contact of relay 2239, conductor 2254, winding of multicontact relay 2028 to battery. Relay 2028 represents the units digit 6 and when operated associates the testing relays 2202 in the common marker with the group of horizontal connecting circuit 2001 which have access to the subscriber's line in each of the twenty-five vertical rows 2006, 2007, 2008, the number of which has six for its units digit. While only two horizontal links 2009 and 2010 are shown in the group 2001, there may be any number, as for example, six such links, any one of which may serve 15 to connect the incoming trunk to the subscriber's line having units digit 6. The remaining horizontal link 2011 is common to the other connecting links in the group and has for its function to test the condition of 20 the subscribers' lines to which connection is desired.

It will be assumed that the first link 2010 in the group 2001 is busy and that the second link 2009 is idle. The remaining links, not 25 shown, in the group may be either in busy or idle condition. With the relay 2028 energized a circuit is completed from battery through the right-hand winding of test relay 2225, outer contact of relay 2226, conductor 2255, contact of relay 2028, conductor 2034 to ground over the conductor 2035 of the busy link 2010. It will be seen hereinafter how the test conductor of a busy link 30 is grounded. Relay 2225 operates and locks in a circuit from battery through its left-hand winding and contact, conductor 2256, to ground over conductor 2123. Another path may be traced from battery through the right-hand winding of relay 2227, outer 35 contact of relay 2228, conductor 2257, contact of relay 2028, conductor 2036, test conductor 2037 of the link 2009. Since the link 2009 is idle, no ground potential exists on conductor 2037, hence the test relay 2227 remains 40 inert. Similar circuits may be traced for each of the remaining test relays 2229, 2231, 2232 and 2233. These relays will operate or remain deenergized according as the 45 links are busy or idle.

At the time magnet 2018 operates, a circuit is also closed from ground through its contact, conductors 2033, 2250 and 2344 through the windings of multicontact relays 2314 and 2318 to battery. Multicontact relays 2314 and 2318 relate to the group of trunks leading 50 from the group selector switch 1900 to the particular connector switch 2000 and are, therefore, operated whenever any one of the vertical magnets 2018, 2019, 2020, etc. of 55 said connector switch is operated. These multicontact relays 2314 and 2318 associate the set of testing relays 2306 with the corresponding trunks of the group leading from the group selector switches to the particular 60 connector switch 2000. Had the called sub-

scriber's line been located on another connector switch, the operation of the vertical magnet on such connector would close a circuit over the conductor 2345 through the windings of relays 2313 and 2317 in parallel 70 to battery. Relays 2313 and 2317 represent the group of trunks extending from the group selector switch 1900 to said other connector switch and are arranged to associate the common testing relays 2306 with this 75 group of trunks. Still a third connector switch 2000, when taken for use, would complete a circuit over conductor 2346 for another set of multicontact relays, one of which, relay 2316, is shown. Multicontact relay 2316 80 serves to associate the common testing relays with the group of trunks extending from the group selector 1900 to said third connector switch. In like manner there are other multicontact relays, one for each group of 85 trunks leading to each of the eight different connector switches and which, when operated, associate the common testing relays 2306 with the corresponding groups of 90 trunks.

It was previously explained that a terminal group of 2000 subscribers' lines is served by a plurality of group selector switches similar to the switch 1900. Considering, for example, that there are four of these group 95 selectors. In order to associate the common line marker with the proper one of the four different selector switches, there are provided the multicontact relay sets 2300, 2301 and 2302. The relays 2307, 2311 and 2348 are individual to the particular group selector 1900, shown in the drawing. Relays 2308 and 2312 are individual to the second group selector. Relays 2309, 2349 and 2350 are individual to the third group selector and relays 2310, 2351 and 2352 are individual to the fourth group selector switch. Whenever a connection is extended over a trunk incoming to the group selector 1900, the relays 2307, 2311 and 2348 are operated for 100 the purpose of associating the common line marker with this particular group selector switch. Similarly, whenever the connection is extended over a trunk leading to any one of the other four group selector switches, the individual multicontact relays are operated for the same purpose. With this in mind and recalling the operation of the vertical magnet 1915, a circuit may be traced from ground through the contact of said magnet, conductor 1930, winding of relay 2307 to 105 battery. Relay 2307 closes a circuit from ground through its contact, conductor 2353, winding of relays 2311 and 2348 in parallel to battery.

With relay 2307 actuated and relay 2314 energized, as explained, a circuit is closed from ground through the contact of relay 2314, conductor 2347, contact of relay 2307, conductor 2354, winding of magnet 1918 to 110

115

120

125

130

battery. The operating magnet 1918 rotates the bar associated with the vertical row 1906 in the upper half 1902 of which appear a group of trunks extending to the connector 5 switch 2000.

Relay 2314 also closes a circuit from battery through the winding of multicontact relay 2355, conductor 2358, contact of relay 2314, conductor 2359, conductor 2360 10 to ground over conductor 2256. Relay 2355 identifies the upper section of the horizontal trunks in the group selector switch 1900, and, therefore, testing relays 2306 are connected through contacts of relay 2355 and contacts 15 of relay 2348 to the horizontal links 1902 in the upper half of the switch.

When magnet 1918 becomes energized it closes a circuit from ground through its contact, conductor 1931, contact of relay 2307, 20 conductor 2357, winding of relay 2113 to battery. Relay 2113 operates and a circuit is closed from battery through the winding of relay 2114, back contact of relay 2115, right contact of relay 2113, conductor 2359, thence over conductors 2360, 2256, 2248 and 2263, to ground. Relay 2114 operates and closes a circuit from battery through the winding of relay 2112, inner contact of relay 2114, to the grounded conductor 2123. Relay 2112 closes 25 a circuit from battery through the winding of relay 2116, right front contact of relay 2112, to the grounded conductor 2123. The control relays in Fig. 21 remain in their present condition until the group of trunks have 30 been tested and an idle one thereof ascertained.

Before proceeding further with the testing and selecting operations, a description will be made of the testing relay set 2306. 40 It was previously mentioned that there may be, as an example, four group selector switches 1900 into which incoming trunks from district selectors lead. Each of these four group selectors have access to each of 45 the several groups of trunks leading to the connector switches. The testing relay equipment is so arranged that when a particular group of trunks is selected the test for an idle one in the group is started at a given 50 point dependent upon the group selector over which the connection is being extended. In other words, the particular trunk in the group with which the testing operation is commenced differs in accordance with 55 which one of the four group selector switches is attempting to make connection with an idle trunk in the group. Assume that a given group of trunks outgoing from the group selector switch 1900 comprises thirty-five trunks, as hereinbefore suggested. This 60 group may be arbitrarily divided into four subdivisions of 9, 9, 9, and 8 trunks, respectively. Of course, any other suitable division of the four groups may be employed. 65 As regards the testing relay set 2306, there

will also be a division of these relays into four corresponding groups. As illustrated, the three relays 2320, 2321 and 2322 relate to the first trunk in the first group of nine; relays 2323, 2324 and 2325 relate to the second trunk in the first group of nine, and so on for the entire group of nine trunks. The three relays 2326, 2327 and 2328 represent the first trunk in the second group of nine; relays 2329, 2330 and 2331 represent the second trunk in the second group of nine, and so on. Relays 2332, 2333 and 2334 correspond to the first trunk in the third group of nine; relays 2335, 2336 and 2337 represent the second trunk in the third group of nine, etc. Similarly, relays 2338, 2339 and 2340 70 and relays 2341, 2342 and 2343 correspond respectively to the first and second trunks in the fourth group of eight. In the drawing, if a connection is extended into the final line 75 group by way of the group selector 1900, then the test in the group of trunks extending to the connector switch desired is commenced in the first subgroup of nine trunks, of which the trunks 1928 and 1927 are the 80 first and second trunks, respectively. If none of these trunks are idle, the testing is 85 continued in the next subgroup of nine trunks, and so on until an idle one is found. If, however, a connection is extended to the 90 final line group by way of the second group selector switch, not shown, then the testing operation is commenced in the second subgroup of nine trunks extending between the 95 group selectors and connector switches. In 100 like fashion, when connections are extended in by way of the third and fourth group selector switches, the testing operation for locating an idle trunk interconnecting the group selectors and connector switches is begun, respectively, in the third and fourth 105 subgroups of nine and eight trunks.

The disposition of trunks between the group selectors and connector switches may be seen from the schematic drawing given 110 in Fig. 35. Here, only three of the group selector switches 3500, 3501 and 3502 are shown. The group of thirty-five trunks is illustrated by the five trunks 3503, which are multiplied to all group selectors and extend to a connector switch 3504. When the connection is extended into the first group selector switch 3500, the relay 3506 operates and the start circuit 3515 is extended to operate the testing relay 3510 of the common 115 set of relays. The operation of relay 3510 determines that a trunk in the first subgroup, such as the trunk 3516, is to be employed if idle. When the connection is extended into the second group selector switch 3501, the multicontact relay 3507 is operated and the start circuit 3515 is extended to cause the operation of relay 3511 belonging to the second subgroup of testing relays. This relay determines that a trunk in the 120

second subgroup, such as the trunk 3517, is to be used. Likewise, when connections are extended in over the third group selector switch 3502 and the fourth group selector switch, not shown, the start circuit 3515 is led into different points of the testing relay series with the result that the testing for an idle trunk in the total group of thirty-five is commenced in a different 10 subgroup.

The connection here being discussed has been extended over the trunk 1129 to the first group selector switch 1900, and hence it will be seen that the testing operation commences in the first subgroup of nine trunks 15 extending from group selector 1900 to the particular connector switch 2000. It will be assumed that the first trunk 1928 in the desired group is idle, that the corresponding 20 horizontal link 1911 is busy, that the second trunk 1927 and the corresponding horizontal link 1910 are both idle. A path may now be traced from battery through the right-hand winding of testing relay 2322, 25 outer right back contact of relay 2320, outer right back contact of relay 2321, contact of relay 2314, conductor 2361 to the sleeve conductor 1932 of the trunk 1928. Since the trunk is idle no potential exists on the sleeve 30 conductor and hence the right-hand winding of relay 2322 remains deenergized. However, a circuit is also completed from battery through the left-hand winding of relay 2322, outer left back contact of relay 2320, conductor 2362, contact of relay 2355, 35 contact of relay 2348, conductor 2363 to the test conductor 1933 of the link 1911. The link 1911 being busy, ground exists on conductor 1933 and the left-hand winding of relay 2322 is energized to operate said relay. 40 Relay 2322 immediately locks in a circuit from battery through its right-hand winding and right contact to ground over the conductor 2359, as hereinbefore traced. Relay 2322, at its inner left contact, closes a circuit for relay 2321 and relay 2321 closes an energizing circuit for relay 2320.

Considering the second trunk in the group a path may be followed from battery 45 through the right-hand winding of relay 2325, outer right back contact of relay 2323, outer right back contact of relay 2324, contact of relay 2314, conductor 2364 to the sleeve conductor 1934 of the trunk 1927. The trunk 1927 being idle no potential exists 50 on the sleeve conductor and the right hand winding of relay 2325 remains deenergized. Another path may be traced from battery through the left hand winding of relay 2325, 55 outer left back contact of relay 2323, conductor 2365, contact of relay 2355, contact of relay 2348, conductor 2366 to the test conductor 1935 of horizontal link 1910. Inasmuch as the horizontal link is idle no potential exists on conductor 1935, and, there-

fore, the left-hand winding of relay 2325 remains inert. The fact that relay 2325 does not operate over either of its windings is an indication that the corresponding trunk and link circuits are simultaneously idle 70 and may be taken for the establishment of the connection. In a similar manner the succeeding test relays are associated with their corresponding trunks and links and operate or remain deenergized according to the 75 condition existing on said trunks and links.

After the testing relays have been positioned to indicate the condition of the trunks and links, a circuit is completed from ground over the conductor 2359 through the left contact of relay 2113, conductor 2125, contact of relay 2307, conductor 2367, inner left front contact of relay 2321, inner left back contact of relay 2324, winding of relay 2323 to battery. Relay 2323 operates 80 and prepares an operating circuit for the horizontal magnet 1926 of the selected link circuit 1910. The magnet 1926, however, does not operate to extend the connection 85 from the incoming trunk 1129 through to the connector switch until after a test has been made of the called subscriber's line to determine that this line is idle. Relay 2323, in operating, however, closes a circuit for the vertical operating magnet 2015 at the 90 connector switch 2000, which pertains to the row of contacts 2003 in which appears the trunk 1927 ascertained by the testing relays to be idle and available for the connection. The circuit for magnet 2015 may be traced 95 from ground over the conductor 2359, right contact of relay 2113, conductor 2126, inner right contact of relay 2323, middle right back contact of relay 2324, conductor 2368, contact of relay 2318, conductor 2369, winding of magnet 2015 to battery. Magnet 2015 rotates the associated rod and prepares the contacts in the row 2003 for connection 100 with the horizontal link circuit 2009. Magnet 2015, in operating, completes a circuit 105 from ground through its contact, conductor 2037, contact of relay 2318, conductor 2370, winding of relay 2115 to battery. Relay 2115 energizes and a circuit is closed from 110 ground over conductor 2359, right contact of relay 2113, front contact of relay 2115, conductor 2127, contact of relay 2028, conductor 2038, winding of the magnet 2023 to battery. Magnet 2023 rotates the associated 115 bar and connects the test link 2011 to the incoming trunk 1927 and also to the called subscriber's line 2031.

When relay 2115 operates it opens the circuit of relay 2114. Relay 2114, being slow to release, maintains its armatures for an interval after the circuit is opened. After the interval has expired, relay 2114 retracts its armatures and in so doing opens the circuit of relay 2112. Relay 2112 is 120 also slow to release and requires an interval 125

before its armatures are retracted. During this period a test circuit is closed to determine the condition of the subscriber's line 2031. This circuit may be traced from battery through the winding of test relay 2107, left contact of relay 2112, outer contact of relay 2114, conductor 2128, outer right front contact of relay 2323, outer right back contact of relay 2324, contact of relay 2314, conductor 2364, test conductor 1934 to the conductor 2039 of the test trunk 2011, thence to the test conductor 2040 of the called subscriber's line 2031. Assuming that the called line is idle, no ground potential exists on the test conductor 2040, and, therefore, the test relay 2107 in the line marker fails to operate. After the necessary interval expires, relay 2112 releases its armatures and opens the circuit of relay 2116. Relay 2116 being slow to release remains energized for an appreciable period after relay 2112 releases. During this time a circuit is completed from ground over conductor 2123, right back contact of relay 2112, right contact of relay 2107, outer left contact of relay 2117, conductor 2129, inner right front contact of relay 2321, inner right back contact of relay 2324, through the two left front contacts of relay 2323 over conductors 2365 and 2371, contacts of relay 2355, contacts of relay 2348, conductors 2366 and 2372, windings of magnet 1926 to battery. The magnet 1926 operates and the link 1910 is connected to the trunk 1129 and also to the trunk 1927, thus extending the connection through to the connector switch 2000. The instant the contacts of the trunk 1129 engage the link circuit 1910, a circuit is established from battery through the winding of relay 1801, test conductor 1803, contacts of the selector switch 1900, conductor 2363 to ground over the circuit just traced. Relay 1801 operates and closes a holding circuit for itself from battery through the winding of said relay, normal right contact of relay 1804, outer left contact of relay 1801, test conductor 1143, contacts of the district selector 1100, conductor 1138, contacts of the district selector to the test conductor 150, and thence to ground at the front contact of relay 204. With relay 1801 operated a holding circuit is closed for the horizontal magnet 1926 traceable from battery through the right hand winding of said magnet, contacts of the selector 1900, sleeve conductor 1803, normal right hand contact of relay 1804, outer left contact of relay 1801 to ground over the sleeve conductor 1143.

While relay 2116 is holding its armatures attracted, another circuit is completed from ground over conductor 2123, right back contact of relay 2112, right contact of relay 2107, inner left contact of relay 2117, conductor 2130, right front contact of testing relay 2225, right back contact of relay 2227,

winding of relay 2228 to battery. Relay 2228 operates and the grounded conductor 2130 is extended through the inner contact of relay 2228 to conductor 2258, contact of relay 2028, conductor 2041, left hand winding of horizontal magnet 2021 to battery. Magnet 2021 operates the associated rod whereby the trunk 1927 is extended over the link circuit 2009 to the called subscriber's line 2031. Immediately that the connector switch is operated a locking circuit is closed for the magnet 2021 from battery through its right hand winding, contacts of the connector switch, sleeve conductor 1934, contacts of the group selector 1900, conductor 1935, contacts of the group selector 1900 to the grounded sleeve conductor 1803.

Release of the line marker.

The apparatus is now in condition for applying ringing current to the called subscriber's line, but before proceeding with this phase of the connection a description will be given of the restoration of the line marker. At the end of the required interval following the release of the relay 2112, slow relay 2116 retracts its armatures. A circuit may now be traced from battery through the winding of release relay 2104, outer right contact of relay 2117, back contact of relay 2116, conductor 2131, outer right front contact of relay 2101 to ground over conductor 2119. Relay 2104 operates and closes a momentary locking circuit for itself through its winding and inner right front contact, outer left contact of relay 2101, to ground over the conductor 2420. Relay 2104 opens the circuits of relays 2105 and 2108. Relay 2108 is designed to operate slowly both on energization and deenergization. Hence, this relay does not release immediately. Relay 2105 removes ground from the conductor 2123, whereby the energized relays 2224, 2221, 2219, 2220, 2215, 2216, 2212, 2207, 2209 and 2235 retract their armatures. Relays 2225 and 2228 also become energized.

After an interval has expired relay 2108 attracts its armature and disconnects ground from the conductor 2119. Relays 2101, 2401, 2104, 2103, and 2107 are thereupon restored to normal and the line marker is disconnected from the recording sender. When relay 2101 releases it opens the holding circuit of relay 2104 and this relay deenergizes to in turn open the circuit of relay 2108. Relay 2101 also opens the locking circuit of relay 2117.

When relay 2105 operates it opens the circuit of the vertical magnet 2018 which deenergizes and restores the vertical rod to normal. Magnet 2018, at its contact, opens the circuit of the relays 2314 and 2318. Relay 2314 deenergizes and opens the circuit of the vertical magnet 1918. Magnet 1918

- 1918 releases and restores the vertical rod to normal and also opens the operating circuit of relay 2115. Magnet 2018 also opens the circuit of relay 2239, which in releasing 5 opens the circuit of relay 2028, whereby the line marker is disconnected from the connector switch 2000. Relay 2105 also opens circuit of magnet 2023 which is deenergized. When the line marker is disconnected from 10 the recording sender the circuit hereinbefore traced for the incoming vertical magnet 1915 is opened when 2108 operated. Magnet 1915 restores the associated rod to its normal position. The connection through 15 the group selector and connector switches is now held by the maintained energization of magnets 1926 and 2021 under the control of the calling subscriber's switchhook.

Release of the recording sender.

- 20 During the interval that relay 2108 is holding its armature retracted following the operation of release magnet 2104, a circuit is momentarily completed from ground 25 through the contact of relay 2108, conductor 2119, outer left contact of relay 2104, conductor 2132, contact of relay 2401, conductor 936, winding of relay 500 to battery. Relay 500 operates and locks in a 30 circuit from battery through its winding and inner right contact to the grounded conductor 506. Relay 500 closes a circuit which may be traced from ground through the inner left contact of relay 927, thence 35 over conductor 930, inner right contact of relay 517, conductor 518, conductor 519, inner left front contact of relay 513, inner left back contacts of relays 502 and 503, lowermost contact of relay 501, outer right 40 back contact of relay 520, inner left front contact of relay 500, conductor 557, outer left back contact of relay 1013, conductor 1014, conductor 525, winding of relay 412 to battery. Relay 412 becomes energized 45 and locks in a circuit from battery through its winding and inner right contact, conductor 348, to ground at the innermost right contact of slow relay 402. Relay 412, at its left-hand contacts, opens the circuit 50 including the calling subscriber's line 101 and the impulse relay 400. Relay 400 releases and opens the circuit of relay 401. Relay 401, after an interval, retracts its armatures and opens the circuit of relay 55 402. After a further interval, the slow relay 402 becomes deenergized. Ground potential is removed from the various holding conductors and the energized relays in the recording sender are all released. 60 When relay 402 releases it opens the circuit of the horizontal magnet 310 of the sender selector switch 300 and also opens the holding circuit of the relay 201. Magnet 310 restores the associated rod and the 65 recording sender is disconnected from the
- trunk circuit 114, ready to be taken for use in connection with a subsequent call. When relay 201 releases it opens the circuit of relay 204. Relay 204, however, holds its armatures attracted for an interval of 70 time. During this interval a circuit is established from battery through the lower left hand winding of repeating coil 227, winding of supervisory relay 203, lowermost contact of relay 202, left hand normal 75 contact of relay 201, conductor 149, thence through the line switch and over the calling subscriber's line, returning by way of trunk conductor 148, right hand normal contact of relay 201, uppermost back contact of 80 relay 202, upper left hand winding of repeating coil 227 to ground. Relay 203 operates in series with the calling subscriber's line and completes a new holding circuit for the slow relay 204. Relay 204 is now 85 held under the control of the calling subscriber's switchhook and maintains ground potential on the sleeve conductor 150 to hold the line switch 100, district selector switch 1100, and the group selector and connector switches 1900 and 2000, respectively. When the relay 201 retracts its armatures it opens the holding circuit of relay 208. Relay 208 releases and completes the tip and 90 ring conductors of the trunk 114 from the repeating coil 227 through to the district selector switch 1100.
- 95
- Application of ringing current to the called line.*
- 100
- When the group selector switch 1900 operates it connects, in the manner above described, a source of ground potential from the line marker to the sleeve conductor 1803, winding of relay 1801 to battery. A branch 105 of this circuit also leads through the outer right hand contact of relay 1805, contact of relay 1806, winding of relay 1807 to battery. Another branch leads through the right hand winding of relay 1805, right hand normal contacts of the relay, winding of relay 1807 to battery. Relay 1807 operates but relay 1805, being shunted by the relay 1806, remains deenergized at this time. Relay 110 1807 completes a circuit from battery through the winding of relay 1800, conductor 1808, outermost left contact of relay 1807, to ground over the sleeve conductor 1143. Relay 1800 becomes energized and locks in a circuit from battery through its 115 winding and inner right contact to the grounded sleeve conductor 1143. Relay 1800, at its left back contacts, disconnects the trunk conductors 1142 and 1144 from the conductors 1810 and 1811, respectively, 120 and this occurs prior to the time relay 208 releases, following the restoration of the recording sender to extend the circuit including the repeating coil 227 through to the 125 trunk conductors 1142 and 1144. Relay 130

- 1800, moreover, establishes a circuit from ground through its inner left front contact, conductor 1811, inner left front contact of relay 1801, left hand winding of relay 1804 to battery. Relay 1804 energizes and at its right hand make-before-break contact applies ground to the conductor 1803 in substitution of the ground potential momentarily applied by the line marker during the operation of the group selector. The horizontal magnets 1926 and 2021 and relays 1807 and 1801 are held under the control of the relay 1804 after the line marker is disconnected.
- 15 Relay 1807, in operating, closes the ringing circuit which may be traced as follows: from the source of ringing current 1822 through the winding of marginal relay 1806, inner front contact of relay 1807, conductor 1814, contacts of group selector switch 1900, trunk conductor 1938, contacts of connector switch 2000, line conductor 2043 over the loop of the subscriber's line, line conductor 2042, contacts of connector switch 2000, 25 trunk conductor 1937, contacts of group selector switch 1900, trunk connector 1813, middle front contact of relay 1807 to ground. Relay 1806, being marginal, does not operate while the called subscriber's receiver is on the switchhook.
- The calling subscriber in removing his receiver responsive to the ringing of his call bell reduces the resistance of the circuit sufficiently to permit the operation of relay 35 1806. Relay 1806 opens the shunt around the right hand winding of relay 1805. Relay 1805 operates and locks in a circuit from battery through its right hand make-before-break contact and right-hand winding to ground at the right hand front contact of relay 1804. Relay 1805, at its outer right contact, opens the circuit of relay 1807, which releases and disconnects ringing current from the subscriber's line.
- 40 45 Upon the release of relay 1807 the talking circuit for supplying current to the called subscriber's line is established and may be traced as follows: battery, through the innermost lower back contact of relay 207, innermost lower back contact of relay 206, lower half of the lower right hand winding of repeating coil 227, winding of relay 231, lowermost back contact of relay 208, thence over the ring conductor of the trunk 114 through the district selector, group selector and connector switches over the called subscriber's line and returning over the tip side of the trunk to the uppermost back contact of relay 208, upper half of the upper right hand winding of repeating coil 227, upper back contact of relay 206, inner upper back contact of relay 207 to ground. It will be noted that only half of the right hand windings of repeating coil

227 is included in the talking circuit. The 65 call, being a local one, involves a comparatively short conversational circuit which requires a minimum of inductive loading.

Release of the established connection.

After the conversation is over the calling and called subscribers replace their receivers on the switchhooks and the connection is automatically restored. When the calling subscriber hangs up his receiver he opens 75 the circuit through the left hand windings of repeating coil 227 and the winding of supervisory relay 203. Relay 203 retracts its armature and opens the circuit of relay 204. After an interval relay 204 retracts its armature and in so doing removes ground potential from the sleeve conductor 150. The removal of ground potential from the sleeve conductor results in the deenergization 80 of horizontal magnet 124, relay 126, cut 85 off relay 120 and trunk relay 146. The magnet 124, in releasing, restores the line switch 100 and the calling subscriber's line is thereby disconnected from the trunk 114. The removal of ground from the sleeve conductor 90 also results in the deenergization of horizontal magnet 1126 of the district selector, whereby said selector restores to normal and disconnects the trunk 114 from the trunk 1129. When ground potential is 95 withdrawn from the sleeve conductor 1143, the circuit of relay 1800 is opened and this relay becomes deenergized. Relay 1800 opens the circuit through the left hand winding of relay 1804. If however, the 100 called subscriber has not yet replaced his receiver on the switchhook, relay 1804, being slow to release, is held energized in a new circuit which may be traced as follows: battery, through the left-hand winding of 105 said relay, inner left front contact of relay 1801, conductor 1811, inner left back contact of relay 1800, conductor 1144, inner left back contact of relay 1807, conductor 1814, thence through the group selector and the 110 connector switches over the called subscriber's line and returning by way of conductor 1813, outermost back contact of relay 1807, conductor 1142, outer left contact of relay 1800, conductor 1810, inner right front contact of relay 1801, right hand winding of 115 relay 1804 to ground. Relay 1804 remains energized in series with the called line and maintains ground potential on conductor 1803 to hold the group selector and connector switches in their operated condition. The trunk 1129 is held busy by the following path: ground at outer right contact of relay 1800, left contacts of relays 1804 and 1801 to sleeve conductor 1143.

When the called subscriber finally replaces his receiver on the switchhook, relay 1804 releases and opens the holding circuits 125

of relays 1801 and 1805. Also relay 1804 removes ground from conductor 1803, whereby the circuits of horizontal magnets 1926 and 2021 are opened. These magnets release the associated bars and the group selector and connector switches are thereby restored.

The called subscriber's line tests busy.

10 It was first assumed that the called subscriber's line 2031 was found to be idle when a test was made by the line marker through the common test horizontal trunk or link circuit 2011. It will now be considered 15 that the line is busy when the test is made and an explanation will be given of how the system functions under this condition. Returning to the point where relay 2114 releases its armatures, the circuit from battery through the winding of the test relay 2107 through the left-hand contact of relay 2112 through the outer contact of relay 2114 is completed, as above traced, over conductor 2128 to the conductor 1934, contact of 25 the horizontal test link 2011, conductor 2039 of said link, contact of link 2011, conductor 2040 of the called subscriber's line, thence through the contacts of the particular connecting link which is rendering the called 30 subscriber's line busy to ground over the sleeve conductor of the existing connection. The test relay 2107, therefore, energizes and locks in a circuit from battery through its winding and inner left contact to the 35 grounded conductor 2123.

After the necessary time has elapsed relay 2112 becomes deenergized. The circuit hereinbefore traced for the horizontal magnets 1926 and 2021, which was completed at the 40 right back contact of relay 2112, is now held open at the right contact of relay 2107. Hence, the connection is not made through the group selector and connector switches to the called subscriber's line when it is ascertained to be busy. Relay 2112 opens the 45 circuit of relay 2116, which, after an interval, releases its armature and completes the circuit for the release relay 2104 in the manner explained. During the interval following the energization of relay 2107 and prior to the operation of relay 2104 a circuit is closed as follows to transmit an indication from the line marker back to the recording sender that the called line was 50 found busy: ground, over conductor 2123, outer left contact of relay 2107, conductor 2133, contact of relay 2401, conductor 2428, winding of relay 517 to battery. Relay 517 operates and locks in a circuit from battery 55 through its winding and innermost left contact to ground over conductors 509 and 507. Relay 517, at its middle left contact, closes a circuit for the register 526 which operates to record the fact that a connection was at

tempted and failed because the called line 65 was found busy. Relay 517 also closes a circuit from ground through the left hand winding of the tone coil 527, outer right front contact of relay 517, conductor 528, outer left front contact of relay 710, 70 conductor 733, condenser 424, lower winding of coil 422, conductor 425, to ground at the outer left contact of relay 402. The induced current in this circuit in turn induces a current in the upper winding 75 of coil 422 which flows over the calling subscriber's line, producing a characteristic sound which he recognizes as a busy signal.

After a time the relay 2104 in the line marker operates and the line marker is disassociated from the recording sender in the manner above described. Also the circuit above traced is closed for the operation of relay 500. It will be recalled that relay 500 in operating, after the called line has been 80 found idle, closed a circuit for the sender release relay 412. In the present case, however, where the called subscriber's line is busy, the relay 517 is operated and hence the relay 500 fails to close the circuit mentioned for the relay 412. The recording sender, therefore, does not release automatically but is held under the control of the calling subscriber until he hangs up his receiver. The calling subscriber hearing the 85 busy tone in his receiver knows that the wanted line is busy and thereupon restores his receiver to the switchhook. The act of hanging up the receiver opens the circuit of relay 400 which initiates the release of 90 the recording sender and sender selector switch in the manner already described. Moreover, the restoration of the calling subscriber's receiver removes ground potential 95 from the sleeve conductor 150 and the partially established connection is restored to normal.

Message registration.

If the subscribers' lines are provided with 110 message registers for measuring the service rendered, they may appear in line switches 100 which have access to trunk circuits especially equipped for making charges at the end of conversation. Assuming that the 115 subscriber's line 101 is provided with a message register 172, this line will have access through the line switches to one of the specially equipped trunk circuits. For the purpose of illustration, the trunk 114, already 120 discussed, is shown as provided with the additional relays 228, 229 and 230, employed in connection with the message register operation.

Consider that the subscriber of line 101 125 has succeeded in building up a connection in the manner hereinbefore discussed to the called subscriber's line 2031, which was

- tested and found to be idle. In response to the ringing the called subscriber removes his receiver from the switchhook and in so doing ringing current is disconnected from the called line and relay 1807 restores its armatures. With relay 1807 released a circuit, including the called subscriber's line, is completed over the tip and ring conductors through the connector, group selector and district selector switches through the right hand winding and repeating coil 227 to battery and ground at the contacts of relay 207. This circuit, it will be noted, includes the supervisory relay 231. Relay 231 operates and completes a circuit from battery through the winding of relay 229, contact of relay 231, left back contact of relay 230, to the grounded conductor 150. Relay 229 energizes and locks in a circuit from battery through its winding and right contact, right back contact of relay 228, to ground at the left contact of relay 204. The relay 229 is thus operated in response to the removal of the called subscriber's receiver to record the fact that the call proved to be successful.

- At the end of the conversation when the calling subscriber hangs up his receiver, the circuit of relay 203 is opened and this relay releases to close the following circuit: battery, through the winding of slow-to-release relay 228, left contact of relay 229, back contact of relay 203 to ground. Relay 228 operates and before relay 204 releases, the following circuit is established: battery, through the winding of relay 204, right front contact of relay 228, left contact of relay 204 to ground. Relay 204 is thereby held operated after the release of relay 203. Relay 228, in operating, opens the circuit of relay 229 and this relay immediately deenergizes. Relay 229, at its left contact, opens the circuit of relay 228 which, after the required interval, retracts its armatures. Relay 228, upon releasing, opens the holding circuit of relay 204 and after a further interval this latter relay becomes deenergized to release the established connection, as hereinbefore described.
- During the period measured by the slow-to-release relays 228 and 204, a circuit is completed for operating the calling subscriber's message register 172. This circuit is traceable from ground through the left contact of relay 228, conductor 152, contacts of line switch 100, conductor 173, winding of message register 172, to battery.

- In telephone systems where message registration is employed for measuring the service rendered to subscribers' lines, it is frequently necessary to provide for connections to certain classes of lines free of charge. Such lines as these are known as free lines and include lines extending to fire and police

stations, hospitals and the like. According to the present system if a subscriber, whose line is equipped with a message register, extends a connection to one of these free lines, an indication is first recorded in the line marker, which thereafter transmits the indication back into the recording sender, which influences the trunk circuit in such a manner that normal operation of the message register is prevented at the end of the conversation. Assume that the line 2044 is a free line. In order to prevent message registration on connections extended to this line, it is only necessary to connect the conductor 2259 extending from the common marker to the contact of line 2044 which engages the horizontal conductor 2045 of the common test link 2014. When, during the establishment of the connection, the horizontal link magnet 2026 is operated to connect in the common test link 2014, a circuit is completed from battery through the winding of the relay 2102, conductor 2259, contact of link 2014 in the vertical row 2008, conductor 2045, contact of link 2014 in the vertical row 2003, conductor 2262 to ground. Relay 2102 operates and locks in a circuit from battery through its winding and right contact to ground over conductor 2120. Relay 2102 closes a circuit from ground through its left contact, conductor 2134, contact of relay 2401, conductor 2429, winding of relay 937 to battery. Relay 937 operates and locks through its right contact to ground over conductor 506.

In the manner hereinbefore described the line marker is disconnected upon the completion of the call and while undergoing release prepares the recording sender for restoration by bringing about an operation of the relay 412. When relay 412 operates it closes a circuit from ground through its outer right contact, conductor 444, outer left contact of relay 529, left front contact of relay 937, conductor 530, outer left front contact of relay 513, conductor 515, thence through the sender selector switch 300 to conductor 352, inner right front contact of relay 205, winding of relay 230 to battery. Relay 529 will be operated at this time in the manner hereinafter explained. Relay 230 operates and locks through its upper front contact to the grounded sleeve conductor 150. When the called subscriber answers, relay 231 is operated as described. Relay 231 closes its left contact but the circuit of relay 229 is now held opened at the upper back contact of relay 230 which was operated since the called line was a free line.

At the end of conversation when the calling subscriber replaces his receiver on the switchhook, relay 204 releases and disconnection takes place, as previously described. Where the relay 229 remains deenergized

relay 228 will not energize and, therefore, the circuit of the calling subscriber's message register 172 is held opened and the call is not charged.

5 *Monitoring the recording sender.*

The recording sender is so arranged that if irregularities in operation occur the presence of these conditions and their exact nature are brought to the attention of a monitoring operator whose position is designated generally by the character 445 in Fig. 4. For instance, the calling subscriber may remove his receiver from the switchhook and then fail to transmit impulses within a prescribed interval of time. Again he may dial the first digit but fail to dial all the digits. Moreover, a complete record may be received on the sender but for some reason or other the sender fails to function properly within a definite time. All of these conditions are brought to the attention of the monitoring operator by suitable signals and a peg count record is taken of each occurrence of each kind of trouble.

Assume that the calling subscriber removes his receiver from the switchhook and then fails to transmit any impulses. The initiation of a call causes the recording sender to be attached by the sender selector and relay 402 applies ground potential to the conductor 507. When this happens a circuit is closed from battery through the winding of time measuring device 532, lowermost back contact of relay 533, middle contact of device 532 to ground over conductors 531 and 507. The device 532 energizes in this circuit and immediately moves its plunger element to the full extent of its forward stroke. The device 532 is so arranged that the plunger on its initial forward movement opens the lowermost contact and at the extreme end of its forward movement opens the middle contact and closes the uppermost contact. After reaching its full forward position the device 532 commences to restore under the control of a dash-pot, escapement or other suitable method, and measures an appreciable interval of time during its release. The device is further arranged such that at the beginning of its restoration it opens its uppermost contact and closes its middle contact, but does not close its lowermost contact until it measures the interval and reaches its fully restored position.

When the device 532 reaches its operative position it opens its own circuit and also closes a circuit from battery through the winding of relay 533, uppermost contact of device 532, outer left back contact of relay 534, middle left contact of relay 529, to ground over conductor 531. Relay 533 operates and locks through its innermost lower contact, right back contact of relay 534, mid-

dle left contact of relay 529, to ground over conductor 531. Under the assumption the device 532 has time to restore to its normal position before the subscriber dials the first series of impulses. On reaching its restored position, said device closes a circuit from battery through the winding of relay 535, right back contact of relay 529, lowermost contact of device 532, lowermost front contact of relay 533, middle contact of device 532 to the grounded conductor 531. Relay 535 operates and locks in a circuit from battery through its winding and innermost left contact, to ground over conductor 531. Relay 535 closes a circuit from ground through its inner right contact, right back contact of relay 536, left back contact of relay 537, conductor 538, left contact of relay 409, lamp 446 to battery. The lamp 446, which is located at the monitoring operator's position illuminates to advise the operator that a sender has been seized and that the first series of impulses has not been received within the allotted time. The monitoring operator may take such action as is necessary to ascertain the nature of the trouble.

The relay 535 also initiates the operation of the sender connector 1500 to connect the district marker to the recording sender for the purpose of governing the operation of the district selector switch to extend the calling subscriber's line to a trouble operator's position. The circuit for operating the sender connector may be traced from ground through the middle left contact of relay 535, conductor 540, outer right back contact of relay 513, conductor 514, winding of relay 1509 to battery. Relay 1509, in the manner hereinbefore described, operates the sender connector to connect the district marker to the particular recording sender attached to the subscriber's line. When the marker is associated with the sender a circuit is completed from ground through the outermost left contact of relay 535, conductor 539, contact of relay 1501, conductor 1542, winding of relay 1209 to battery. Relay 1209 operates and locks in a circuit through its winding and contact, conductor 1225, contact of relay 1205, inner left contact of relay 1206, to ground through the contact of relay 1204. Relay 1209 completes a circuit over the grounded conductor 1216, inner right contact of relay 1206, inner left contact of relay 1209, conductor 1227, thence over conductor 1354 to a particular group relay similar to the relays 1406, 1407, 1408, etc. in the district marker, which is individual to the group of trunks of the district selector switch 1100 leading to the trouble operator's position. In the manner already thoroughly explained, this group relay causes the selection of the group of trunks and the selection of an idle trunk therein, whereby the calling sub-

scriber's line is extended through the district selector to the operator's position.

- Relay 1209, moreover, closes a circuit from ground through the outer right contact of relay 1206, outer left contact of relay 1209, conductor 1228, thence over conductor 1355, contact of relay 1501, conductor 1543, winding of relay 542 to battery. Thus the district marker, through the class conductors 1336 of the district translator 1300, establishes a circuit leading back to the recording sender whereby an indication is produced in the sender that the call undergoing extension is one of the class involving the selection of an operator's position. With this information the recording sender is enabled to govern its action to meet the requirements of that particular class of call. The relay 542, in operating, locks through its winding and inner right contact to the grounded conductors 531 and 507.
- As soon as the district selector switch has functioned, the district marker is prepared for restoration. Just before the district marker releases from the recording sender a circuit is closed, as hereinbefore traced, for the operation of relay 513. Relay 513 locks through its winding and inner right contact to the grounded conductor 506. Relay 513 having operated, a circuit for the releases relay 412 is established from battery through the winding of said relay 412, conductor 525, conductor 543, outer right front contact of relay 542, outer right back contacts of relays 503 and 502, outer left back contact of relay 504, outer right front contact of relay 513, conductor 540, to ground at the middle left contact of relay 535. Relay 412 operates and in the manner hereinbefore explained brings about the restoration of the recording sender, inasmuch as the sender has been notified by the district marker that its service will no longer be required in connection with this particular call. The trouble operator may communicate with the calling subscriber and complete the connection for him manually, if desired. At the end of conversation release of the operated equipment may take place in the usual manner.

Consider next that the calling subscriber, after initiating a call, transmits the first series of impulses regularly but that he fails to complete the transmission of all series of impulses within a prescribed interval following the transmission of the first series. This is known as an unfinished dialing condition in the sender and the presence thereof should be brought to the attention of the monitoring operator. When the first series of impulses are transmitted the relay 710 is operated, as hereinbefore explained. Relay 710 closes a circuit from ground through its inner left contact, conductor 753, wind-

ing of relay 529 to battery. Relay 529 operates and opens the circuit of relay 533, which is locked at this particular instant. Relay 533 releases and in so doing recloses the circuit of the time measuring device 532, which device at this time is in the act of restoring to its normal position. The reclosure of the circuit of device 532 immediately causes said device to move back to the end of its forward stroke. When relay 533 releases a circuit is closed from battery through the winding of relay 534, inner left contact of relay 529, uppermost back contact of relay 533 to ground over conductor 531. Relay 534 operates and locks through its inner left contact to ground over conductor 531. Therefore, when the device 532 is moved back to its fully operated position following the transmission of the first series of impulses, relay 533 is again operated in a circuit from battery through its winding, uppermost contact of device 532, outer left front contact of relay 534, outer left back contact of relay 544, outer left contact of relay 545, to ground over conductor 531. Relay 533 operates and locks through its winding and innermost lower contact, right front contact of relay 534, right back contact of relay 544, to ground over conductor 531.

Having again reached its full forward position, the device 532 opens its own circuit and commences to release measuring a new interval of time which starts with the instant the first series of impulses are transmitted over the line. Under the assumption the subscriber does not finish the dialing of all series within this required interval of time, therefore, the device 532 fully restores to normal before the units series of impulses are received and relay 927 is operated. This being the case a circuit is established from battery through the winding of relay 536, right back contact of relay 545, right front contact of relay 529, lowermost contact of device 532, lowermost front contact of relay 533, middle contact of device 532, to ground over the conductor 531. Relay 536 operates and locks to the grounded conductor 531. Relay 536 establishes a circuit from ground through the resistance 546, right front contact of relay 536, left back contact of relay 537, conductor 538, left contact of relay 409, lamp 446 to battery. Due to the resistance 546 the lamp 446 burns dimly and this signal advises the monitoring operator that an unfinished dialing condition exists in the sender.

The next assumption is that the subscriber transmits the first series of impulses within the allotted time, transmits all series of impulses in the regular manner, but that the recording sender fails to complete its func-

tions within a definite time following the receipt of the last series of impulses. A condition of this kind is due to what is known as a "stuck" sender and the monitoring operator should be advised accordingly.

- When the last or units series of impulses are received in regular operation, the relay 927 actuates before the device 532 has time to restore to normal. A circuit, therefore, is closed from ground through the inner left contact of relay 927, conductor 930, inner right contact of relay 517, conductor 518, winding of relay 545 to battery. Relay 545, at its outer left contact, opens the locking circuit of relay 533 and this relay immediately releases and recloses the energizing circuit of the device 532. The device 532 thereupon moves back to its forward position, opens its own circuit and commences to release gradually to measure a third interval of time which is calculated as sufficient for the sender to complete its function when acting normally. The relay 545, in operating, closes a circuit from battery through the winding of relay 544, inner left contact of relay 545, inner upper contact of relay 533, to ground over conductor 531. Relay 544 operates and when the device 532 moves back to its full forward position in readiness to commence the measurement of the third interval, the relay 533 is energized in the following circuit: battery, through the winding of relay 533, uppermost contact of device 532, outer left front contact of relay 534, outer left front contact of relay 544, conductors 509 and 507 to ground. Relay 533 locks through its innermost lower contact, right front contacts of relays 534 and 544, to ground over conductor 509.
- Since the sender fails to function properly the device 532, in restoring to its normal position, closes a circuit from battery through the winding of relay 537, inner right contact of relay 510, outermost left contact of relay 517, right front contact of relay 545, right front contact of relay 529, lowermost contact of device 532, lowermost front contact of relay 533, middle contact of device 532 to ground over conductor 531.
- Relay 537 operates and locks to the grounded conductor 531. Relay 537 completes a circuit from ground through the interrupter 547, left front contact of relay 537, conductor 538, left contact of relay 409, lamp 446 to battery. Due to the interrupter 547, the lamp 446 flashes to instruct the monitoring operator that a "stuck" sender condition exists. The monitoring operator may insert the plug of her cord circuit in the jack 447 and communicate with the calling subscriber advising him to repeat the attempted connection and may take such other action as is necessary.

Should the sender complete its functions

before the device 532 has time to restore, release then takes place, as above explained, before the monitoring operator can be given a signal.

Extension of connection to an operator's position. 70

In some cases the subscriber may wish to obtain connection directly with an operator who may give him such information as he requires, or may complete the connection through to another operator or to the called subscriber's line. For this purpose the subscriber dials a single digit 0. Digit 0 is represented by a series of ten impulses which, from inspection, will be found to result in the operation of counting relays 413, 416, 417 and 418. With these relays operated and relay 709 actuated, a circuit may be traced from ground over the conductor 432, outer left front contact of relay 413, conductor 442, outer right front contact of relay 418, conductor 448, uppermost contact of relay 709, windings of relays 707 and 708 in series to battery. Relays 708 and 707 operate and lock in a circuit through the right contact of relay 707, to ground over conductor 736. Relay 707 completes a circuit from the grounded conductor 736 through its left contact, conductors 739 and 740, winding of relay 505 to battery. Relay 505 operates and closes the circuit for relay 1509, whereby the sender connector 1500 operates to associate the recording sender with the district marker.

Providing relay 1205 in the district marker is released, and since the register 1301 remains in normal position, no code digit having been dialed, a circuit is closed from battery through the winding of relay 1210, conductor 1229 to the inner right back contacts of relays 1327, 1326, 1325 and 1324, conductor 1343, contact of relay 1205, inner left contact of relay 1206, to ground through the contact of relay 1204. Relay 1210 operates and locks through its right contact to the grounded conductor 1225. Relay 1210 closes a circuit from ground over conductor 1216, inner right contact of relay 1206, inner left contact of relay 1210, conductor 1230, thence over the conductor 1357 to one of the group relays 1406, 1407 and 1408 in the district marker individual to the group of trunks leading from the district switch to the desired operator's position. In response to the operation of this group relay, selection of the group of trunks and the operation of the district switch takes places in the manner already described and the calling subscriber's line is extended through to the operator's position.

Relay 1210 also closes a circuit from ground through the outer right contact of relay 1206, outer left contact of relay 1210,

thence over the conductor 1228 in the manner traced, to relay 542 in the recording sender. Relay 542 operates and governs the behavior of the sender in the manner explained.

On an operator's call it is not necessary to utilize the repeating coil 227 in the trunk circuit for talking purposes inasmuch as the operator's cord circuit is ordinarily provided with means for supplying conversational current. The adjustment of the trunk circuit 114 to eliminate the repeating coil for this particular class of call is taken care of by the common link circuit 1131 of the 15 district selector switch 1100. It will be recalled that the link 1131 is connected in circuit whenever one of the incoming vertical magnets 1115, 1116, 1117, etc., is operated. Therefore, when the relay 1210 operates on 20 a call of this character it also closes a circuit from ground over the conductor 1228 as traced, conductor 1358, conductor 1359, contacts of horizontal link 1131 in the vertical row 1108, conductor 1145, winding of 25 relay 202 to battery. Relay 202 operates and locks in a circuit from battery through its winding and inner lower front contact to the grounded sleeve conductor 150. Relay 202 completes a circuit from battery 30 through the winding of relay 208, inner upper contact of relay 202, to the grounded conductor 150. Relays 202 and 208 being operated, the subscriber's line is extended for conversation over the tip and ring conductors 148 and 149 of the trunk 114 through the normal contacts of relay 201, which relay releases when the sender is discharged, front contacts of relay 202, through the outer right front contacts of 35 40 relay 205, which is also operated at this time in the manner above explained, front contacts of relay 208, and thence over the tip and ring conductors of the trunk through the district selector switch 1100 to the operator's position.

When the particular vertical operating magnet 1115, 1116, employed in establishing connection, is released, the circuit of the horizontal magnet 1127 is opened and this 50 magnet restores to disconnect the common class horizontal link 1131.

Establishment of an interoffice connection.

It has been shown how the central office 55 equipment involving line switches, recording senders, district selectors, district markers, group selectors, connectors and line markers functions when a full mechanical connection is being established between two 60 subscribers' lines in the same office. To further illustrate the workings of the system it will next be considered that a connection is to be established from a subscriber's line in the local office over a trunk outgoing to a 65 distant office and thence to a subscriber's

line therein. To this end there has been shown a distant or called office of the manual type equipped with operator's positions and relay call indicators which respond to impulses automatically transmitted from 70 the mechanical office to display that portion of the entire designation necessary for the manual operator's information in completing the connection to the called subscriber's line.

In the connection previously discussed, the subscriber's line was directed through a district selector switch and thence through the group selector switch and connector switch. Where outgoing or interoffice calls 80 are concerned, however, the district selector switch first chooses a trunk leading to an office selector 2600 and the office selector in turn selects the outgoing trunk leading to the distant office. Due to the interposition 85 of these office selector switches, it is necessary also to provide an office marker which corresponds in function to the district marker and is similarly common to a large number of office switches.

The mechanical portion of the connection is established over the line switch and district selector switch and office selector switch, all under the control of the recording sender and the district and office markers. Beyond this point lies the relay call indicator mechanism in the distant manual office and this must be numerically controlled by impulses transmitted over the interoffice trunk from the recording sender in accordance with the numerical portion of the designation representing the called subscriber's line. All of this will be thoroughly discussed in describing the detailed operation which will presently be given. Suppose that the subscriber of the line 101 in the local mechanical office wishes to obtain a connection with the subscriber of line 3122 which terminates in a distant manual office. For illustration, it will be taken that the manual office has a name which is represented by the abbreviation L E R, which in terms of dial impulses corresponds to a series of 5, 3 and 7 impulses. Assume also that the number of the called subscriber's line in the manual office is 1 3 2 6, the same as the number previously assumed.

The operation of the line switch 100 to extend the subscriber's line 101 to an idle trunk 114 leading to the district selector switch 1100, and the operation of the sender selector switch 300, associating the selected idle trunk 114 with the idle allotted recording sender mechanism, all take place in precisely the same manner as hereinbefore fully described. The calling subscriber on receiving the dial tone informing him that the apparatus is ready, manipulates his transmitter 171 to send a series of five impulses representing the first letter L in the office 130

- abbreviation. As previously explained, the first four impulses of the series result in the operation of relays 413, 414, 415, and 416 successively and in the successive deenergization of relays 413, 414 and 415. When the fifth and last impulse of the series is received relay 408 operates and closes a circuit from battery through its right winding and right contact, conductor 430, outermost right front contact of relay 416, outer right back contact of relay 417, winding of relay 417, to the grounded conductor 432. Relay 417 operates, opens the circuit of relay 416 and locks in a circuit from battery through its inner right contact and winding to ground over conductors 431 and 432. After an interval has expired and relay 405 releases, the circuit above traced is completed including the windings of relays 403 and 709. Relay 709 operates and extends the counting relay leads through to the first register 700. A circuit may now be traced from ground over conductors 432 and 431, inner left front contact of relay 417, inner left back contact of relay 418, conductor 441, lowermost contact of relay 709, winding of relay 706, conductor 735, winding of relay 708 to battery. Relays 708 and 706 operate and lock in a circuit through the innermost left contact of relay 706, to ground over conductor 736, as above explained. Relay 708 operates and causes the operation of relay 710, which removes the shunt from relay 403 which operates in series with relay 709, causing the release of relay 404 and the restoration of the impulse receiving circuit ready for the next series of impulses, all in the manner previously described in detail.
- The next two letters, it will be noted, correspond to the corresponding letters of the abbreviation assumed for the first call, and, therefore, the operation resulting from the transmission of the corresponding series of impulses need not be described in detail. It is sufficient to say that series of 3 and 7 impulses are transmitted resulting in the operation, respectively, of the register relays 711 and 712 of register 701 and relays 719 and 721 of register 702. Furthermore, it will be noted that the number of the called subscriber's line is the same as the one previously discussed. Hence, series of 1, 3, 2 and 6 impulses are transmitted over the line, resulting in the operation of the thousands register relay 803, the hundreds register relays 810, 814, 811 and 815, the tens register relays 903 and 907, and the units register relays 912, 916, 915 and 919.
- Association of the sender with the district marker and transfer of the record.

As soon as the first three or office registers have been positioned and the thousands register 800 set, a circuit is established for the relay 1509 as described, and the district

marker is associated with the recording sender. After the district marker is thus associated, the office record set up on the three registers 700, 701 and 702 is transferred to the registers 1301, 1302 and 1303, 70 respectively, in the district marker. These registers, through the translator 1300, determine the selection of a trunk leading to an office selector switch, and also determine the necessary class indications to be 75 sent back into the sender.

The connection of the sender with the marker results in the closure of a circuit from ground through the contact of relay 1204, thence, as hereinbefore traced, over 80 conductors 1220 and 1532, outer left back contact of relay 513, conductor 515 through the sender selector switch to conductor 352, innermost right back contact of relay 205, conductor 221, winding of the vertical magnet 1115 of the district selector switch to battery. Magnet 1115 operates and prepares the contacts of the incoming trunk for connection to the horizontal link circuits. As above explained, the magnet 1115 closes a 90 circuit for magnet 1127 which operates the horizontal rod associated with the common horizontal trunk 1131.

The transfer of the office record from the recording sender to the district marker will 95 now be discussed. Since the register relay 706 is operated, a circuit is established over the grounded conductor 1223 through the sender connector 1500, conductor 1534, outermost right contact of relay 706, conductor 100 754, contact of relay 1501, conductor 1231, winding of relay 1324 to battery. Relay 1324 operates and the remaining three relays of register 1301 remain deenergized. Since the two registers 701 and 702 have 105 identically the same setting as assumed in the previous call, it is not necessary to trace in detail the circuits which they control. As previously explained, the register 701 causes the operation of relays 1330 and 1331, while 110 register 702 causes the operation of relays 1332 and 1334. The thousands register 800 will cause the corresponding relay 1338 in the register 1304 of the district marker to operate. This relay, however, will be ineffective, as will be explained hereinafter, inasmuch as the present call involves the selection of a trunk leading to an office switch and not a trunk extending to a terminal line group. 115

Marking the group of trunks at the district selector switch.

Since the register relay 1324 is operated, a circuit is traceable from ground over conductors 1225 and 1343, outer left contact of relay 1327, left contact of relay 1324, left back contact of relay 1325, outer left back contact of relay 1326, winding of the multi-contact relay 1309 to battery. Relay 1309 130

operates and connects the horizontal conductor 1344 to the two horizontal conductors 1359 and 1360, and also connects the horizontal conductor 1347 to the horizontal conductor 1361.

Register 1303 causes the operation of multicontact relay 1319, and due to the operation of register 1302 the multicontact relay 1305 is also operated in the manner described. A circuit may now be followed from ground over conductors 1225, 1343, 1351 and 1352 through the horizontal conductor 1347, thence through contacts of relay 1309 to conductor 1361, thence through the contact of relay 1305, conductor 1362, winding of relay 1409 to battery. Relay 1409 is individual to the group of trunks leading to the particular office selector switch 2600, which has access to trunks outgoing to the called manual office. This particular group of trunks is illustrated as occupying the entire vertical row 1111 of the district selector switches, and one trunk 1128 is shown in full.

Relay 1409 closes a circuit traceable over the grounded conductor 1222 through the outer left front contact of relay 1446, left contact of relay 1447, conductor 1451, contact of relay 1426, conductor 1452, middle lower contact of relay 1409, thence through the windings of multicontact relays 1412 and 1415 in parallel to battery. The multicontact relays 1412 and 1415 operate and associate the lower set of testing relays 1403 with the lower half of the trunk group 1101 and associate the upper set of testing relays 1400 with the upper half of the trunk group 1102. In tracing the circuit of relays 1412 and 1415, it was assumed that relays 1448, 1447 and 1446 were operated. The manner in which these relays are operated has already been described in detail.

Testing the trunks of the selected group.

With the multicontact relays 1415, 1412, 1423, 1426 and 1420 operated, and the testing relays associated with the group of trunks appearing in the fourth vertical row 1111, test circuits are prepared to determine the condition both of the outgoing trunks and of the horizontal link circuits. Assuming that the trunk 1128 is the first trunk in the group that is idle simultaneously with its corresponding horizontal link 1107, the relay 1441 corresponding to this link remains deenergized, while relays 1438, 1435, 1432 and 1429 of all preceding trunks are energized through either one winding or the other or both windings.

When relay 1409 operates it closes the circuit of relay 1446, and relay 1446 energizes to establish a circuit from ground through its inner left contact, right front contact of relay 1447, conductor 1460, inner upper contact of relay 1409, conductor 1468, contact of

relay 1426, conductor 1469, winding of magnet 1118 to battery. Magnet 1118 operates and prepares the contacts in the vertical row 1111 for connection with the horizontal link circuits. Magnet 1118 also closes a circuit from ground over conductor 1140, contact of relay 1426, winding of relay 1449 to battery.

When relay 1446 operates it opens the circuit of relay 1448. After an interval relay 1448 releases its armatures and a circuit is closed from ground over conductor 1222, right contact of relay 1449, back contact of relay 1448, innermost right contact of relay 1446, conductor 1463, contact of relay 1412, inner left front contacts of relays 1427, 1430 and 1433 in series, contact of relay 1412, conductor 1470, contact of relay 1415, inner left front contact of relay 1436, inner left back contact of relay 1439, winding of relay 1440 to battery. Relay 1440 operates and a circuit is traceable from ground through the left contact of relay 1449, conductor 1464, contact of relay 1412, right front contacts of relays 1427, 1430 and 1433 in series, contact of relay 1412, conductor 1463, contact of relay 1415, right front contact of relay 1436 right back contact of relay 1439, front contacts of relay 1440 through contacts of the relay 1423, thence over conductors 1471 and 1472 through the windings of horizontal magnet 1126 to battery. Magnet 1126 operates and in the manner fully described connects the incoming trunk 114 through the idle link 1107 to the idle trunk 1128 outgoing to the office selector switch 2600. In a manner similar to that described, a holding circuit for the horizontal magnet 1126 is closed through the contacts of the switch to the grounded sleeve conductor 150 of the trunk.

90

95

100

105

Class indications.

Another function of the translator 1300 is to determine the class of the call being extended and through the common class horizontal link 1131 to prepare circuits for obtaining the proper type of supervision and the necessary loading of the talking circuit of the trunk 114. Where the call is one for a distant call indicator office, it will be assumed that reverse current supervision is required and that the maximum of loading should be included in the talking circuit. That is to say, the polarized supervisory relay 233 should be connected in and both sections of the right-hand windings of repeating coils 227 should be included to produce the full inductive loading. For securing this a circuit is traceable from ground through the outer right contact of relay 1206, conductor 1232, conductor 1344, contacts of relay 1309, conductor 1359, contact of relay 1305, conductor 1341, conductor 1364 of horizontal link 1131, contacts in the row 1108, conductor 1146, winding of relay 206 to battery. Relay 206 operates and includes both sections of

110

115

120

125

130

each of the right hand windings of the repeating coil 227. Another circuit is traceable from ground over the conductor 1232, contacts of relay 1309, horizontal conductor 1360, contact of relay 1305, conductor 1340, over the horizontal link 1131, contacts in row 1108, conductor 1147, winding of relay 207 to battery. Relay 207 operates and connects the windings of the polarized relay 233 to the tip and ring conductors of the trunk 114.

Another function of the translator 1300 is to send class indications back to the recording sender in order that the latter may prepare itself first to make connection with the office marker and then to transmit the codes of impulses over the selected trunk to the distant manual office. The translator 1300 accomplishes this requirement by placing ground potential on certain ones of the class leads 1336 which extend back to the recording sender. For some classes of calls it will only be necessary to prepare a circuit involving one of the class leads. For other classes it may be necessary to place a ground potential on two of these leads, while on still other classes of calls it is necessary to ground three or more of the leads. If only one or two of the leads need be grounded this may be done directly from the contacts of the relays 1305, 1306, 1307, etc., inasmuch as two of the horizontal conductors in the section 1323 are grounded at the same time. Where more than two class leads must be grounded, one or more of the relays 1517, 1518, 1519, 1520 and 1521 may be operated from the translator bank and these relays in turn apply ground to the class conductors.

In the present case only two class circuits are required and hence the relays 1517, 1518 and 1519 need not be employed. One of these class circuits is traceable from ground in the marker over the conductor 1232, as explained, to contacts of relay 1309, horizontal conductor 1359, contact of relay 1305, conductor 1365, contact of relay 1501, conductor 1544, winding of relay 502 to battery. Relay 502 operates and locks in a circuit from battery through its winding and right contact to ground over conductors 506 and 507. Another circuit is completed over the grounded conductor 1232, contact of relay 1309, horizontal conductor 1360, contact of relay 1305, conductor 1366, contact of relay 1501, conductor 1545, conductor 548, winding of relay 520 to battery. Relay 520 operates and locks in a circuit through its winding and inner right contact to the grounded conductor 506. A branch of the circuit traced for relay 520 extends over conductor 548 through the winding of relay 825 to battery. Relay 825 thereupon operates. Still another branch extends by way of conductor 548 through back contacts of relays 601 and 602, winding of relay 603 to

battery. Relays 825 and 603 lock in circuits traceable from battery through their windings, thence in parallel over conductor 548 through the inner right front contact of relay 520, to the grounded conductor 506. ⁷⁰

After an interval following the release of relay 1448 in the district marker, relay 1447 becomes deenergized and the circuit previously traced is closed for the release relay 1200. In the manner already described in detail, the district marker is disassociated from the recording sender and also from the district selector switch 1100. Also in the manner previously described, the district marker, during its releasing period, prepares a circuit for operating the relay 513 in the sender which locks to the grounded conductor 506. ⁸⁰

Association of the sender with the office marker and transfer of record. ⁸⁵

The next phase in the operation is to connect the recording sender with the office marker and to thereupon transfer the office record registered on the registers 700, 701 and 702 to the corresponding registers 2802, 2803 and 2804 of the office marker. Relay 513, upon energizing during the release of the district marker, establishes a circuit traceable over the grounded conductor 507, conductor 509 through the inner left back contact of relay 510, outer left contact of relay 511, conductor 512, inner left contact of relay 505, outer right front contact of relay 513, outer left back contact of relay 504, outer right front contact of relay 502, conductor 549, winding of relay 3006 to battery. Relay 3006 operates and closes a circuit from ground through its right contact, right back contact of relay 3012, winding of relay 3011 to battery. Relay 3011 operates and locks in the following circuit, provided no sender in another group is attempting connection with the office marker: battery, through the winding and right contact of relay 3011, left back contact of relay 3005 and through the left back contacts of similar relays, conductor 3015, outer right back contact of relay 2701, conductor 2708, to ground at the contact of relay 2703. Relay 3011 establishes a circuit from battery through the right hand winding of relay 3007, left contact of relay 3006, thence over the circuit traced to ground at the contact of relay 2703. Relay 3007 completes a circuit from battery through the winding of relay 3012, to ground at the inner right contact of relay 3007. Relay 3012 closes a circuit from battery through the left hand winding and left contact of relay 3007, left back contact of relay 3010 through the left back contacts of similar relays in the same group, outer left contact of relay 3012, conductor 3016, outer left back contact of relay 3004 and through the contacts of similar relays, con- ¹⁰⁰ ¹¹⁰ ¹²⁰ ¹³⁰

ductor 3017, winding of relay 2701 to ground over conductor 2708. Relay 2701 operates and relay 3007 locks in this circuit. A circuit is now traceable from battery through the winding of multicontact relay 3008, outer right contact of relay 3007, conductor 3018, inner left contact of relay 2701, to grounded conductor 2708. Relay 3008 operates its contacts and connects the recording sender to the common office marker.

Relay 2704 is energized in a circuit from battery through its winding, conductor 3014, right front contact of relay 3012, to ground at the right contact of relay 3006. Relay 2704 closes a holding circuit for relay 3012 traceable from battery through the winding and inner left contact of relay 3012, conductor 3019, left contact of relay 2704, to ground at the contact of relay 2705. Relay 3012 is locked while relay 3011 becomes released since its circuit is opened at the right back contact of relay 2701 and also at the right back contact of relay 3012.

The arrangement of the multicontact relays of the sender connector 3000 for the office marker is substantially the same as that discussed in detail in connection with the sender connector 1500 of the district marker and it is not thought necessary to go further into the description thereof. Relay 2701, in operating, closes a circuit from battery through the winding of relay 2702, inner right back contact of relay 2700, outer left contact of relay 2701, conductor 2708, contact of relay 3008 to ground.

Relay 2702 completes a circuit from ground through its outer right contact, conductor 2709, contact of relay 3008, conductor 3020, outer left contact of relay 502, inner left back contact of relay 504, conductor 556, through contacts of the sender selector switch 300, conductor 353, middle right contact of relay 205, uppermost front contact of relay 208, conductor 225, through contacts of the district selector switch 1100 involving link circuit 1107, conductor 1148 of trunk 1128, outer left back contact of relay 1815, conductor 1816, winding of the vertical operating magnet 2613 of the office selector switch 2600 to battery. Magnet 2613 rotates the associated rod and prepares the contacts of trunk 1128 for connection with the horizontal link circuits of the office selector switch.

As soon as the sender is connected to the office marker a circuit is completed from ground over conductor 2708, inner left contact of relay 2702, conductors 2710 and 2711, contacts of relays 3008, conductor 3021, conductor 756, middle right contact of register relay 706, conductor 757, contact of relay 3008, conductor 3022, winding of relay 2805 to battery. Another circuit is completed from ground in the office marker over the path traced including conductor 3021, conductor 756, middle right contact of relay

712, conductor 758, contact of relay 3008, conductor 3023, winding of relay 2806 to battery. Another circuit is traceable from ground over the conductor 2708, and thence over the conductor 3021, conductor 756, through the middle right contact of relay 711, conductor 759, contact of relay 3008, conductor 3024, winding of relay 2807 to battery. Another circuit leads from ground over conductor 3021, middle right contact of relay 719, conductor 761, contact of relay 3008, conductor 3026, winding of relay 2809 to battery. Still another circuit is traceable from ground over the conductor 3021, as described, conductor 756, middle right contact of register relay 721, conductor 760, contact of relay 3008, conductor 3025, winding of relay 2808 to battery.

Marking and testing the trunks at the office selector switch.

With the registers 2802, 2803 and 2804 positioned in accordance with the office designation, the translator device 2800 and 2801 is operated to select one of the group relays shown at the right of Fig. 29 which identifies the group of trunks leading to the desired distant office. First, a circuit is traceable from ground over conductor 2708, inner left front contact of relay 2792, conductors 2710 and 2711, contact of relay 2706, conductor 2712, conductor 2810, outer left back contact of relay 2811, left front contact of relay 2805, left back contact of relay 2812, outer left back contact of relay 2813, winding of multicontact of relay 2814 to battery. Another circuit is traceable from ground over the conductor 2712, conductor 2814, outer left contact of relay 2815, left contact of relay 2808, left back contact of relay 2816, outer left front contact of relay 2809, winding of multicontact relay 2817 to battery. With relay 2817 operated a circuit is closed from ground over conductors 2712 and 2810, inner right contact of relay 2819, inner right back contact of relay 2820, inner right front contact of relay 2806, inner left front contact of relay 2807, horizontal conductor 2821 of the translator 2801, contact of relay 2817, conductor 2822, winding of multicontact relay 2823 to battery. With relays 2823 and 2814 energized, a circuit is established from ground over conductor 2710, horizontal conductor 2824, contacts of relay 2814, horizontal conductor 2825, contact of relay 2823, conductor 2825, winding of group relay 2912 to battery.

At the time the office marker is first connected to the sender a circuit is completed from ground over conductor 2708, outer right front contact of relay 2701, outer left front contact of relay 2702, conductor 2714, outer left back contact of relay 2907, winding of slow-to-release relay 2930 to battery. Relay 2930 operates and closes a circuit from

battery through the winding of relay 2909, to ground at the left contact of relay 2930. When the relay 2912 is selected and operated it closes a circuit from ground through its 5 lowermost contact, conductor 2913, winding of relay 2907 to battery. Relay 2907 opens the circuit of relay 2930 but this latter relay being slow holds its armatures attracted for an interval of time. During this interval a 10 circuit is established from ground over conductor 2714 as above traced, outer left front contact of relay 2907, left contact of relay 2909, conductor 2914, contact of relay 2933, conductor 2915, middle lower contact of relay 15 2912, winding of multicontact relay 2911 to battery.

It will be noted that relay 2933 is energized at this time. This relay, together with relays 2932 and 2931, is operated in a circuit 20 from battery through their windings in parallel, conductor 2916, to ground at the contact of magnet 2613.

Relay 2911 is individual to the row 2611 of the office selector switch 2600 containing 25 the desired group of trunks and serves to associate the upper set 2906 of testing relays in the marker with the respective trunks of said group. Another circuit is closed from ground through the inner left 30 contact of relay 2907, right front contact of relay 2909, conductor 2917, innermost upper contact of relay 2912, conductor 2918 of relay 2933, conductor 2919, winding of the magnet 2616 to battery. Magnet 2616 rotates 35 the associated bar and prepares the contacts of the trunk in the vertical row 2611 for connection with the horizontal link circuits. The magnet 2616, in operating, closes a circuit from ground over its contact, 40 conductor 2628, contact of relay 2933, conductor 2920, winding of relay 2908 to battery.

When the multicontact relay 2911 is operated the double wound test relays 2921, 5 2922 and 2933 are associated respectively, with the horizontal links 2606, 2607, etc. in the upper group 2602 and with the outgoing trunks 2629, 2923, etc. in the upper section 10 of the row 2611. In the manner already described in connection with the testing relays of the district marker, the double wound relays 2921, 2922, 2923, etc. are operated over one winding or the other, according as the corresponding link circuits and 15 outgoing trunks are busy. Assuming that the link 2606 or the trunk 2629 is busy, or both are busy, the testing relay 2921 is operated. Assuming that the next link 2607 and the corresponding outgoing trunk 2623 20 are both idle, the next successive relay 2922 remains inert. Relay 2921, in operating, locks in a circuit from battery through its right hand winding and right contact, conductor 2924, to ground at the middle right contact of relay 2907. Relay 2921 closes a

circuit from battery through the winding of relay 2925, left contact of relay 2921, to ground over conductor 2924. Relay 2925, at its outer left front contact, closes an energizing circuit for relay 2926. 70

After the necessary interval has elapsed, relay 2930 releases and a circuit may now be traced from ground over conductor 2714, inner right contact of relay 2908, right contact of relay 2930, innermost right contact 75 of relay 2907, conductor 2927 contact of relay 2911, inner left front contact of relay 2925, inner left back contact of relay 2928, winding of relay 2929 to battery. Relay 2929 operates and a circuit may now be 80 traced from ground through the inner left contact of relay 2908, conductor 2934, contact of relay 2911, right front contact of relay 2925, right back contact of relay 2928, left front contacts of relay 2929, contacts of relay 2931, conductors 2935 and 2936, windings of horizontal magnet 2622 to battery. The magnet 2622 operates the associated bar and the trunk 1128 is connected through the horizontal link 2607 to 85 the outgoing trunk 2623 leading to the distant called office. 90

The instant the trunk 1128 is connected to the horizontal link 2607 and while the office marker is associated with the office switch 95 2600, a circuit is closed from ground at the inner left contact of relay 2908, and thence, as above traced, over conductor 2935, contacts of the office switch 2600 in the row 2608, sleeve conductor 2630, winding of relay 1815 to battery. Relay 1815 operates and locks through its winding and right contact to the grounded sleeve conductor 1817. At its left contact relay 1815 completes the tip and ring conductors of 10 the trunk 1128 through the office selector switch. At its right contact relay 1815 extends the grounded sleeve conductor 1817 over the sleeve conductor 2630 to the office selector switch, whereby the horizontal magnet 2622 is held operated after the office marker is discharged. Relay 1815, at its outer left back contact, opens the circuit of the vertical magnet 2613 and this magnet releases to restore the vertical operating 11 bar. Magnet 2613, in releasing, opens the circuit of multicontact relays 2931, 2932 and 2933, and these relays in turn disassociate the common office marker from the office selector switch 2500. 12

Release of the office marker.

After an interval following the release of relay 2930, the slow relay 2909 becomes deenergized and in so doing opens the circuit of multicontact relay 2911, whereupon the testing relay set 2906 is disconnected from the outgoing group of trunks. All energized relays in this set are now released. With relays 2933 and 2909 released, the cir- 13

cuit of magnet 2616 is opened and this magnet restores the operating rod associated with the row of contacts 2611. The connection through the office selector switch 2600 is now held solely by the maintained energization of the horizontal magnet 2622.

Relay 2909, in releasing, completes a circuit from ground through the inner left contact of relay 2907, right back contact of relay 2909, conductor 2938, winding of release relay 2700 to battery. Relay 2700 operates and closes a circuit from battery through the winding of relay 2703, to ground at the outer right contact of relay 2700. Relay 2703 being slow to operate and slow to release does not attract its armature until after a definite interval of time has expired. Relay 2700 locks in a circuit from battery through the winding and inner right front contact, outer left contact of relay 2701, conductor 2708, to ground at the contact of relay 3008. Relay 2700 opens the circuits of relay 2702 which opens the circuits of relays 2805, 2806, 2807, 2808, 2809, 2814, 2817 and 2823. Also the circuit of relay 2912 is opened at this time resulting in the deenergization of relay 2907. After an interval the relay 2703 operates and opens the circuit of relays 2701, 3007 and 3008. Relay 3007 releases and opens the circuit of relay 3008. Relay 2701 releases and opens the circuit of relay 2700. Relays 3012 and 2704 may also be released at this time. The relay 3008, on deenergizing, disconnects the common office marker from the recording sender and this marker may now be associated with any other of the recording senders.

Prior to the disconnection of the office marker and during the interval relay 2703 is holding its armature retracted, a circuit is established from ground through the contact of relay 2703, conductor 2708, outer left contact of relay 2700, conductor 2715, winding of relay 504 to battery. Relay 504 operates and locks in a circuit from battery through its winding and inner right contact, to ground over conductors 506 and 507.

50 *Transfer of the numerical record from the recording sender to the call indicator.*

Immediately that the calling subscriber's line is extended over the inter office trunk to the operator's cord circuit 3100 in the manual office, the recording sender in the mechanical office is prepared to transmit codes of impulses, representing the designation of the wanted line, over the trunk circuit to operate the call indicator at the operator's position. Where certain of the subscribers' lines terminating in the manual office have a plurality of substations thereon, party line ringing selection is necessary and also it is necessary to give the operator the proper indication. For this purpose

the register 1000 in the recording sender is used to store the stations designation. In the call here being considered, the subscriber's line does not involve party designations and hence the register 1000 was not positioned. However, for uniformity, a code of impulses is transmitted which operates the called indicator to display a lamp before the operator, indicating that the called line is a direct one. According to the circuit arrangement employed herein, the stations designation is transmitted in advance of the numerical digits.

If at the time the office marker is discharged and relay 504 in the recording sender is operated the units series of impulses has been transmitted over the calling subscriber's line and recorded on the units register 901, a circuit is closed for the relay 550. However, if at the time the marker is released the subscriber has not yet transmitted the units digit, the circuit for relay 550 is held open until such time as the units digit impulses have been received. The circuit of relay 550 may be traced as follows: battery, through the winding of said relay, right back contact of relay 551, conductor 553, outer right front contact of relay 520, lowermost contact of relay 501, outer right front contact of relay 504, inner left front contact of relay 502, inner left contact of relay 513, conductors 519 and 518, inner right contact of relay 517, conductor 930, to ground at the inner left contact of relay 927. Relay 550 together with relays 551 and 552 are designed to measure an interval of time following the instant when the office marker has been released and the units impulses have been received. This interval is calculated as sufficient for the transmission of a series of stations impulses. If stations impulses are transmitted they are recorded on the register 1000 in a manner already explained whereas if they are not transmitted the relays 550, 551 and 552 measure off their interval at the end of which time the sender commences to transmit code impulses to the distant manual office. Relay 550, in operating, closes a circuit from ground through its contact and the winding of relay 552 to battery. Relay 552 completes a circuit from battery through the winding of relay 551, left front contact of relay 552, to ground over conductor 506. Relay 551 operates and locks through its inner left contact to the grounded conductor 506. Relay 551 opens the circuit of relay 550, which, being slow to release, retains its armature attracted for a definite interval. Relay 550, upon releasing, opens the circuit of relay 552 and a circuit is established from ground at the inner left contact of relay 927, conductor 930, inner right contact of relay 517, conductor 518, conductor 519, inner left contact of relay 513, inner left front 125 130

contact of relay 502, outer right contact of relay 504, lowermost contact of relay 501, outer right front contact of relay 520, right front contact of relay 551, right back contact of relay 552, conductor 554, winding of relay 604 to battery. Relay 604 locks in a circuit from battery through its winding and left contact, conductor 507 to ground.

Relay 604, at its right contacts, extends 10 the conductors 524 and 556, which lead to the tip and ring conductors of the trunk circuit, to the impulse mechanism shown in Fig. 6. The following circuit may now be traced: battery, through the inner lower 15 back contact of relay 3119 (Fig. 31), right hand winding of relay 3106, winding of relay 3107, inner normal contact of relay 3114, outer back contact of relay 3101, tip conductor 2625 through contacts of the office selector switch 2600, tip conductor of the trunk 1128, outer left front contact of relay 1815 through contacts of district selector switch 1100, tip conductor of trunk 114, uppermost front contact of relay 208, middle right contact of relay 205, conductor 353, contacts of the sender selector switch 300, conductor 556, inner right contact of relay 604, outer right contact of relay 606, winding of relay 607, inner right contact of relay 606, outer right 30 contact of relay 604, conductor 524 through contacts of sender selector switch 300, conductor 355, outer right contact of relay 205, lowermost front contact of relay 208 over the ring side of the trunk 114, thence 35 through the district selector switch 1100, and the office selector switch 2600 over the ring side of the line 2626 to the distant office, inner back contact of relay 3101, outer normal contact of relay 3114, left hand winding of relay 3106 to ground. Relay 607 becomes energized in this circuit and a circuit is closed from battery through the winding of relay 608, front contact of relay 607, conductor 609, conductors 611 and 507 to 40 ground. Relay 608 operates and locks through its winding and left contact to ground over conductor 609 as traced.

The above traced circuit being closed, relay 3106 at the operator's position and relay 50 3107 operate. Relay 3107 closes a circuit for relay 3108. Relay 3106, at its contact, closes a circuit for relay 3109. Relay 3109, at its outer left contact, establishes a shunt around the winding of relay 3107 and this 55 latter relay releases to release in turn relay 3108. Relay 3109 completes a circuit from battery through the signal lamp 3111, lower winding of relay 3110, outer right back contact of relay 3103, inner upper contact of relay 3110, inner right contact of relay 3109 to ground. Due to the resistance of lamp 3111, relay 3110 remains inert. The illumination of lamp 3111 notifies the operator 60 that a call has been extended to her cord circuit 3100 and is waiting for her to associate

the relay call indicator with said cord circuit. At her convenience the operator responds to the call by depressing the assignment key 3105 which is individual to the incoming trunk circuit. The depression of key 3105 operates to associate the trunk with the call indicating mechanism at the operator's position. A circuit is closed from battery through the winding of relay 3221, conductor 3222, lower contact of relay 3110, right hand winding of relay 3103, contact of key 3105, conductor 3124, contact of relay 3216, right back contact of relay 3218 to ground. Relay 3103 operates and locks in a circuit from battery through the winding of relay 3221, conductor 3222, lower contact of relay 3110 through both windings of relay 3103, left contact of said relay to ground. The operator's key may now be released since the relays 3103 and 3221 are locked independently thereof. Relay 3103 closes a circuit from battery through the lamp 3111, lower winding of relay 3110, outer right front contact of relay 3103, interrupter 3104 to ground. The lamp 3111 is caused to flash in this circuit due to the rotation of the interrupter 3104. Relay 3103 also prepares a circuit from battery through the winding of relay 3101, inner right contact of relay 3103, conductor 3125, winding of relay 3216, left back contact of relay 3218 to ground. Relay 3101 attracts its armatures and extends the incoming trunk conductors 2625 and 2626 by way of conductors 2632 and 2633 to the operating relays 3200, 3201 100 and 3202 of the call indicator mechanism. Up to this time the relay 607 in the mechanical office has been energized in series with the windings of relay 3106 at the manual office. When relay 3101 attracts its armatures the battery supply through the windings of relay 3106 is discontinued and relays 3106 and 607 release. Relay 3106 also causes the deenergization of relay 3109. 105

When relay 607 retracts its armature a circuit is closed from battery through the winding of relay 606, inner front contact of relay 608, back contact of relay 607, to ground over the conductor 609 as hereinbefore traced. Relay 606 operates and locks 110 through its inner left contact to the grounded conductor 609. Relay 606, at its right contacts, disconnects the winding of relay 607 from the tip and ring conductors of the line circuit.

Returning to the point where relay 608 was operated during the energization of relay 607, a circuit may be traced from ground through the outer right contact of relay 608, conductor 612, outer left contact of relay 927, conductor 938, inner right back contact of relay 613, winding of relay 614 to battery. It will be noted that parallel branches of the energizing circuit of relay 614 extend through the outer left back con- 120

tacts of relays 820, 822, 920 and 922 and the outer left front contacts of corresponding relays 808, 818, 910 and 927, to ground over conductor 612. Hence, the relay 614 having 5 operated over any one of these branches will remain operated so long as any one of them is closed.

The equipment is now in condition for transmitting code impulses over the line 10 circuit to the distant manual office for setting the relay call indicator. The code impulses are sent to the indicator mechanism over a full metallic circuit comprising both the tip and ring sides of the line in series. 15 These impulses may be of either positive or negative polarities, dependent upon the pole of battery that is connected to a given side of the line circuit. They may also be weak or strong, dependent upon whether a 20 h^h or low resistance is included in the circuit. Relay 3200 at the distant end of the impulse circuit is polarized in such a manner as to respond only when current of positive polarity flows over the ring side of 25 the line; that is over the conductor 2633. The relay 3201 is polarized in such a manner as to respond to current of the opposite polarity. Both relays 3200 and 3201 respond either to strong or weak impulses 30 provided the polarity is in the proper direction. Relay 3202 responds to strong impulses only of either positive or negative polarity. This relay being marginal does not operate on weak impulses.

35 Relays 615 and 616 cooperate with each other to measure intervals of time during which the code impulses are produced and transmitted over the line circuit to the distant office. Due to the characteristics of 40 these relays they operate and release slowly. The relays 617, 618, 619 and 620 operate in a definite sequence and their function is to measure a sufficient number of periods or 45 code impulses to represent each of the different digits.

Relay 614, upon operating, completes a circuit from ground through the right contact of relay 608, inner left contact of relay 614, conductor 624, innermost right back 50 contact of relay 619, conductor 625, inner right back contact of relay 617, outer right back contact of relay 618, left back contact of relay 619, left hand winding of relay 620, left hand winding of relay 619 to battery. 55 Relay 619 being marginal does not receive sufficient current through its left hand winding in series with the winding of relay 620 to operate. Relay 620, however, attracts its armatures and closes a circuit from battery 60 through the left hand winding of relay 619, left hand winding of relay 620, right hand winding of relay 619, inner right contact of relay 620 to ground over conductors 611 and 507. Relay 619, however, still remains deenergized since its right hand winding is

shunted by the circuit previously traced to ground over conductor 624. Relay 620 completes a circuit from ground through its outer right contact, contact of relay 621, middle left back contact of relay 613, conductor 70 626, inner left front contact of relay 603, conductor 627, conductor 628, outer right back contact of relay 1006, winding of relay 1007 to battery. Relay 1007 operates and closes a circuit from battery through its 75 winding and inner lower contact, conductor 1012, winding of relay 621, outer right contact of relay 620 to ground. Relay 1007 locks but relay 621 remains inert since its winding is shunted over the circuit previously traced. Relay 1007, at its upper contacts, connects certain operating conductors from the impulse circuit in Fig. 6 through to the register relays 1008, 1009, 1010 and 1011 of the stations register 1000.

80 Relay 614 also completes a circuit from battery through the resistance 630, winding of relay 615, left back contact of relay 616, conductor 631, outer left contact of relay 614, outer left contact of relay 606 to ground. 85 Relay 615 operates and locks through its winding, inner right front contact, to ground over the conductor 631 as traced. Relay 615 closes a circuit from battery through the resistance 632, winding of relay 90 616, inner left contact of relay 615, conductor 631 to ground. Relay 616 operates and closes a circuit from battery through resistance 630 middle right contact of relay 616 95 to the grounded conductor 631. This circuit is in shunt of relay 615 which thereupon releases. Relay 616 also closes a circuit from battery through the winding and normal contact of relay 633, outer right front contact of relay 616, to ground over conductor 100 631. Relay 633 operates and locks 105 through its left hand make-before-break contact to the grounded conductor 631. Relay 615, on releasing, closes a circuit from battery through resistance 632, right back contact 110 of relay 615, to ground over conductor 631. This circuit shunts the winding of relay 616, which relay thereupon retracts its armatures.

115 During the period measured by the release of relays 615 and 616 which follows the operation of relay 633, an impulse is transmitted over the line in case the stations registers have been given the necessary setting. When relay 633 operates at the beginning of this period it closes a circuit from ground through its outer right contact, conductor 638, middle right contact of relay 614, conductor 639, outer normal contact of relay 640, outer contact of relay 604, conductor 524, thence, as above traced, over the ring side of the line to the distant office, conductor 2633, windings of relays 3202, 3201 and 3200, conductor 2632, returning over the tip side of the line to conductor 556 in the 125 130

- manner traced, inner right contact of relay 604, inner normal contact of relay 640, left back contact of relay 618, conductor 641, outermost right contact of relay 614, right 5 back contact of relay 622, outer right front contact of relay 603, conductor 642, inner left back contact of relay 1006 to the right contact of register relay 1008. Since no stations registration is recorded on the register 10 1000, relay 1008 is deenergized and hence the circuit thus far traced is held opened at the right hand contact of said relay. Therefore, no impulse of current is sent over the line during the first releasing period of relays 615 15 and 616, and none of the relays 3202, 3201 and 3200 is operated at the relay call indicator mechanism. 20 When relay 616 releases a circuit is closed from battery resistance 647 through the 25 winding of relay 640, outer left contact of relay 615, back of relay 616, inner right contact of relay 633 to the grounded conductor 631. Relay 640 operates and reverses the connection of the tip and ring 30 conductors of the line circuit to the impulse sending mechanism. Relay 640 also closes a locking circuit for itself from battery through its winding and right contact to ground over conductor 631. Relay 616, 35 on releasing, also establishes a circuit from ground over conductor 631, outer right back contact of relay 616, outer left contact of relay 633, conductor 643, left back contact of relay 617, left hand windings of relays 40 618 and 617 to battery. Relay 617 being marginal does not receive sufficient current through its left hand winding to operate in series with relay 618. Relay 618, however, attracts its armatures and a circuit 45 is closed from battery through the left hand winding of relay 617, left hand winding of relay 618, right hand winding of relay 617, inner right contact of relay 618, to ground over conductor 507. Although 50 both windings of relay 617 are included in this circuit the relay is shunted due to the direct ground applied to conductor 643, as above traced. Therefore, relay 617 still remains deenergized. Relay 618, on attracting its armatures, opens the shunt circuit which has been maintained around the right hand winding of relay 619. Relay 619 thereupon operates in series with relay 620 in the circuit already described. Relay 55 619 completes a circuit from battery through the winding of relay 622, outer right contact of relay 619, to ground over conductor 507. Relay 622 operates and locks through its winding and left contact to the grounded conductor 507. Relay 619 also establishes a circuit from ground over conductor 507, middle right contact of relay 619, conductor 645, lowermost contact of relay 1007, winding of relay 1006 to battery. Relay 1006 60 65 operates and locks through its inner right contact, conductor 737, and thence to ground at the contact of the relay 402. Relay 1006, at its outer right contacts, opens the shunt around the winding of relay 621 and this latter relay becomes energized. 70 The next action to take place is the re-operation of relays 615 and 616 which measure a second interval for the transmission of an impulse over the line circuit. Immediately that the relay 616 released its 75 armatures, the above traced circuit for relay 615 is closed and this latter relay operates. Relay 615, in operating, closes the circuit traced for relay 616, which relay also attracts its armatures again. During the operating interval of relays 615 and 616, a path may be traced from ground through the outer right contact of relay 633, conductor 638, middle right contact of relay 614, conductor 639, inner left front contact 80 of relay 640, inner right contact of relay 604, conductor 646, thence over the tip side of the line through the windings of relays 3200, 3201 and 3202, returning by way of the ring side of the line to conductor 524, 85 outer contact of relay 604, middle front contact of relay 640, conductor 646 through the high resistance 763 to battery. The polarity of the current flowing through its circuit is such as to cause the operation of 90 polarized relay 3201. Due to the inclusion of the high resistance 763, the marginal relay 3202 remains inactive. Relay 3201 completes a circuit from ground through the outer left contact of relay 3220, left contact of relay 3221, conductor 3225, contact 95 of relay 3201, conductor 3226, left back contact of relay 3203, left hand windings of relays 3204 and 3203 to battery. Relay 100 3203, being marginal, does not receive sufficient current through its left hand winding to operate in series with the winding of relay 3204. Relay 3204, however, attracts its armatures and completes a circuit from battery through the left hand winding of 105 relay 3203, left hand winding of relay 3204, right hand winding of relay 3203, inner right contact of relay 3204, conductor 3227, conductor 3225 to ground. Although both windings of relay 3203 are included in this 110 circuit said relay fails to operate due to the direct ground applied to conductor 3226 through the contact of relay 3201. Relay 3204 completes a circuit from battery through the winding of relay 3206, innermost back contact of relay 3205, outer right contact of relay 3204, to ground over conductor 3227. Relay 3206 operates and prepares a circuit from battery through its winding and the winding of relay 3205, 115 inner right contact of relay 3206, to ground over conductor 3227. Relay 3205, however, does not operate so long as it remains shunted at the outer right contact of relay 3204. 120 125 130

When relay 616 operates it closes a circuit from battery through the resistance 647, conductor 648, middle left contact of relay 633, outermost front contact of relay 616, to the grounded conductor 631. This circuit shunts the winding of relay 640 and said relay retracts its armatures thus interrupting the impulse of current being transmitted over the line circuit. In response to the interruption of the impulse, relay 3201 releases and removes ground from the conductor 3226. The removal of this ground permits the relay 3203 to operate in series with relay 3204. Moreover, relay 616, in operating, opens its outer right back contact and removes ground from the conductor 643. This removes the shunt around the right hand winding of relay 617 and said relay operates in series with relay 618.

Relay 616, in operating, shunts relay 615 and this latter relay becomes deenergized, in turn shunting and releasing the relay 616. During the releasing period of relays 615 and 616 with relay 640 deenergized, a path may be traced from ground over conductor 638, middle right contact of relay 614, conductor 639, middle normal contact of relay 640, thence over the ring side of the line to the call indicator office and returning over the tip side of the line to the inner normal contact of relay 640, left front contact of relay 618, conductor 649, conductor 765, middle upper contact of relay 1007 to the contact of relay 1010. Register relay 1010 being deenergized, the path traced is broken at this point and hence no impulse of current is transmitted over the line. When relay 616 releases it completes a circuit from battery through the winding of relay 640, outer left back contact of relay 615, innermost right contact of relay 616, inner right contact of relay 633, to ground over conductor 631. Relay 640 operates and locks as above described. In addition, relay 616 completes a circuit from ground through the conductor 631, outermost right back contact of relay 616, outermost left contact of relay 633, conductor 643, left front contact and left hand winding of relay 617 to battery. Relay 617 is held in this circuit and relay 618 is shunted and becomes released.

The next period is measured by the energization of relays 615 and 616 which takes place in the manner already described. During this period the circuit hereinbefore traced is closed from ground over conductors 638 and 639 over the tip side of the line through the relays 3202, 3201 and 3200, returning over the ring side of the line through resistance 763 to battery. In response to this impulse relay 3201 is operated and a circuit is closed from ground over conductor 3225, contact of relay 3201, conductor 3226, left front contact and left hand winding of relay 3203 to battery. Relay 3203 is held in this circuit and relay 3204 being shunted releases its armatures. The relay 3205 is still shunted by a path through the inner right contact of relay 3203 to the grounded conductor 3225. When relay 616 operates it closes the above traced shunt circuit through resistance 647 around the winding of relay 640 and this latter relay releases its armatures. Furthermore, relay 616, at its outer right back contact, opens the holding circuit of relay 617, which thereupon becomes deenergized. With relays 617 and 618 released a circuit may be traced from battery through the left hand winding and left front contact of relay 619, outer right contact of relay 618, inner right contact of relay 617, conductor 625, inner right front contact of relay 619, inner right front contact of relay 620, to ground over conductor 507. Relay 620 is shunted by this circuit and releases its armatures. Relay 620, at its outer right contact, opens the holding circuit of relays 621 and 1007. Relay 1007 releases and disconnects the impulse circuit from the stations register 1112. Relay 620, at its inner right contact, opens the circuit of relay 619, whereupon this relay retracts its armatures.

When relay 640 becomes deenergized it interrupts the impulse being transmitted over the line and relay 3201 in response releases its armature. Relay 3201 removes ground from conductor 3226 and relay 3203 becomes deenergized. Relay 3203 removes the shunt from the winding of relay 3205 and this latter relay operates in series with relay 3206. With the relays 3205 and 3206 energized the impulse operating relays 3203 and 3204 are associated with the thousands register relays of the indicator shown in Fig. 33.

The code impulses representing the thousands digit recorded on the register 800 will now be transmitted. With relays 617, 618, 619 and 620 all released, the energizing circuit of relay 620 is immediately closed as above traced and this relay operates. Relay 620 completes a circuit from ground through its outer right contact, back contact of relay 621, middle left back contact of relay 613, conductor 626, inner left front contact of relay 603, thence over conductors 627 and 628, outer right front contact of relay 1006, conductor 1016, outer left back contact of relay 623, outer left front contact of relay 603, outer right back contact of relay 623, conductor 651, outer right back contact of relay 820, winding of relay 821 to battery. Relay 821 operates and locks through its winding and inner lower contact, conductor 1012, winding of relay 621, to ground at the outer right contact of relay 620. Relay 621 being shunted does not operate at this time.

During the interval measured from the energization of relay 616 until the deener-

- gization of relays 615 and 616, a circuit is completed from ground over the conductors 638 and 639, thence over the ring side of the line, as above traced, through the 5 impulse relays at the call indicator and returning over the tip side of the line through the inner normal contact of relay 640, left back contact of relay 618, conductor 641, outermost right contact of relay 614, right 10 front contact of relay 622, outermost right back contact of relay 613, conductor 650, inner right back contact of relay 820, inner left front contact of register relay 803, conductor 847, high resistance 763 to battery. 15 Current flowing in this circuit is of the proper polarity to cause the operation of relay 3200. Due to the high resistance 763 the marginal relay 3202 remains deenergized. Relay 3200 completes a circuit from 20 ground over conductor 3225, contact of said relay, left back contact of relay 3204, left front contact of relay 3206, left back contact of relay 3208, conductor 3229, left hand winding of relay 3300 to battery. Relay 25 3300 operates and locks in a circuit from battery through its windings and inner right front contact, conductor 3318, conductor 3319, right contact of relay 3221, right contact of relay 3220 to ground. 30 After an interval relays 615 and 616 become deenergized and relays 640, 619 and 618 become energized in the manner above described. Relay 619 closes a circuit from ground over conductor 507 through its 35 middle right contact, conductor 645, lowermost contact of relay 821, winding of relay 820 to battery. Relay 820 operates and locks through its winding and inner right contact, to ground over conductor 737. Relay 40 640 discontinues the impulse being transmitted and reverses the connection of the tip and ring conductors. Relay 640 also locks through its winding and right contact to ground over conductor 631. Upon 45 the discontinuance of the impulse the polarized relay 3200 retracts its armature and opens the energizing circuit of relay 3300. Following in regular order, the relays 615 and 616 are energized in succession. 50 During the interval measured by these relays while energizing a circuit may be retraced from ground over conductors 638 and 639 to the inner left front contact of relay 640, thence over the tip conductor 55 of the line circuit through the operating relays 3202, 3201, and 3200, returning over the ring conductor to the middle left front contact of relay 640, conductor 646, high resistance 763 to battery. The current in 60 this circuit is of the proper polarity to operate the polarized relay 3201 and due to the high resistance 763 relay 3202 remains inert. Relay 3201 closes a circuit from ground over conductor 3225 through its 65 contact, conductor 3226, left back contact of relay 3203, left hand windings of relays 3204 and 3203 to battery. Relay 3204 operates and relay 3203 remains deenergized. Relay 3204 closes a circuit from battery through the winding of relay 3208, left back 70 contact of relay 3207, innermost left front contact of relay 3205, outer right front contact of relay 3204, to ground over conductor 3227. Relay 3208 operates and prepares a circuit from battery through its winding 75 and the winding of relay 3207, inner right contact of relay 3208, to the grounded conductor 3227. Relay 3207, however, does not operate due to the shunt maintained around its winding by the relay 3204. 80 Relays 615 and 616 operate in succession and in so doing cause the release of relay 640 in the manner described and also remove ground from conductor 643, whereby the relay 617 operates. Relay 640, in releasing, interrupts the impulse undergoing transmission and relay 3201 becomes deenergized. Relay 3201 removes ground from conductor 85 3226 and relay 3203 operates in series with relay 3204. Following the release of relay 90 640 and while the relays 615 and 616 are undergoing release, a circuit is closed from ground over the conductors 638 and 639 through the middle normal contact of relay 640, thence over the ring side of the line 95 and returning over the tip of the line through the inner normal contact of relay 640, left front contact of relay 618, conductor 649, conductor 765, middle upper contact of relay 821, to the inner left front contact 100 of relay 805. Relay 805 of the thousands register 800 is deenergized and hence the impulse circuit is not completed and no impulse is transmitted over the line during this 105 period. After a further interval has expired, relays 615 and 616 deenergize successively in the manner explained. The release of relay 616 causes the shunting and releasing of relay 618. Relay 616, on releasing, also causes the operation of relay 640, reversing the tip and ring conductors of the line circuit. During the interval required for relays 615 and 616 to reenergize, a circuit is 110 closed from ground over conductors 638 and 639 through the inner front contact of relay 640, thence over the tip side of the line returning by way of the ring side of the line through the front contact of the relay 640, conductor 646, high resistance 763 to battery. The current in this circuit is of the proper polarity to operate relay 3201 and due to the high resistance 763 relay 3202 remains inoperated. Relay 3201 places 115 ground on conductor 3226 holding relay 3203 operated and shunting relay 3204. Relay 3203 maintains the shunt around the winding of relay 3207. After an interval 120 of time is measured relays 615 and 616 operate in succession and relay 640 is shunted 125 130

and released. Relay 640 interrupts the impulse being transmitted over the line whereupon relay 3201 becomes deenergized. Relay 3201 removes ground from conductor 3226 and relay 3203 is unlocked and released. Relay 3203 opens the shunt around the winding of relay 3207 and this last mentioned relay operates in series with relay 3208. Relay 616, in operating, removes ground from conductor 643 and relay 617 becomes deenergized. With relays 617 and 618 released the above traced circuit is closed for shunting relay 620. Relay 620, in releasing, opens the circuit of relay 619. Thus, the stations and thousands designations have been transmitted and the equipment is ready for transmitting impulses representing the hundreds designation.

Relay 620, on releasing, opens the circuit of relays 621 and 821, whereupon these latter relays become deenergized. Relay 821 disassociates the impulse circuit from the thousands register 800. With relays 617, 618 and 619 released, the relay 620 is immediately energized. Relay 620 completes a circuit from ground through its outer right contact, contact of relay 621, middle left back contact of relay 613, conductor 626, inner left front contact of relay 603, thence as traced over conductors 627 and 628 through the outer right front contact of relay 1006, conductor 1016 through the outer left back contact of relay 623, outer left front contact of relay 603, outer right back contact of relay 623, conductor 651, outer right front contact of relay 820, outer right back contact of relay 822, winding of relay 823 to battery. Relay 823 operates and closes a holding circuit from battery through its winding and inner lower contact, conductor 1012 through the winding of relay 621, to ground at the contact of relay 620. Relay 621 being shunted remains inert until the shunt is removed by the operation of relay 622.

During the period that relays 615 and 616 are undergoing release and while relay 640 is deenergized, a circuit is completed from ground over conductors 638 and 639, normal contacts of relay 640, over the ring side of the line returning by way of the tip side of the line to the normal contacts of relay 640, left back contact of relay 618, conductor 641, outermost right contact of relay 614, right front contact of relay 622, outermost right back contact of relay 613, conductor 650, inner left front contact of relay 820, inner left back contact of relay 822, inner right contact of relay 810, conductor 847, high resistance 763 to battery. In response to this impulse the relay 3200 operates and closes a circuit from ground over conductor 3225, contact of relay 3200, left back contact of relay 3204, left front contacts of relays 3206

and 3208, outer left back contact of relay 3210, conductor 3230, left winding of relay 3304 to battery. Relay 3304 operates and locks through both its windings and inner right contact to ground over conductor 3318. 70 After relays 615 and 616 have released relay 618 operates, as explained. Also the relay 619 retracts its armatures. When relay 616 becomes operated following the operation of relay 615, the above traced circuit is closed 75 for the energization of relay 640. Relay 640 interrupts the impulse and causes the de-energization of relay 3200. When relay 619 operates a circuit is closed over the grounded conductor 507, middle right contact of relay 80 619, thence over conductor 645, as traced, through the lowermost contact of relay 823, winding of relay 822 to battery. Relay 822 operates and locks independently through its inner right contact to the grounded conductor 85 737.

During the succeeding period while relays 615 and 616 are energizing in succession and while the reversing relay 640 is operated, a circuit is traceable from ground 90 over conductors 638 and 639, front contact of relay 640, over the tip side of the line and returning over the ring side of the line through the front contact of relay 640, conductor 646, outermost left contact of relay 95 640, outer right back contact of relay 617, conductors 652 and 767, lowermost upper contact of relay 823, inner right front contact of relay 811, conductor 848, low resistance, 764 to battery. Current flowing in this circuit is of the proper polarity to operate relay 3201 and since the low resistance 764 is included, the marginal relay 3202 attracts its armature. Relay 3201 causes the operation of relay 3204 in the manner described. Relay 3204 closes a circuit from battery through the winding of relay 3210, left back contact of relay 3209, left front contact of relay 3207, innermost back front contact of relay 3205, outer right contact 110 of relay 3204, to the grounded conductor 3227. Relay 3210 operates and prepares a circuit from battery through its winding and the winding of relay 3209 in series, inner right front contact of relay 3210, to the 115 grounded conductor 3227. Relay 3209, being shunted, does not operate at this time. Relay 3202 completes a circuit from ground over conductor 3225, contact of said relay, outer right back contact of relay 3203, outermost left contact of relay 3205, inner right front contact of relay 3207, inner right back contact of relay 3209, conductor 3231, left hand winding of relay 3305 to battery. Relay 3305 operates and locks through its 120 windings and inner right contact to ground over conductor 3318.

At the end of the interval the relays 615 and 616 become energized, whereupon relay 617 operates and the reversing relay 640 re- 130

leases. Relay 640 interrupts the impulse being transmitted over the line and relays 3202 and 3201 retract their armatures. Relay 3201 removes ground from conductor 3226 and relay 3203 operates in series with relay 3204. During the following interval while relays 615 and 616 are releasing, no impulse is transmitted over the line since both register relays 812 and 813 of the hundreds register are deenergized. The absence of a circuit for transmitting an impulse during this interval may be verified by inspection. When finally the relays 615 and 616 become deenergized, the previously traced circuit is completed for the energization of relay 640. Also ground is connected to conductor 643 and the relay 618 is shunted and released. Relay 640 reverses the tip and ring conductors of the line and prepares for the transmission of an impulse during the last or fourth period involved in connection with the hundreds digit. This impulse endures while the relays 615 and 616 are operated. The circuit, therefore, may be traced from ground over the conductors 638 and 639 through a front contact of relay 640 over the tip side of the line and returning by way of the ring side of the line through a front contact of relay 640, conductor 646, high resistance 763 to battery. The polarized relay 3201 operates but due to the high resistance in the circuit the marginal relay 3202 remains deenergized. Relay 3201 applies ground potential to conductor 3226 and relay 3204 is shunted and released. The shunt around the relay 3209 is now maintained at the inner right contact of relay 3203. After an interval has expired the relays 615 and 616 operate and relays 640, 619, 620 and 617 become released. Relay 640 terminates the impulse and causes the release of relay 3201. Relay 3201 opens the holding circuit of relay 3203, which latter relay becomes deenergized. Relay 3203 removes the shunt from around the relay 3209 and this relay operates in series with relay 3210. Relay 620, on releasing, opens the holding circuit of relays 621 and 823. Relay 823 releases and disconnects the impulse circuit from the hundreds register 801.

With relays 617, 618 and 619 deenergized, the above traced circuit is completed for relay 620 and this relay operates at once. Relay 620 completes a circuit from ground through its outer right contact, contact of relay 621, thence, as hereinbefore traced, over conductors 627 and 628 through the outer right front contact of relay 1006, conductor 1016, thence by way of conductor 651 through the outer right front contacts of relays 820 and 822, outer right back contact of relay 920, winding of relay 921 to battery. Relay 921 operates and locks in a circuit from battery through its winding and innermost lower contact, conductor 1012 through the winding of relay 621, to ground at the outer right contact of relay 620. Relay 621 is shunted and does not operate until relay 920 is later energized. While relays 615 and 616 are undergoing release, ground potential is connected to the ring side of the line over conductors 638 and 639, but the impulse circuit is not completed since the register relay 902 is deenergized. Therefore, no impulse of current is transferred over the line to the distant office during the first quarter period pertaining to the tens digit. Relays 615 and 616, on releasing, apply ground potential to conductor 643 causing the operation of relay 618, which in turn causes the operation of relay 619. Relay 616 also completes the energizing circuit for relay 640. Relay 619 completes a circuit over the grounded conductor 507 through its middle right front contact, 85 thence over conductor 645, lowermost contact of relay 921, winding of relay 920 to battery. Relay 920 operates and locks through its inner right contact, to the grounded conductor 737. Relay 920, at its outer right back contact, opens the shunt around the winding of relay 621, permitting this latter relay to operate in series with relay 920.

During the period that relays 615 and 616 are again energizing and while relay 640 is in its released condition, a circuit is closed from ground over conductors 638 and 639 as traced, through the front contact of relay 640, over the tip side of the line, through the impulse relays at the distant office, returning over the ring side of the line, through a front contact of relay 640, conductor 646, outermost left contact of relay 640, outer right back contact of relay 617, 105 conductor 652, conductor 767, inner upper contact of relay 921, right contact of register relay 903, conductor 848, low resistance 764 to battery. Polarized relay 3201 operates in response to this impulse and due to the low resistance 764 the marginal relay 3202 is also energized. Relay 3201 completes a circuit from ground over conductor 3225, contact of said relay, conductor 3226, left back contact of relay 3203, the left hand windings of relay 3204 and 3203 to battery. Relay 3204 operates and relay 3203 remains inert. Relay 3202 closes a circuit from ground over conductor 3225, through the contact of said relay, outer right back contact of relay 3203, outermost contact of relay 3205, inner right front contacts of relays 3207 and 3209, inner right back contact of relay 3211, conductor 3232, left hand winding of relay 3309 to battery. Relay 3309 110 operates and locks through its windings and inner right contact to the grounded conductor 3319. Relay 3204, in operating, closes a circuit from battery through the winding of relay 3212, left back contact of relay 3211, 115

120

125

130

- left front contacts of relays 3209, 3207 and 3205 in series, outer right contact of relay 3204, to the grounded conductor 3227. Relay 3212 operates and prepares a circuit from 5 battery through its winding and the winding of relay 3211 in series, innermost right contact of relay 3212, to the grounded conductor 3227. Relay 3211, however, being shunted, does not operate at this time.
- 10 After an interval relays 615 and 616 operate, relay 617 operates and relay 640 releases. Relay 640 interrupts the impulse being transmitted, whereupon relays 3201 and 3202 become deenergized. Relay 3201 removes 15 ground from conductor 3226, permitting relay 3203 to operate in series with relay 3204. During the ensuing interval while relays 615 and 616 are undergoing release, a circuit is partially prepared for the transmission 20 of an impulse over the line but is held opened at the contact of register relay 904. Hence, during the third quarter period measured by the timing relays 615 and 616, no impulse of current is transmitted. At 25 the end of the third period the relays 615 and 616 have released and relay 640 energizes. The release of relay 616 also causes the deenergization of relay 617.
- During the fourth period which is measured 30 by the energization of relays 615 and 616 and with the reversing relay 640 operated, a circuit may be traced from ground over the conductors 638 and 639, through the front contact of relay 640, over the tip side of the line returning over the ring side of the line through the front contact of relay 640, conductor 646, high resistance 763 to battery. In response to this impulse of current the relay 3201 alone is operated. Relay 35 3201 applies ground potential to conductor 3226, whereupon the relay 3204 is shunted and releases. Relay 3211 is held shunted after the release of relay 3204 by a path through the inner right contact of relay 3203.
- 40 When relays 615 and 616 finally operate relay 640 releases and also the relays 618, 619 and 620 are deenergized in the manner explained. Relay 640, in releasing, interrupts the impulse and relay 3201 becomes deenergized, whereupon relay 3203 retracts its 45 armature. Relay 3203 removes the shunt from the winding of relay 3211 and this latter relay operates in series with relay 3212. The apparatus is now in condition for the transmission of impulses representing the units designation.
- With relays 617, 618 and 619 released, the circuit for operating relay 620 is closed and this latter relay becomes energized. Relay 50 620 closes a circuit from ground through its outer right contact, contact of relay 621, thence, as traced, over conductors 626, 627 and 628, through the outer right front contact of relay 1006, conductor 1016, thence over conductor 651, through the outer right front contacts of relays 620, 822 and 920, outer right back contact of relay 922, winding of relay 923 to battery. Relay 923 operates and locks through its inner lower contact over conductor 1012, through the winding of relay 621, to ground at the outer right contact of relay 620. Relay 923 connects the impulse circuit to the units register 901, but relay 621, being shunted, does not operate until after relay 922 is energized. During the interval measured by the release of the timing relays 615 and 616 with relay 640 deenergized, a circuit is closed from ground over conductors 638 and 639, through the normal contact of relay 640, 55 thence over the ring side of the line, returning over the tip side of the line through the normal contact of relay 640, left back contact of relay 618, conductor 641, outermost right contact of relay 614, right front contact of relay 622, outermost right back contact of relay 613, conductor 650, inner left front contacts of relays 820, 822 and 920, inner left back contact of relay 922, right contact of relay 912, conductor 847, high resistance 763 to battery. In response to this impulse of current relay 3200 attracts its armature and completes a circuit from ground over conductor 3225, thence through the contact of said relay, left back contact of relay 3204, left front contacts of relays 3206, 3208, 3210 and 3212, conductor 3233, left hand winding of relay 3312 to battery. Relay 3312 operates and locks through its windings in series and inner right contact to ground over the conductor 3319. When relays 615 and 616 release, relays 618, 619 and 640 become energized. Relay 640 60 interrupts the impulse and causes the deenergization of relay 3200. Relay 619 completes a circuit from ground over conductor 507, middle right contact of relay 619, conductor 645, through the lowermost contact of relay 923, winding of relay 922 to battery. Relay 922 locks through its inner right contact, to ground over conductor 737. Relay 922 opens the shunt around relay 621 and this latter relay energizes in series with relay 923.
- During the succeeding interval while relays 615 and 616 are again operated, a circuit is completed from ground over conductors 638 and 639 as traced, through a front contact of relay 640, over the tip side of the line, returning over the ring side of the line, through a front contact of relay 640, conductor 646, high resistance 763 to battery. Relay 3201 responds to this impulse but due to the high resistance in the circuit relay 3202 remains inert. Relay 3201 applies ground to conductor 3226 causing the operation of relay 3204. Relay 3204 closes a circuit from battery through the winding of relay 3214, inner left contact of relay 3213, left front contacts of relays 3211, 3209, 3207 and 3205 in series, outer right contact of 65 70 75 80 85 90 95 100 105 110 115 120 125 130

relay 3204, to the grounded conductor 3227. Relay 3214 operates and prepares a circuit from battery through its winding and the winding of relay 3213 in series, innermost 5 right contact of relay 3214, to the grounded conductor 3227. Relay 3213, being shunted, however, remains inert for the present. At the end of the interval, relays 615 and 616 operate and cause the operation of relay 10 617. Moreover, relay 616, in operating, releases the relay 640. Relay 640 interrupts the impulse allowing relay 3201 to release. Relay 3201 withdraws ground potential from conductor 3226 and relay 3203 operates 15 in series with relay 3204.

During the next interval while relays 615 and 616 are undergoing release, attempt is made to complete an impulse circuit over the line. This circuit is held opened, however, 20 due to the fact that register relay 914 is de-energized. When relays 615 and 616 are both released, relay 640 operates and relay 618 retracts its armatures.

During the following and last interval 25 while relays 615 and 616 are operating, a circuit may be traced from ground over the conductors 638 and 639, through the front contact of relay 640, over the tip side of the line, returning by way of the ring side of 30 the line, through the front conductor 640, conductor 646, outermost left contact of relay 640, outer right front contact of relay 617, conductor 654, conductor 769, uppermost contact of relay 923, right contact of 35 relay 915, conductor 848, low resistance 764 to battery. Relays 3201 and 3202 operate in response to this impulse. Relay 3201 applies ground potential to conductor 3226, whereupon relay 3204 releases. Relay 3213 40 remains shunted at the contact of relay 3203. Relay 3202 completes a circuit from ground over conductor 3225, contact of said relay, outer right front contact of relay 3203, middle left contact of relay 3205, outer right 45 front contacts of relays 3207, 3209 and 3211, conductor 3234, right hand winding of relay 3315 to battery. Relay 3315 locks through its windings and inner left front contact, to the grounded conductor 3319. After an 50 interval expires relays 615 and 616 operate and relays 640, 619, 620 and 617 become deenergized. Relay 640 interrupts the impulse being transmitted over the line and relays 3201 and 3202 retract their armatures. Relay 3201 removes ground from conductor 3226, permitting relay 3203 to release. Relay 3203 opens the shunt around the winding of relay 3213 and this latter relay operates in series with relay 3214.

Release of the recording sender.

Immediately that relays 619, 618 and 617 become deenergized, the previously traced circuit is closed for the operation of relay 620. Relay 620 completes a circuit from 55

ground through its outer right contact, contact of relay 621, middle left back contact of relay 613, conductor 626, thence, as traced, over conductors 627, 628 and 651, through the outer right front contacts of relays 820, 822, 920 and 922, lowermost contact of relay 923, conductor 940, outer right back contact of relay 602, conductor 655, right front contact of relay 520, conductor 543, thence over conductor 525, through the 70 winding of release relay 412 to battery. Relay 412 operates and, in the manner here-fore explained, opens the circuit of the impulse relay 400 which releases, in turn causing the deenergization of relays 401 and 402, whereby the holding ground potential is removed from the various holding conductors and all energized relays in the recording sender and registers are restored to their normal condition. At the same time 85 the sender is disassociated from the trunk circuit 114 by the release of the sender selector switch 300.

Display of the number before the operator 90 and completion of the connection to the called line.

The numerical record of the wanted subscriber's line has been established on the operator's call indicator mechanism where it 95 causes the illumination of the number lamps to inform the operator as to which of the lines appearing in her position is desired. When relay 3210 operates a circuit is closed from battery through the lamp 3235, right 100 back contact of relay 3236, inner left contact of relay 3210, to ground over conductor 3227. The lamp 3235 burns and advises the operator that the called subscriber's line has no stations suffix. When relay 3212 operates it closes the circuit for relay 3215. Relay 3215 connects battery and ground potential to certain of the conductors leading to the lamp circuits shown in Fig. 33.

Since the thousands digit of the called 110 line is 1, a circuit is completed from battery through the lower right contact of relay 3215, conductor 3237, inner right back contact of relay 3303, left back contact of relay 3301, outer right front contact of 115 relay 3300, lamp 3320, outer left back contact of relay 3303, conductor 3318, conductor 3319 to ground. Since the hundreds digit is 3, a circuit is closed from battery through the upper right contact of relay 3215, conductor 3240, inner right back contact of relay 3307, left front contact of relay 3305, inner left front contact of relay 3304, lamp 3321, inner left back contact of relay 3307, to the grounded conductor 3318. 120 The tens digit being 2, a circuit is established from battery through the outermost right contact of relay 3214, conductor 3241, inner right back contact of relay 3311, left front contact of relay 3309, inner left back 125 contact of relay 3307, to the grounded conductor 3318. The ones digit being 1, a circuit is established from battery through the outermost right contact of relay 3214, conductor 3241, inner right back contact of relay 3311, left front contact of relay 3309, inner left back 130

- contact of relay 3308, lamp 3322, outer right front contact of relay 3309, outer left back contact of relay 3308, outer right back contact of relay 3310, conductor 3324, middle right contact of relay 3214, to ground over conductor 3227. Since the units digit is 6, a circuit is completed from battery through the outer right contact of relay 3213, conductor 3242, inner right front contact of relay 3215, lamp 3323, outer right front contact of relay 3312, left back contact of relay 3313, inner left contact of relay 3315, to ground over conductor 3319.
- Relay 3213, in operating, completes a circuit from ground through its outer left contact, contact of relay 3217, winding of relay 3218 to battery. Relay 3218 operates and opens the circuit of relay 3101. Relay 3101 releases and disconnects the call indicator equipment from the incoming trunk circuit and completes the tip and ring conductors of the trunk through to the repeating coil 3116 in the operator's cord circuit.
- The operator, observing the number displayed on her lamps, seizes the plug 3120 of the cord 3100 and inserts it in the jack 3121 of the called line 3122. The insertion of the plug in the jack completes a circuit from ground through the sleeve relay 3127, sleeve of the jack and plug, winding of relay 3119, outer right contact of relay 3109, contact of relay 3113, inner back contact of relay 3118, winding of relay 3117 to battery. A branch circuit leads through the lamp 3112 but this lamp does not illuminate so long as it is shunted. Another branch of the circuit traced extends through the winding of relay 3118. This relay, however, being shunted by the relay 3113 does not attract its armatures. Relay 3119 also completes a circuit from battery through the upper winding of relay 3110, lowermost front contact of relay 3119 to ground. Relay 3110 operates and opens the holding circuit of relays 3103 and 3221. Relay 3103 opens the circuit of lamp 3111 and this lamp ceases to flash. Relay 3221 removes ground from conductors 3319 and 3225, whereupon all operated relays in the indicator equipment are released.
- Relay 3117 operates in the circuit above traced and completes a ringing circuit as follows: source of ringing current 3128, winding of marginal relay 3113, lower front contact of relay 3117, ring of plug and jack 3120 and 3121, over the loop of the subscriber's line, returning to the tip of the jack and plug, upper front contact of relay 3117 to ground. Relay 3113, being marginal, does not operate until the subscriber removes his receiver from the switchhook. When the called subscriber answers relay 3113 actuates and opens the shunt around the winding of relay 3118. Relay 3118 operates and closes a circuit from battery through its inner front contact and winding, thence through the

winding of relay 3127 as traced. Relay 3117, being shunted, releases its armatures and opens the ringing circuit, whereupon relay 3113 becomes deenergized.

When relay 3118 operates it closes a circuit from ground through its outer contacts, contact of relay 3115, this relay being operated in series with the called subscriber's line, winding of relay 3114 to battery. Relay 3114 operates and at its make-before-break contacts reverses the connection of the tip and ring conductors of the trunk to the windings of relay 3106.

When the recording sender is discharged the circuit of relay 201 is opened and this relay releases extending the tip and ring conductors of the trunk 114 through to the windings of the repeating coil 227. Relay 201, at its outer right front contact, opens the holding circuits of relays 208 and 205. Relay 208, on releasing, completes the tip and ring conductors from the right hand windings of the repeating coil 227 through to the district selector switch 1100. It will be noted that the sender is released and relay 208 becomes deenergized prior to the response of the called subscriber and consequently before relay 3114 has time to operate and reverse the current. During this interval current flows through the windings of relay 3106 over the line through the repeating coil 227 and the windings of the polarized relay 233 in such a direction as not to cause the operation of the relay 233. However, when the called subscriber answers and current is reversed over the line, relay 233 operates and completes a circuit from ground through its contact, winding of relay 229 to battery in case the trunk circuit is equipped for message registration. As has been fully explained hereinbefore, relay 229 determines that the calling subscriber's message register shall be operated when the connection is released. The connection has thus been established and conversation may then take place between calling and called subscribers.

Release of the established connection.

After the conversation has been completed the calling subscriber replaces his receiver on the switchhook causing the deenergization of relay 203. Relay 203 opens the circuit of relay 204, which releases after an interval and brings about the restoration of the line switch 100, district selector switch 1100 and office selector switch 2600. When the connection is broken at the office selector switch, relay 3106 releases and opens the circuit of relay 3109 in the operator's cord circuit. Relay 3109 deenergizes and removes the shunt from the lamp 3112. Lamp 3112 illuminates to notify the operator that connection is no longer required. She, therefore, seizes the plug 3120 and removes it from the jack of the called subscriber's line.

Allotment of trunks at the line switch.

A few words of explanation will now be given concerning the action of the allotter 143 of the line switch 100. As was pointed out hereinbefore, the allotter 143 serves to continually keep an idle trunk allotted for use whenever a call is initiated. Each time a call is put through the allotter advances to 10 find and allot a new idle trunk. Should, however, all trunks in the group leading from the line switch be busy, it is desirable to take a record of this condition provided a subsequent call is initiated and fails. Assuming that all trunks, except one, are busy and a call is initiated, the last trunk being taken into use, relay 147, for example, is operated and a series circuit is completed through the left contacts of all similar relays, conductor 175, winding of relay 140 to battery. Should another call be initiated while all trunks are in a busy condition, relay 135, in operating, completes a circuit from ground over conductor 158, outer right 20 back contact of relay 137, left front contact of relay 135, conductor 176, outer left contact of relay 140, left contact of relay 141, winding of relay 142 to battery. Relay 142 operates and prepares a circuit from battery 25 through its winding and the winding of relay 141 in series, contact of relay 142, to ground at the inner left contact of relay 140. Relay 141, however, is shunted so long as ground potential exists on the conductor 176. When ground is removed from conductor 30 176, relay 141 operates and closes a circuit for the register 177. Register 177 records that a call was initiated at a time when all trunks were busy. Due to the existence of an all-trunk busy condition, the allotter switch 143 is prevented from operating since the circuit of magnet 138 is held opened at the right contact of relay 140.

40 *Special features of the marker mechanisms.*

The common markers are so arranged that in case one of them is associated with the recording sender and the operations fail to proceed within reasonable time, the marker is automatically released and rendered free for association with other senders. Considering the district marker, it 50 will be recalled that when the marker is attached to the recording sender, relay 1201 operates. A circuit may now be traced from ground through the contact of relay 1204, inner right contact of relay 1201, conductor 1234, left back contact of relay 1214, winding of relay 1212 to battery. Relay 1212 operates and closes a circuit from battery through the winding of relay 1213, contact of relay 1212, to ground over conductor 55 1234. Relay 1213 actuates and closes a circuit from battery through the winding of relay 1214, inner front contact of relay 1213, conductor 1234 to ground. Relay 1214 locks through its winding and left front contact to the grounded conductor 70 1234. Relay 1213 opens the circuit of relay 1212, which, being slow, releases its armature after an interval. Relay 1212 opens the circuit of relay 1213, which also, being slow to release, requires an interval of time 75 for retracting its armatures. When relay 1213 releases a circuit is closed from ground over conductor 1234, inner back contact of relay 1213, inner right contact of relay 1214, conductor 1221, winding of relay 1200 to battery. The release relay 1200 operates and causes the restoration of the marker in the manner heretofore explained.

80 While the district marker is undergoing release, a circuit is completed from ground through the contact of relay 1204, conductor 1216, outer back contact of relay 1213, outer right front contact of relay 1214, inner left front contact of relay 1200, conductor 1235, contacts of relay 1501, conductor 1546, winding of relay 511 to battery. Relay 511 operates and locks through its winding and inner left contact to the grounded conductor 90 531. Relay 511 completes a circuit from ground through its inner right contact, conductor 558, lamp 449 to battery. Lamp 449 illuminates to advise the monitoring operator of the existing trouble. Relay 511 may also complete a circuit from ground through its outer right contact to a peg count register. 95

100 Similar time measuring devices are provided in the office and line markers for freeing the markers in case of trouble after they have been associated with the record- 105 ing sender.

110 Relay 2106 of the line marker, and relay 2706 of the office marker, have functions identical to that of the corresponding relay 1205 of the district marker described in detail.

115 What is claimed is:

1. The combination in a telephone system, having a series of selective stages and a plurality of switches at each stage for extending connections, of lines, a selection controlling device for each stage and common to the switches thereat, a recording mechanism operable over one of said lines for recording a designation, and means 120 separate from the connection extended for connecting said recording mechanism with each of said controlling devices to selectively operate a switch at each stage.
2. The combination in a telephone system, 125 having series of selective stages and a plurality of switches at each stage for extending connections, of lines, a selection controlling device for each stage and common to the switches thereat, a recording 130

- mechanism operable over one of said lines for recording a designation, means for connecting said recording mechanism with one of said controlling devices to selectively operate a switch at the corresponding stage, and means separate from the extended connection for connecting the recording mechanism to a succeeding controlling device to operate a switch at the corresponding stage.
3. The combination in a telephone system, having a series of selective stages and a plurality of switches at each stage for extending connections, of lines, a selection controlling device for each stage and common to the switches thereat, a recording mechanism operable over one of said lines for establishing a designation record, and means separate from the connection extended for associating the recording mechanism with said controlling devices in succession to selectively operate a switch at each stage.
4. The combination in a telephone system, having a series of selective stages and a plurality of switches at each stage for extending connections, of lines, a selection controlling device for each stage and common to the switches thereat, a recording mechanism operable over one of said lines for establishing a record, and means separate from the connection being extended for associating the recording mechanism with and disassociating it from each of said controlling devices in succession to selectively operate a switch at each stage.
5. The combination in a telephone system having a series of selective stages and a plurality of switches at each stage, of lines, a selection controlling marker for each stage and common to the switches thereat, a registering mechanism operable over any one of said lines to establish the record of a designation, means for associating the registering mechanism with the marker at one stage for selectively operating a switch at such stage to extend a connection to a succeeding stage, and means separate from the extended connection for associating said mechanism with the marker at said succeeding stage to selectively operate a switch thereat to extend the connection.
6. The combination in a telephone system having a number of selective stages and a plurality of equivalent switches at each stage, of lines, trunks incoming to the switches at a given stage, trunks outgoing from said given stage to the switches of a succeeding stage, said outgoing trunks accessible to all the equivalent switches at said given stage, a marker for each stage common to the switches thereat, a recording mechanism operable over one of said lines, and means separate from said switches for connecting the recording mechanism with each of said markers to selectively operate a switch at each stage to extend a connection over said trunks.
7. The combination in a telephone system having a number of selective stages, of lines, a plurality of switches at each stage for extending connections, selection controlling markers, one for each stage and common to the switches thereat, a registering mechanism, means for associating said mechanism with any line, said mechanism being operated over the line to record a designation, and means separate from the connection extended for connecting the registering mechanism with each of said markers to selectively operate a switch at each stage.
8. The combination in a telephone system having a number of switching stages, of lines, a plurality of switches at each stage for extending connections, selection controlling markers, one for each stage and common to all switches thereat, a recording mechanism, means for extending automatically a calling line to a switch at a given stage, means for extending automatically the calling line to said recording mechanism, said mechanism being operated over the calling line to record a wanted designation, and means separate from the connection extended for connecting the recording mechanism with each of said markers to selectively operate a switch at each stage.
9. The combination in a telephone system having a series of selective switching stages, a plurality of switches at each stage, for extending connections, a selection controlling device for each stage common to all switches thereat, a plurality of recording mechanisms operable by the calling party for recording designations, and means separate from the extended connection for connecting any recording mechanism with each of said controlling devices to selectively operate the switch at each stage.
10. The combination in a telephone system having a number of selective stages and a plurality of switches at each stage for extending connections, selection controlling devices, one for each stage and common to the use of all switches thereat, a plurality of registering mechanisms operable by the calling party, and means apart from the connection extended for associating the particular registering mechanism having a designation thereon first with one and then with another of said devices to selectively operate a switch at each stage.
11. The combination in a telephone system having a series of selective stages and a plurality of switches at each stage for extending connections, of lines, a selection controlling device common to all switches at one of said stages, means for associating the controlling device with any one of the switches to which it is common, a selection controlling device common to the switches

at another stage, a recording mechanism operable over a calling line, and means separate from the extended connection for connecting the recording mechanism with each 6 of said controlling devices to selectively operate a switch at each of the stages.

12. The combination in a telephone system having a number of group selecting stages and a plurality of switches at each stage 10 for extending connections, of lines, a selection controlling device common to the switches at one of said stages, a plurality of recording mechanisms operable over one of said lines to record a designation, means for connecting the controlling device to any one of the switches to which it is common and to any one of said recording mechanisms for selectively operating such switch, a selection controlling device for another stage common to the switches thereat, and means separate from the extended connection for connecting said last controlling device to any one of said recording mechanisms to operate a switch 20 at said last stage.

13. The combination in a telephone system having a number of selective switching stages and a plurality of switches, of each stage for extending connections, of 30 lines, selection controlling devices, one for each stage and common to the switches thereat, a plurality of recording mechanisms operable over a calling line to establish a designation record, and means separate from the extended connection for connecting each 35 controlling device to any one of the corresponding switches and to any one of said recording mechanisms for selectively operating a switch at each stage to extend a connection.

14. In a telephone system, selective switches, a variably operable recording sender for receiving the designation record of a called subscriber's line, a plurality of 45 selection controlling devices, means including a multicontact relay for connecting the sender to one of said devices and for transferring to such device a part of the record on said sender, said device selectively operating one of said switches to extend a connection, and means including a multicontact relay for connecting the sender to another of said devices and for transferring thereto another portion of the record on said sender, 50 said last device selectively operating another of the switches to further extend the connection.

15. In a telephone system, selective switches, a plurality of variably operable recording senders for establishing records, a plurality of selection controlling devices, means individual to each sender for connecting the same to one of said controlling devices and for transferring to such a device a part of the record on the connected 65

70 sender, said device selectively operating one of said switches to extend a connection, and means individual to such sender for connecting the same to another of said devices and for transferring to such other device another portion of said record, said last device selectively operating another of the switches to further extend the connection.

16. In a telephone system having a number of selective stages and a plurality of 75 switches at each stage, groups of circuits accessible to the switches at each stage, selection controlling devices, one for each stage and common to the switches thereat, a recording sender for receiving the record of a wanted 80 designation, means including a multicontact relay for connecting the sender to the controlling device at a given stage and for transferring a part of the record from the sender to such device, a multicontact relay for connecting the controlling device to one of the switches at the corresponding stage, means controlled by said device for operating the connected switch to select a group of circuits, 85 means including a multicontact relay for connecting the sender to the controlling device at a succeeding stage and for transferring another portion of the record to said last device, a multi-contact relay for connecting said last mentioned device to one of the 90 switches at the succeeding stage, and means controlled by the last mentioned device for selectively operating the connected switch to select a group of circuits.

17. In a telephone system having a number of selective stages and a plurality of 95 switches at each stage, groups of circuits accessible to the switches at each stage, selection controlling devices, one for each stage and common to the switches thereat, 100 a plurality of recording senders for receiving the record of the designation, means including multi-contact relays for connecting any desired sender to the controlling device at a given stage and for transferring a part 105 of the record from said sender to such device, multi-contact relays for connecting said device to any one of the switches at the corresponding stage, means controlled by said device for operating the connected 110 switch to select a group of circuits, means including multi-contact relays for connecting said desired sender to the controlling device at a succeeding stage and for transferring to such device another portion of 115 the record, multi-contact relays for connecting said last device to any one of the switches at the succeeding stage, and means controlled by the last mentioned device for operating the connected switch to select a group of circuits.

18. In a telephone system having a number of selective stages with a switch at each stage, selection controlling devices, one for each stage comprising a plurality of regis- 120

- ters and a translator mechanism, a recording sender for receiving the designation record, means for connecting the sender to the controlling device at a given stage and for setting the registers thereof, said registers acting to set said translator, means controlled according to the setting of the translator to selectively operate the switch at the corresponding stage, means for connecting the sender to the controlling device at a succeeding stage, and means controlled by such device to selectively operate the switch at said last stage.
19. In a telephone system having a plurality of selective stages with a plurality of switches at each stage, selection controlling devices, one for each stage, comprising a plurality of registers and a translator mechanism, a recording sender for receiving the record of a designation, means for connecting the sender with the controlling device at a given stage and for transferring to the registers thereof a portion of the record on said sender, said registers acting to set said translator, means controlled according to the setting of the translator to selectively operate any one of the switches at the corresponding stage, means for connecting the sender to the controlling device at a succeeding stage, and means controlled by said later device to selectively operate any one of the switches at said succeeding stage.
20. In a telephone system having a number of selective stages with a plurality of switches at each stage, selection controlling devices, one for each stage comprising registers and a plurality of multi-contact relays, a recording sender for receiving a designation record, means for connecting the sender to the controlling device at a given stage and for setting the registers thereof, said registers acting to select and operate said multi-contact relays, means controlled in accordance with the operated multi-contact relays to selectively operate any one of the switches of the corresponding stage, means for connecting the sender to the controlling device at a succeeding stage, and means controlled by such device to selectively operate a switch at said last mentioned stage.
21. In a telephone system having a number of selective stages with a plurality of switches at each stage, selection controlling devices, one for each stage comprising a plurality of registers and a plurality of sets of multi-contact relays, a recording sender for receiving a designation record, means for connecting the sender to the controlling device at a given stage and for setting the registers thereof, said registers acting to select and operate a multi-contact relay in each of said sets, means controlled jointly by the operation of the multi-contact relays for selectively operating any one of the switches at the corresponding stage to extend a connection, means for connecting the sender to a controlling device at another stage, and means controlled by such device to selectively operate any one of the switches at said last mentioned stage.
22. In a telephone system arranged to establish different classes of connections, a selective switch, a circuit incoming to said switch, means for extending a connection to said switch over said circuit, a selection controlling mechanism for receiving the record of the designation, means controlled by said mechanism for selectively operating said switch to further extend said connection, and means controlled through contacts of said switch by said mechanism for determining the characteristics of said circuit according to the class of the call.
23. In a telephone system arranged to establish different classes of connections, a plurality of selective switches, a trunk incoming to each of said switches, means for extending a connection to a given switch over a corresponding trunk, a selection controlling mechanism common to all switches for receiving the record of the designation, means controlled by said mechanism for selectively operating said given switch to further extend the said connection, and means controlled through the contacts of said switch by said mechanism for determining the characteristics of the trunk incoming to such switch according to the class of the call.
24. In a telephone system arranged to establish different classes of connections, a plurality of selective switches, a trunk incoming to each of said switches, means for extending a connection to a given switch over the corresponding trunk, a selection controlling mechanism common to all switches for receiving the record of a designation, means for connecting said mechanism to said given switch when the connection has been extended thereto, means controlled by said mechanism for selectively operating such switch to further extend the connection, and means controlled through the contacts of said switch by said mechanism for determining the characteristics of the trunk circuit leading to said given switch depending upon the class of the call.
25. In a telephone system arranged to establish different classes of connections, a selective switch, a trunk incoming to said switch, a repeating coil in said trunk, means for extending a connection to said switch over said trunk, a selection controlling mechanism for receiving the record of a designation, means controlled by said mechanism for selectively operating said switch to further extend said trunk, and means controlled

- through contacts of said switch for varying the number of effective turns in said repeating coil according to the class of the call.
26. In a telephone system arranged for 5 different classes of connections, incoming lines, outgoing lines, a switch having intermediate links for interconnecting the incoming and outgoing lines, means for extending a connection to said switch over one of said 10 incoming lines, means for selectively operating said switch to connect the incoming line to one of said outgoing lines, an auxiliary link for said switch, and means controlled over said auxiliary link for determining the 15 characteristics of the incoming line according to the class of the call.
27. In a telephone system arranged for 20 different classes of connections, incoming lines, outgoing lines, a switch having intermediate links for interconnecting the incoming and outgoing lines, means for extending a connection to said switch over one of said incoming lines, means for selectively operating said switch to connect the incoming line 25 to one of said outgoing lines, an auxiliary link for said switch actuated whenever a connection is extended to said switch over an incoming line, and means controlled over said auxiliary link for determining the talk- 30 ing characteristics of the incoming line according to the class of connection.
28. In a telephone exchange system, a selective switch, an incoming line, outgoing lines, said switch having a plurality of intermediate links for connecting the incoming line to the outgoing lines, and a separate link common to said intermediate links for testing the condition of the outgoing lines.
29. In a telephone system, a selective switch, an incoming line, outgoing lines, said switch having a plurality of groups of intermediate link circuits for connecting the incoming line to the outgoing lines, and a separate link common to the intermediate links for testing the condition of the outgoing lines.
30. In a telephone exchange system, a selective switch, an incoming line, a number 50 of groups of outgoing lines, said switch having a group of intermediate links for each group of outgoing lines for interconnecting the incoming line with said outgoing lines, and a separate link common to all links in each group of intermediate links for testing the condition of the corresponding outgoing lines.
31. In a telephone exchange system, a selective switch, an incoming line, outgoing 55 lines, said switch having a plurality of intermediate links for connecting the incoming line to the outgoing lines, means for selecting an idle intermediate link without establishing the connection, a separate link common to the intermediate links for testing 65 the condition of the outgoing lines, and means for thereupon establishing the connection if the tested line is idle.
32. In a telephone exchange system, a selective switch, a plurality of incoming lines, outgoing lines, said switch having a number of intermediate link circuits for connecting the incoming lines to the outgoing lines, and a separate link common to said intermediate links for testing the condition of the 70 outgoing lines.
33. In a telephone system, a selective switch, a plurality of incoming lines, outgoing lines arranged in groups, said switch having a plurality of intermediate links for connecting any incoming line to any outgoing line, and a separate link common to said intermediate links for testing the busy and idle conditions of the outgoing lines.
34. In a telephone exchange system, a selective switch, an incoming line, outgoing lines, said switch having a plurality of intermediate links for connecting the incoming line to the outgoing lines, a selection controlling mechanism for operating said switch, and a separate link common to said intermediate links for testing the condition of the outgoing lines.
35. In a telephone system, a plurality of 85 selective switches, lines incoming to said switches, lines outgoing from said switches, said switches having intermediate links for connecting the incoming lines to the outgoing lines, a selection controlling mechanism common to all of said switches for 90 operating the same, and a separate link for each switch common to the intermediate links thereon for testing the condition of the outgoing lines.
36. In a telephone system, a plurality of 95 selective switches, lines incoming to said switches, lines outgoing from said switches, each switch having a plurality of intermediate links for interconnecting said incoming and outgoing lines, a selection controlling mechanism common to all switches for 100 controlling the selective operation thereof, multi-contact relays, one for each switch for connecting said switch to the selection controlling mechanism, and a separate link for each switch common to the intermediate links thereof for testing the condition of the outgoing lines.
37. In a telephone system, a number of 105 selective switches, means for extending a connection to any one of said switches, a group of trunks accessible to each of said switches, means common to all switches for testing said trunks in succession, and means for commencing the testing operation with 110 a different trunk in the group for each of the switches to which the connection is extended.
- 120
- 125

38. In a telephone system, a number of selective switches, means for extending a connection to any one of said switches, a group of trunks accessible to each of said switches, a testing mechanism common to all switches for testing said trunks in succession, and means controlled according to the switch to which the connection is extended for determining the trunk first to be tested.
39. In a telephone system, a number of selective switches, means for extending a connection to any one of said switches, a number of groups of trunks each divided into subgroups and accessible to all switches, means common to all switches for testing said trunks in succession, and means controlled according to the switch to which a connection is extended for determining the subgroup of a group of trunks first to be tested.
40. The combination in a telephone system having groups of trunks of a number of selective switches, each switch having a plurality of switching members serving respectively said groups or trunks, each member adapted to establish co-existing connections over the trunks of the corresponding group, selection controlling devices, a recording sender for receiving a designation record, and means for connecting the sender in succession with said controlling devices, each device selectively operating a switch to build up a connection.
41. The combination in a telephone system having groups of trunks of a plurality of selective switches, each having a plurality of switching members serving respectively said groups of trunks, each member adapted to establish co-existing connections over the trunks in the corresponding group, selection controlling devices, each serving a plurality of such switches, a recording sender for receiving a designation record, and means for connecting the sender in suc-
- sion with said controlling devices, each device selectively operating one of the switches to which it is connected for building up a connection.
42. The combination in a telephone system having groups of trunks of a number of selective switches, each having a plurality of switching bars individual respectively to different groups of trunks, each bar adapted to establish a number of co-existing connections over the trunks of the corresponding groups, selection controlling devices, each serving a plurality of such switches, a recording sender for receiving a designation, means for connecting the sender in succession with said controlling devices, and means for connecting each controlling device to any one of the switches to which it is individual, each controlling device selectively operating the switch to which it is connected for building up a connection.
43. The combination in a telephone system of selective switches, a marker for controlling said switches, a plurality of senders connectible to said marker and arranged in groups, and means when senders in different groups are attempting connection to the marker for connecting said senders to such marker in a definite sequence.
44. The combination in a telephone system of selective switches and a marker for controlling said switches, a plurality of senders arranged in groups and connectible to said marker, and means for preventing a second sender in any group from being connected to the marker until a sender in each remaining group having a sender seeking connection has been connected to said marker.

In witness whereof, I hereunto subscribe my name this 17th day of October A. D., 1922.

SAMUEL B. WILLIAMS, JR.

DISCLAIMER.

1,517,331.—*Samuel B. Williams, jr., Brooklyn, N. Y.* TELEPHONE-EXCHANGE SYSTEMS. Patent dated December 2, 1924. Disclaimer filed May 5, 1926, by the patentee, assignee, *Western Electric Company, Incorporated*, consenting.

Hereby enters this disclaimer to the said claims of said Letters Patent which are in the following words, to wit:

“28. In a telephone exchange system, a selective switch, an incoming line, outgoing lines, said switch, having a plurality of intermediate links for connecting the incoming line to the outgoing lines, and a separate link common to said intermediate links for testing the condition of the outgoing lines.

“31. In a telephone exchange system, a selective switch, an incoming line, outgoing lines, said switch having a plurality of intermediate links for connecting the incoming line to the outgoing lines, means for selecting an idle intermediate link without establishing the connection, a separate link common to the intermediate links for testing the condition of the outgoing lines, and means for thereupon establishing the connection if the tested line is idle.

“32. In a telephone exchange system, a selective switch, a plurality of incoming lines, outgoing lines, said switch having a number of intermediate link circuits for connecting the incoming lines to the outgoing lines, and a separate link common to said intermediate links for testing the condition of the outgoing lines.

“33. In a telephone system, a selective switch, a plurality of incoming lines, outgoing lines arranged in groups, said switch having a plurality of intermediate links for connecting any incoming line to any outgoing line, and a separate link common to said intermediate links for testing the busy and idle conditions of the outgoing lines.

“34. In a telephone exchange system, a selective switch, an incoming line, outgoing lines, said switch having a plurality of intermediate links for connecting the incoming lines to the outgoing lines, a selection controlling mechanism for operating said switch, and a separate link common to said intermediate links for testing the condition of the outgoing lines.”

DISCLAIMER.

1,517,331.—*Samuel B. Williams, jr., Brooklyn, N. Y. TELEPHONE-EXCHANGE SYSTEM. Patent dated December 2, 1924. Disclaimer filed April 4, 1928, by the assignee, Western Electric Company, Incorporated.*

Hereby enters this disclaimer to that part of the claims in said specification which are in the following words to wit:

“28. In a telephone exchange system, a selective switch, an incoming line, outgoing lines, said switch having a plurality of intermediate links for connecting the incoming line to the outgoing lines, and a separate link common to said intermediate links for testing the condition of the outgoing lines.”

“31. In a telephone exchange system, a selective switch, an incoming line, outgoing lines, said switch having a plurality of intermediate links for connecting the incoming line to the outgoing lines, means for selecting an idle intermediate link without establishing the connection, a separate link common to the intermediate links for testing the condition of the outgoing lines, and means for thereupon establishing the connection if the tested line is idle.

“32. In a telephone exchange system, a selective switch, a plurality of incoming lines, outgoing lines, said switch having a number of intermediate link circuits for connecting the incoming lines to the outgoing lines, and a separate link common to said intermediate links for testing the condition of the outgoing lines.

“33. In a telephone system, a selective switch, a plurality of incoming lines, outgoing lines arranged in groups, said switch having a plurality of intermediate links for connecting any incoming line to any outgoing line, and a separate link common to said intermediate links for testing the busy and idle conditions of the outgoing lines.

“34. In a telephone exchange system, a selective switch, an incoming line, outgoing lines, said switch having a plurality of intermediate links for connecting the incoming line to the outgoing lines, a selection controlling mechanism for operating said switch, and a separate link common to said intermediate links for testing the condition of the outgoing lines.”
